UNITED STATES PATENT OFFICE

2,155,176

TELEPHONE SYSTEM

John Wicks, Oak Park, Ill., assignor to Associated Electric Laboratories, Inc., Chicago, Ill., a corporation of Delaware

Application November 7, 1936, Serial No. 109,671

23 Claims. (Cl. 179—27)

The present invention relates to telephone systems but is concerned more particularly with telephone systems wherein both toll connections and local connections are established through 5 the medium of automatic switches.

The object of the invention is the production of a new and improved telephone system wherein toll calls passing through the switchboard of a toll operator in an automatic exchange may 10 be completed by way of toll line and through automatic switches located in a distant exchange to the desired line in the distant exchange, while the toll operator performs the same sort of controlling operations in extending a call through 15 a distant exchange as she does when setting up a connection to a local line, and receives uniform supervision in the two cases.

An additional object is the production of new and improved circuit arrangements having to 20 do with the efficient and satisfactory handling of switch-control and supervisory impulses of voice-frequency current.

A further object of the invention is the production of suitable circuit arrangements for 25 enabling automatic long distance calls to be established interchangeably between automatic exchanges wherein the automatic switches are operated according to different systems of control.

30 The following patents are cited as showing the state of the art pertaining to the control of automatic switches and the supervision of connections by means of alternating-current impulses transmitted over the talking channel: 33 1,573,991, P. B. Murphy, February 23, 1926; 1,606,316, P. B. Murphy, November 9, 1926; 1,893,691, John Wicks, January 10, 1933; 1,932,-235, Smith et al., October 24, 1933; 2,040,637, John Wicks, May 12, 1936.

40 Outstanding features of improvement over the disclosures in these patents may be enumerated as follows:

1. An audible carrier frequency modulated at a single modulation frequency serves to provide 45 a common channel over a toll line for the transmission of the seizing pulse, ring-control pulses, supervisory pulses, and a release pulse. The said carrier frequency is pulse-modulated at a lower frequency in the transmission of the 50 switch-controlling digit pulses.

2. The calling toll operator receives flashing-lamp supervision indicative of an overflow busy condition at a trunk group and a flashing at a 55 distinctively different rate indicative of a busy called subscriber line, in addition to being able

to hear the transmitted actuation pulses of modulated carrier frequency in the event that she has her telephone connected.

3. When the toll operator actuates switching apparatus in a distant exchange to seize a toll line extending to a third automatic exchange, the impulse repeaters of the intermediate exchange are disabled from repeating digit pulses and supervisory pulses, while the talking circuit is closed through to the third exchange to permit 10 the outgoing repeater in the first exchange to cooperate directly with the incoming repeater in the third exchange in the further transmission of digit, supervisory, and ring-control pulses.

4. In order to avoid the switching operations 15 which take place in the terminating exchange, as the automatic switches respond in building up the connection, from affecting the responding toll-line apparatus, the talking conductors are maintained open in the incoming and outgoing repeaters until all of the digit pulses have been transmitted, whereupon they are closed through upon the receipt of a line-supervisory condition from the switch train in the called exchange, when connection is made with the 25 called line.

5. When a connection is set up over a toll line between two toll boards, the operation of the ringing key at either toll board serves to transmit a pulse of modulated carrier current to signal the other operator.

6. When an operator sets up a connection through a second exchange to a third exchange operated on a manual basis, the incoming repeater in the intermediate exchange transmits 35 a line supervisory pulse back to the originating exchange to effect closure of the talking circuit following which it transmits a pulse indicative of answer supervision to maintain the calling supervisory lamp dark in the originating exchange.

GENERAL DESCRIPTION

It has been chosen to illustrate the invention as applied in meeting the specific requirements 45 of the system of toll lines interconnecting a group of cities in Brazil, South America, and including the cities of Sao Paulo and Rio de Janeiro. Since they are the two principal cities of Brazil, Sao Paulo and Rio de Janeiro each 50 serves as a concentration point for toll traffic. Moreover, since the cities are within about two hundred miles of each other, considerable toll traffic passes between them. The relative locations of the cities of Sao Paulo, Rio de Janeiro, 55

and certain nearby cities are indicated generally in Fig. 1 of the accompanying drawings.

Referring now to the drawings, Fig. 1, as mentioned above, is a map showing the relative locations of cities containing the equipment embodying the new toll system;

Fig. 2 is a trunking diagram illustrating the local and toll trunking arrangements in the Sao Paulo and Rio de Janeiro exchanges;

10 Figs. 3-21 are circuit diagrams;

Fig. 22 shows the way in which Figs. 3-21 should be arranged in order that they be understood best.

A. THE TOLL-LINE ROUTES

15 Referring now particularly to Fig. 1, the toll-line routes between the exchanges indicated therein will be discussed. The toll line TL¹ is one of a group of toll lines extending between Jundiah and Sao Paulo. The encircled number 5 associated with the toll line TL¹ indicates that this toll line is one of a group of five.

The toll line TL² is one of a group extending between Campinas and Sao Paulo. The encircled number 15 adjacent toll line TL² indicates that this toll line is one of a group of 15.

The toll line TL³ is one of a group extending between Santos and Sao Paulo. The encircled number 45 adjacent this toll line indicates that there are 45 toll lines in this group. This relatively large number is made necessary by the fact that there is a heavy toll traffic between Santos and Sao Paulo because of the relative nearness of Santos to Sao Paulo and the comparatively large number of telephone subscribers in Santos.

35 The toll line TL⁴ is one of a group of toll lines extending between the cities of Sao Paulo and Rio de Janeiro. This toll line is one of a group of 25, as is indicated by the adjacent encircled number 25.

40 The toll line TL⁵ is one of a group of toll lines extending between Rio de Janeiro and Campos. The encircled number 10 indicates that this toll line is one of a group of 10.

The Campos, Sao Paulo, and Santos exchanges 45 are of the automatic type using the Strowger vertical-and-rotary switches which respond directly to generated digit impulses, while the Rio de Janeiro exchange is of the automatic type using rotary switches which are positioned by 50 the reverte system of impulsion in the well-known manner common to the so-called power-driven automatic systems. The exchanges in Jundiah and Campos are of the usual manual type.

55 Through the medium of controlling arrangements herein disclosed, toll calls for Rio de Janeiro arriving at or originated in Sao Paulo may be completed to the desired line in Rio de Janeiro through the automatic switches in Rio de Janeiro responsive to the transmission of controlling voice-frequency impulses transmitted over a toll line such as TL⁴. Similarly, toll calls arriving at or originated in Rio de Janeiro may be completed to a desired line in Sao Paulo 60 through the automatic switches in Sao Paulo responsive to the transmission of voice-frequency impulses over a toll line such as TL⁴. In addition, voice-frequency impulses (referred to hereinafter as dial pulses) may be transmitted over 65 a toll line such as TL² in either direction to enable an operator at Campinas to control automatic switches in Sao Paulo to complete a toll connection and to enable an operator in Sao Paulo to complete a toll connection through the 70 75 automatic switches in Campinas.

Similarly, dial pulses may be transmitted in either direction over any one of the toll lines in the group including TL³ to enable the Sao Paulo toll operator to set up a connection automatically to a desired line in Santos and to enable the Santos toll operator to set up a desired connection automatically to a called line in Sao Paulo. The automatic switching apparatus in Sao Paulo is so arranged (as will be hereinafter disclosed) that the toll operator in either Campinas, Santos, or Rio de Janeiro may forward toll calls automatically through Sao Paulo as a switching center to either of the other two exchanges named and transmit further pulses to the called exchange to cause the connection to be completed automatically therein. For example, the toll operator at Campinas may transmit dial pulses over a toll line such as TL² to cause switching apparatus in Sao Paulo to select an idle toll line such as TL⁴ extending to Rio de Janeiro, following which additional dial pulses transmitted from the toll board in Campinas pass over the toll lines TL² and TL⁴ to cause automatic switching apparatus in Rio de Janeiro to extend a toll connection to the desired line. 25

B. THE TRUNKING LAYOUT IN SAO PAULO

Referring now particularly to Fig. 2, consisting of two parts, the trunking layout in the Sao Paulo and Rio de Janeiro exchanges will be explained. Fig. 2, part 1, shows the trunking layout in the Sao Paulo exchange, while Fig. 2, part 2, shows the trunking layout in the Rio de Janeiro exchange.

The Sao Paulo exchange employs a five-digit numbering system, of which the first digit designates the desired office of the exchange while the remaining four digits designate the desired line in the office. The offices equipped are the second, third, fifth, and eighth, corresponding to the second, third, fifth, and eighth levels of office selectors, such as the office selector OS-1 in office 8, indicated at the lower part of Fig. 2, part 1. Each of the offices is housed in a separate office building, and the toll office is accommodated in a still further building more conveniently located with respect to serving as a terminus for the inter-city toll lines. Each of the illustrated Strowger switches in the Sao Paulo exchange is indicated by a rectangle representative of the relays and mechanical equipment, below which the contact bank is indicated by ten short, heavy, horizontal lines, each of which indicates a separate level of the bank.

The office selector OS-1 is one of a group of first selectors provided in office 8 for responding to the first digit dialled by calling local subscribers to select the office indicated thereby. Each of the office selectors such as OS-1 is paired with a line finder such as finder F-2. These finders are controlled in groups by the usual automatic starting means. When a call is initiated at a substation, such as A, a finder such as the finder F-2 first searches for the level containing the calling line and then searches for the contact set in the level in which the line terminates. When the line is found it is extended to the office selector OS-1. When the first digit is dialled, the office selector OS-1 raises its wipers (not shown) opposite the desired level of bank contacts and rotates them in search of an idle thousands selector in the called office. If the call originated at substation A is a local call, the first digit dialled is the digit 8, resulting in the office selector OS-1 extending the calling line 75

to an idle local thousands selector such as the thousands selector MS.

Of the tens groups of hundreds selectors accessible to the thousands selector MS, the hundreds 5 selector HS—1 is illustrative of the 4th group. The fact that this selector is one of a group seized when the first digit 8 is followed by the digit 4 is indicated by the number 84 placed within the rectangle representing the selector. The 10 hundred selectors in the group containing the selector HS—1 have access in common to ten groups of connectors, one of which is the group containing the connector C—1, one of the connectors in hundreds group 841.

15 Each of the connectors in the group including connector C—1 has access to a maximum of 100 subscriber lines, one of which is the line of substation A. If the two final digits of a number dialled after the connector C—1 has been reached 20 are "6" and "1", the line of sub-station A is the one selected, as the number of this line is 84161, as indicated.

The foregoing description of the trunking layout in office 8 of Sao Paulo reveals that the trunking arrangement used there is the standard and well-known trunking system laid out according to the decimal numbering system, commonly used in exchanges employing the step-by-step Strowger switches.

30 The toll thousand selector TMS is one of a group of selectors provided in office 8 for handling calls incoming to office 8 from the toll office. This selector has access to ten groups of toll hundred selectors, of which the toll hundred selector THS in selector group 84 is representative of the fourth group. On its various levels, the toll hundreds selectors have access to connectors which are provided solely for the completion of toll calls and also to combination toll-and-local 35 connectors. The connector C1 is one of the combination toll-and-local connectors. The arrangement here discussed is, of course, well known, the trunking system through toll calls are extended from toll lines to called subscriber lines being what is commonly referred to as the toll-service 40 trunking system.

Toll calls are originated by the subscribers responsive to the dialing of the digit "0". The office 50 selectors such as OS—1 are provided with trunks extending from the tenth level thereof to the toll board, one of which is the trunk T1 extending by way of the trunk circuit TC to the combined line and recording circuit CLR—1, associated with the toll board.

An automatic toll board is employed at Sao 55 Paulo. This toll board is represented by the cord circuit CC—1 at one of the positions of the toll board, together with the associated position equipment PE—1. Each of the cord circuits terminates at one end in a finder such as F—1 and at the other end in a toll first selector such as TFS—1. The finder F—1 receives calls over manual toll lines such as a toll line TL—1, Figs. 1 and 2, and from local trunks such as 60 trunk T—1 incoming from the 10th level of the first selectors in the various offices of the Sao Paulo exchange.

The toll first selector TFS—1, in common with other toll first selectors associated with other cord circuits, has access to toll-line selectors such as TLS—1, which toll line selectors have access by way of trunk such as T—2 to the manual toll lines, such as TL—1. On another of its 70 levels, the toll first selector TFS—1 has access to toll office selector such as TOS—1, which toll

office selector has access to groups of trunks extending to the various offices of the Sao Paulo exchange. One of these trunks, reached from the eighth level of selector TOS—1, extends to the incoming toll thousand selector TMS in 5 office 8.

On another of its levels, toll first selector TFS—1 has access to toll-line selectors such as TLS—2 which have access to the automatic or dial toll lines, such as TL—3, TL—4, and TL—2, 10 extending to the Santos, Rio de Janeiro, and Campinas exchanges. In order to enable the rather expensive toll lines to be used efficiently, the toll line selector TLS—2 is a level-hunting selector, and adjacent levels are assigned to the 15 group of toll lines extending to a given exchange. On a call to any one of the exchanges accessible to the selector TLS—2, the wipers of the selector are directed to the lowest level in which trunk lines are accessible, and the selector is automatically given an additional vertical movement to bring it successively into association with one or more higher levels in the group in the event that all toll trunks reached by way of the level first selected are in use. It is to be noted that 20 the digit 4 is transmitted to the toll first selector TFS—1 to cause it to select a selector in the group represented by the toll line selector TLS—2. If this first digit 4 is followed by the digit 1, the call is directed to Santos by way of one of the 25 first five levels of bank contacts; if the first digit 4 is followed by a second digit 6 the call is directed by way of one of the levels 6—8 to the Rio de Janeiro exchange; and if the first digit 4 is followed by a second digit 9 the call is directed 30 by way of one of the levels 9 and 0 of the selector TLS—2 to the Campinas exchange.

In order to enable calls incoming to the Sao 35 Paulo exchange from Campinas, Rio de Janeiro, and Santos to be handled automatically responsive to dial pulses received over the toll line in use, each of the toll lines incoming from the exchanges mentioned is provided with an incoming selector. The selectors TFS—2, TFS—3, and TFS—4 are assigned to the toll lines TLS—2, 40 TLS—4, and TLS—3, respectively. These selectors may have their banks connected in multiple with that of toll first selector TFS—1, whereby digits received over these toll lines have the same trunking effect as digits received from the cord circuit 45 CC—1 at the Sao Paulo toll board.

It will be understood, of course, that the trunking layout of the Sao Paulo exchange indicated in Fig. 2, part 1, is incomplete and that the layout given shows only sufficient of the equipment to 55 enable the invention to be understood. For example, other positions of the toll board may be equipped with cord circuits, each of which terminates at each end in a first selector similar to the first selector TFS—1 to enable operators at such 60 positions to complete delayed calls or point-to-point calls. In addition, one of the levels of the incoming toll first selectors may be set aside for the trunking of calls to the toll board whereby a toll operator at Sao Paulo may be called from a distant automatic exchange over a toll line and asked to take over the setting up of a connection to a busy Sao Paulo line and thereby avoid the tying up of a toll line unduly while waiting for the busy Sao Paulo line to become idle.

C. THE TRUNKING LAYOUT IN RIO DE JANEIRO

Referring now particularly to Fig. 2, part 2, the trunking layout in the Rio de Janeiro exchange will be explained.

As previously mentioned, the automatic switches in the Rio de Janeiro exchange are of the revertively-controlled, power-driven, rotary type. As is well known, each of these switches has a bank of two hundred contact sets, arranged in ten levels of twenty contact sets each, and a separate brush set is provided for each level, with means for selectively tripping the brush sets. The diagrammatically illustrated rotary-type switches comprise toll office selector TOS-2, office selector OS-2, thousands selector MS-2, hundreds selector HS-2, and the final selector, or connector, C-2.

As is indicated by the number (484,161) assigned to the line of substation B, six-digit subscriber numbers are used in the Rio de Janeiro exchange. The exchange is divided into eight offices each having a maximum capacity of 20,000 lines, there being two call numbers assigned to each office, each call number indexing 10,000 lines. For example, the call numbers 28 and 48 are assigned to the office terminating the line of substation B, as is indicated by the numbers 28 and 48 placed within the rectangle indicating the thousands selector MS-2.

In the Rio de Janeiro exchange, it is assumed that the toll board is located in the same building with one of the offices of the exchange, and the showing is made accordingly. The finder F-1 is one of the finders which has access to the line of substation B and which may interconnect this line with office selector OS-2 when a call is originated at substation B. The register sender RS-3 is one of a group of subscriber senders for handling calls originated on subscriber lines. This sender may be connected to the link consisting of the office selector OS-2 and the finder F-1 by means of the link finder F-6 to receive the digits dialled by the subscriber at substation B, for example, and to control the positioning of the switches.

The register senders are arranged to effect the desired number translation, in addition to exercising the necessary revertive control over the switches. For example, in a call to line 484,161, the first digit 4 indexes the "4" 10,000-line group in the called office as compared with the "2" 10,000-line group indexed by a first digit 2. The second digit 8 determines the office, as the same level of the office selector is reached responsive to the digit combination 48 as is reached responsive to the digit combination 28.

From the thousands selector MS-2 in the called office, the call is directed to a hundreds selector, such as HS-2, if the digit combination 48 is followed by either of the digits 4 and 5.

From the hundreds selector HS-2, the call is directed to a connector such as C-2 if the digit combination 484 is followed by either of the digits 0 and 1.

In the connector C-2, the left-hand section of the 200-line bank is used to complete the call in accordance with the tens and units digits if the connector is reached by the dialling of the digit combination 4840, while if it is reached by the dialling of the digit combination 4841, the right-hand bank section is used.

The connector C-2 responds to the final two digits 6 and 1 to complete connection with line 484,161, the line of substation B.

In the event that a call arriving at the office selector OS-2 is intended for some other office, the office selector is caused to extend the connection over the appropriate lead to the desired

other office, the control being suitably exercised by a register sender such as RS-3.

The manual toll board in Rio de Janeiro is indicated by means of the cord circuit CC-2 and associated position equipment PE-2 at one of the positions thereof, together with jacks J-1 to J-5. The jack J-3 is associated by way of the toll line circuit TLC-2 with the toll line TL-5 extending between Rio de Janeiro and Campos; the jack J-4 is associated with the CLR (combined line and recording) trunk incoming from a level of the office selector by way of the CLR circuit CLR-2; jacks J-1 and J-2 are, respectively, incoming and outgoing jacks associated with the toll line TL-4 between Sao Paulo and Rio de Janeiro; and the jack J-5 is associated through the line circuit LC-1 with the finder F-4. When the toll operator desires to complete a call through the toll-service trunking system to the line of a Rio de Janeiro subscriber, she may make connection with the jack J-5 and cause a finder such as F-4 to extend connection to a toll office selector such as TOS-2. Having its contact bank connected in multiple relationship with the banks of the office selectors such as OS-2, the toll office selector TOS-2 is able to extend connections by way of the regular switch train of combination toll-and-local switches to the lines of the subscribers.

The register sender RS-2 is generally similar to the subscriber register sender RS-3, except that the register sender RS-2 is arranged to be controlled by a set of digit keys, one of which is included in the position equipment PE-2, instead of by means of dial impulses received over a subscriber line. The finder F-5 is provided to connect the register sender RS-2 to any one of the first-selector toll links to enable it to receive a number and to direct the operation of the rotary switches.

The Rio de Janeiro and Sao Paulo exchanges were originally installed with the toll lines such as TL-4 operated on a manual basis. Sufficient of the senders such as RS-2 were provided to handle the calls on this basis. Upon the conversion of the toll lines to automatic operation, one jack such as J-5, at the Rio de Janeiro toll board was removed from manual service for each toll line, and the three conductors corresponding thereto were connected to an impulse repeater such as IR-4 of one of the toll lines so as to route incoming calls through the rotary system in the same manner as calls are routed from the toll board. In incoming toll calls, the received digits are temporarily stored in a coder such as CR, of which six are provided for the twenty-five toll lines, and are transmitted then to a register sender such as RS-2, as will be pointed out fully hereinafter.

The coders are necessary because the toll register senders are adapted for key control instead of for control by series of dial pulses. The pre-selector PS interconnects an idle one of these coders with a toll-line repeater responsive to an incoming call and disconnects it as soon as all of the digits have been received and transferred to a register sender.

For the handling of calls in the opposite direction, from Rio de Janeiro to Sao Paulo, it is necessary that the operations of the digit keys at the toll board shall be registered and that corresponding series of decimal impulses be transmitted to operate the Strowger switches in Sao Paulo. For the purpose a group of six register senders such as RS-4 are provided for the twen-

ty-five toll lines including toll line TL-4. Each of these senders has a finder such as F-3 to connect to a toll line by way of an impulse repeater such as IR-4. This register sender receives the digits set up on the digit keys and retransmits the decimal impulses over the toll line.

D. TOLL DIALLING

10 In order to enable the setting of the switching apparatus to be effected over the toll lines by means of voice-frequency impulses, each automatic toll line has an impulse repeater at each end thereof with which there is associated a tone unit. For instance, the tone unit TU-2, Fig. 2, part one, is associated with the impulse repeater IR-2 on the Sao Paulo end of the toll line TL-4, while the tone unit TU-4 is associated with the impulse repeater IR-4 on the Rio de Janeiro end of the toll line TL-4. As will be subsequently described, each tone unit constitutes equipment for translating direct current dial pulses into corresponding pulses of voice frequency (1,000 cycles) in outgoing calls and includes equipment for translating received 1,000-cycle pulses into direct-current, switch-operating impulses. In addition, the tone units each includes means for transmitting and translating supervisory pulses constituting a 1,000-cycle current modulated by a 60-cycle current. The arrangement for transmitting the dial pulses and supervisory pulses by means of voice-frequency current is similar to that disclosed in the United States Patent 2,040,637, granted to John Wicks on May 12, 1936.

35 As previously mentioned, the Sao Paulo exchange serves as a switching center through which calls may be routed automatically between Rio de Janeiro on the one hand and Campinas and Santos on the other hand, the Campinas and Santos exchanges each being provided with an automatic toll board and with a switching layout similar to that disclosed for the Sao Paulo exchange.

45 It will be understood, of course, that there are other toll lines connected to the Sao Paulo exchange leading to other points not indicated in Fig. 1, and that similarly there are other toll lines radiating from Rio de Janeiro. The toll calls to and from these other points are handled 50 in the manner hereinbefore described for the handling of toll calls over the illustrated toll-line routes.

The trunking arrangement as disclosed in Fig. 2 having been described, further attention is directed to the circuit drawings shown in Figs. 3 to 21:

55 Fig. 3 shows the combined line and recording trunk CLR-1 interposed between the two-conductor trunk T-1, incoming from the tenth level of subscriber first selectors, and the terminals 250 in the bank of the finder F-1, Figs. 2 and 5, and the multiples thereof in the banks of the other similar finders;

60 Fig. 4 shows the toll line circuit TLC-1 interposed between the two-way toll line TL-1 of Figs. 1 and 2 and the finder bank terminals 450 and the multiples thereof. This trunk circuit serves as a terminus for the trunk T2, incoming 65 from terminals 460 of selector TLS-1, Figs. 2 and 10, and multiples thereof in the banks of other selectors. The common start conductors 307 and 412 of Figs. 3 and 4, respectively, may be connected together and extended by way of 70 any preferred form of distributor to the position

start conductor such as position start conductor 511, Fig. 5;

75 Fig. 5 shows the cord circuit CC-1 of Fig. 2 together with the finder F-1 in which the cord circuit terminates at one end, as well as the position equipment PE-1 common to all of the cord circuits such as CC-1 at the same position;

80 Fig. 6 shows the toll first selector TFS-1 in which the other end of the cord circuit CC-1 terminates;

85 Fig. 7 shows the toll first selector TFS-3 of Fig. 2 by means of a broken-line rectangle, the circuits of this selector being omitted they are the same as those of toll first selector TFS-1, Fig. 6;

90 Fig. 8 shows the toll-line selector TLS-2 of Fig. 2, having access to the automatic toll lines such as TL-2 to TL-4, Fig. 2, by way of repeaters IR-1, IR-2, and IR-3, of which the repeater IR-2 is shown in full in Fig. 11;

95 Fig. 9 shows the toll office selector TOS-1 of Fig. 2 which is accessible from toll first selectors such as TFS-1, Figs. 2 and 6, and has access to interoffice trunk lines extending to incoming toll thousand selectors, such as the toll thousand selector TMS in office eight, Fig. 2;

100 Fig. 10 shows the toll-line selector TLS-1 of Fig. 2, which is accessible to the toll first selectors and which has access to manual toll lines, such as TL-1, Figs. 1, 2, and 4. One set of terminals in the bank of the toll-line selector TLS-1 of Fig. 10 is shown at 460 in Fig. 4;

105 Fig. 11 shows the impulse repeater IR-2 serving as the Sao Paulo terminus for the toll line TL-4, being accessible at terminals 1100 of the toll first selector TFS-1, Figs. 2 and 6, and being connected by way of the four conductors of the trunk T-4 to the toll first selector TFS-3, Figs. 2 and 7;

110 Fig. 12 shows the tone unit TU-2 associated through the connecting cable 1200 with the impulse repeater IR-2, this drawing showing also the telephone repeater or voice-current repeater VCR, one or more of these repeaters being provided in the toll line TL-4 for the two-way amplification of attenuated voice currents;

115 Fig. 13 shows the tone unit TU-4 by means of a broken-line rectangle, as this tone unit is a duplicate of that shown in Fig. 12;

120 Fig. 14 shows the impulse repeater IR-4 on the Sao Paulo end of the toll line TL-4;

125 Fig. 15 shows the pre-selector PS of Fig. 2, which is provided to interconnect any one of the twenty-five repeaters such as the impulse repeater IR-4 of Figs. 2 and 14 to any one of 6 55 coders such as the coder CR of Figs. 2 and 16;

130 Fig. 16 shows the coder CR, which is one of the 6 coders provided as discussed in connection with Fig. 2 to receive the digit impulses from Sao Paulo by way of the translating apparatus in the incoming repeaters and associated tone units and transmit appropriately coded sending impulses to the toll register senders, such as the register sender RS-2, Fig. 2;

135 Fig. 17 shows the finder F-3 of Fig. 2 which is operable to connect the associated register sender RS-1 of Fig. 18 to any one of the twenty-five repeaters such as IR-4 of Figs. 2 and 14. Fig. 17 shows also the finder allotter AL which controls the sequential starting of idle finders responsive to the seizure of repeaters in Rio de Janeiro, together with the relay group RG and the test-transfer relay 1712, associated with the register sender RS-1, Figs. 2 and 18;

140 Fig. 18 shows the register sender RS-1 which

operates under the control of the key set at the Rio de Janeiro toll board to store the keyed digits and to retransmit consecutive trains of digit impulses corresponding in value to the stored digits;

5 Fig. 19 shows the answering jack J-1 and the multiple jack J-2 associated with the impulse repeater IR-4 of Figs. 2 and 14, together with the line circuit associated with the jack J-1 and controlled from the impulse repeater IR-4 10 of Fig. 14.

Fig. 20 shows the cord circuit CC-2 of Fig. 2 at the Rio de Janeiro toll board, together with the jacks J-3 to J-5 and associated line circuits, as well as the line circuit LC-2 associated 15 with the three incoming conductors of the repeater IR-4 Figs. 2 and 14 over which automatic connections are extended to the rotary system;

Fig. 21 shows the position equipment PE-2 of Fig. 2, which includes the digit keys 2100 by 20 means of which the operator keys the digits of a desired number to secure the required operation of the automatic switches through the medium of a register sender.

In addition, Figs. 16A and 16B show code tables 25 for use in connection with the coder of Fig. 16; Fig. 17A shows a code table for use in connection with the receipt of digits at the relay group RG Fig. 17, and their handling and retransmission by the register sender RS-1 of Fig. 18; and Fig. 21A 30 shows a code table for use in understanding the keying operations of the digit keys 2100 of the position equipment PE-2, Fig. 21.

DETAILED DESCRIPTION

35 The disclosure having been described generally, a detailed description of the operation of the system will now be given.

A. CALLING FROM SAO PAULO TO JUNDIAHY

40 In order to describe how connections are completed from the automatic toll board at Sao Paulo to an exchange employing a manual toll board, it will be assumed that a subscriber in the Sao Paulo exchange (for instance the subscriber at substation A, Fig. 2, of office 3) desires to converse with a subscriber reached by way of Jundiah exchange, Fig. 1.

1. Calling the Sao Paulo toll board

50 In order to become connected with the Sao Paulo toll board, the subscriber at sub-station A removes his receiver and thereby obtains connection with an office selector, such as OS-1, Fig. 2, by way of the finder F-2. When the subscriber 55 dials the digit 0, assigned to the toll board, the office selector OS-1 selects an idle trunk extending to the toll board by way of a trunk circuit such as TC. Assuming that the trunk circuit TC is the first one found to be idle, this trunk circuit 60 is seized, whereupon it passes into calling condition to extend the call over the trunk T-1 to the toll board by way of the CLR (combined line and recording) circuit CLR-1 Figs. 2 and 3.

In Fig. 3, it is to be noted that the incoming 65 conductors of the trunk T-1 extend to the line side of the repeating coil 300. Accordingly, when the calling condition is impressed on the trunk T-1 by the trunk circuit TC, Fig. 2, (which calling condition is characterized by a ground or positive potential on the negative conductor and a negative potential on the positive conductor of trunk T-1) line relay 304 in the circuit CLR-1 70 operates, as its two windings (in series with the lower winding of supervisory relay 303) are connected in series with the conductors of the trunk

T-1 by way of the line windings of the repeating coil 300. It is to be noted that the upper winding of line relay 304 is a 12,000-ohm winding. By the presence of this winding in circuit, the current flow over trunk T-1 is held to a low value. At its upper contacts, line relay 304 places a negative potential on the C terminal 250 and the multiples thereof by way of contacts of supervisory relay 303 and the winding of cut-off relay 302, shunted by the 500 ohm resistor 308. This negative potential marks the line circuit CLR-1 as calling in the banks of the finders having access to it.

At its lower contacts, line relay 304 closes a circuit for the upper or polarizing winding of the electro-polarized supervisory relay 303. A branch 15 circuit extends through contacts of relays 303 and 302 to start relay 301. Start relay 301 opens a point in the answering supervisory circuit at its upper contacts, while at its lower contacts it places a ground potential on the common start 20 conductor 307 in order to start a finder searching for the circuit.

As previously mentioned, the start conductors such as 307 and 412 are connected together and extended by way of a suitable distributor so that 25 the grounding of the common start conductor results in the extension of a starting ground potential to a position start conductor such as 511 at one of the toll-board positions. Alternatively, the common start conductor may extend normally 30 to each of the toll board positions without a distributor, this latter arrangement being employed when the toll board has only a few positions.

At each position of the toll board, when an operator is not otherwise occupied she is expected 35 to operate a talking key such as the key K-3, Fig. 5, of an idle cord circuit. When the talking key K-3 is operated at a time when the cord circuit CC-1 is idle, answering supervisory relay 504 and talking relay 503 are energized in series. 40 Relay 504 disconnects the answering supervisory lamp 507, while the talking relay 503 preselects the finder F-1 for operation and extends the talking conductors of the cord circuit CC-1 to the position equipment PE-1. Assuming that the cord circuit CC-1 is in this condition when the call arrives over the trunk TL at the circuit CLR-1 45 of Fig. 3, and that starting ground potential is extended to position start conductor 511 of the illustrated position, a circuit is closed through contacts of the operated talking relay 503 and through contacts of switching relay 503 for start relay 501. Relay 501 grounds conductor 511 so as to light the busy lamp 508 and to prepare circuit for answering supervisory lamp 507.

55 Relay 501 also closes a circuit for the polarizing winding of electro-polarized switching relay 502, an extension of which circuit passes through contacts of relay 502 and through the self-interrupting contacts of magnet 510 to stepping magnet 510. Magnet 510 thereupon operates in a buzzer-like manner to advance the wipers 500 of the finder F-1 over its bank terminals in search of the calling line circuit. The test winding of electro-polarized switching relay 502 is connected to 60 the C wiper 500 by way of the upper contacts of start relay 501, whereby relay 502 is able to operate when the terminals 250 are reached, as a circuit exists at that time for the upper winding of switching relay 502 in series with the winding 65 of cut-off relay 302 and the shunt resistor 308, by way of contacts of the operated line relay 304. Upon operating, the switching relay 502 disconnects magnet 510 so as to terminate the stepping 70 action of the finder F-1. Switching relay 502 75

also transfers start relay 501 from start conductor 511 to ground by way of the contacts of the release answer key K-1 so as to hold the start relay operated; it connects up the negative, positive, and EC wipers 500; and it by-passes its own test winding and extends the C wiper 500 to ground by way of the 10-ohm upper winding of answering supervisory relay 504. The ground potential supplied through this 10-ohm winding of relay 504 is sufficient to guard the circuit of Fig. 3 from seizure by another finder.

The group identity lamp 306 is now lighted over the associated EC terminal 250 and the EC wiper 500, through contacts of relays 502 and 503 to indicate to the operator the line group or trunk group over which the call is received, there being a separate one of these lamps at each position for each group of lines through which calls may be received at the position.

20 In the CLR circuit of Fig. 3, cut-off relay 302 now operates to disconnect start relay 301 and to prepare a supervisory by-pass circuit around the 12,000-ohm upper winding of line relay 304. As soon as start relay 301 restores, this by-pass supervisory circuit is closed, whereupon the current flow over the conductors of the trunk T-1 becomes sufficient to impress a holding condition on the trunk circuit TC, Fig. 2, to cause the connection to be held from the toll board. Relay 303 does not operate, because potential over the conductors of trunk T-1 is applied reversed at the trunk circuit TC, Fig. 2, upon seizure, whereby a positive potential is now applied to the upper conductor trunk T-1, and a negative potential is applied to the lower conductor. The relative polarities of the windings of relay 303, as well as of the windings of the other relays shown throughout the drawings, may be observed as the inner terminal of each relay winding is identified by a small, solid black hemisphere placed just within the confines of the relay winding space at the point of entry of the connecting lead.

In the calling office 8 of Fig. 2, the increased current flow over the conductors of the trunk T-1, in addition to locking up the connection under operator control, causes the application of class tone normally made upon the seizure of the circuit to be discontinued after an interval sufficiently long to enable the operator to take note of the class to which the calling line is assigned. Relay 305 is provided to re-open the supervisory bridge at the will of the operator responsive to a manipulation of her ringing key so as to cause the class tone to be momentarily reapplied in the event that the operator wishes to hear the class tone again.

The answering operator, whose headset 599 is connected with the talking conductors of the cord circuit CC-1 by way of conductors 512 and 513 and contacts of the talking relay 503, may now converse with the calling subscriber and ascertain the destination of the call. Upon learning that the calling subscriber desires to converse with a subscriber in Jundiah, the operator proceeds to associate the calling device CD with her cord circuit, and to dial the three-digit number assigned to the Jundiah exchange, the first digit of which number is used to operate the toll first selector TFS-1 Figs. 2 and 6 to the first level, while the second and third digits are used to operate a toll line selector such as TLS-1, Figs. 2 and 10, to the ninth level and over the ninth level into engagement with the desired group of toll lines.

75 In order to associate the calling device CD

with the circuit, the operator throws the locking dial key K-6. Key K-6 prepares a circuit for the dial-connecting relay 506, and it closes a circuit for transfer relay 522. Upon operating, relay 522 disconnects the loop-test relay 521 and prepares the calling device bridge, at the same time opening a point in the automatic ringing circuit at its inner lower contacts. Also, relay 502 opens a point in the circuit of timing relay 524 and closes a circuit for slow-releasing holding relay 523. Relay 523 operates and locks itself through contacts of unlock relay 525, at the same time opening an additional point in the automatic ringing circuit at its lower contacts and preparing a circuit for the timing relay 524 at its inner upper contacts.

Holding relay 523 also opens a point in the circuit of extending relay 505 and it completes the circuit of the dial-connecting relay 506 through contacts of the operated dial key K-6. Relay 506 now locks itself operated independent of the contacts of the dial key. Relay 506 also prepares a circuit for the extending relay 505; it applies ground potential to the C lead extending to the selector of Fig. 6; and it connects the prepared calling device bridge across the negative and positive talking conductors extending to the selector TFS-1 of Fig. 6.

In the toll first selector TFS-1, Fig. 6, the application of ground potential to the incoming C lead at relay 506 of the cord circuit CC-1, Fig. 5, results in the application of ground potential to the lower terminal of the lower winding of line relay 601 and in the operation of series relay 603, whose upper winding is normally connected to the C lead through off-normal contacts 611. Series relay 603 prepares a circuit for vertical magnet 605 and a holding circuit for its own lower winding; it disconnects the rotary magnet 606; and it performs a switching operation at its upper contacts which is of no concern at this time.

At the same time that relay 603 operates over the C lead, line relay 601 operates over the talking conductor in series with the impulse contacts of the calling device CD, Fig. 5. Line relay 601 closes a circuit for release relay 602 through contacts of switching relay 604. Release relay 602 makes an additional application of ground potential to the C lead; prepares a circuit for vertical magnet 605 and opens the point of the circuit of release magnet 607; it energizes the 1300-ohm polarizing winding of the electropolarized relay 608; and it prepares a test circuit for energizing the test winding of relay 604.

2. Dialling the Jundiah toll-line number

After operating the dial key K-6 with results as described, the operator manipulates the calling device CD in accordance with the digits assigned to the desired toll-line group. Each time the calling device CD is moved from its normal position, the off-normal contacts thereof close a circuit for transfer relay 552 in parallel with the lower contacts of the dial key K-6 whereby the operator may restore the dial key K-6 as soon as she has turned the calling device CD off-normal for the final digit without causing premature disconnection.

Each time the calling device CD returns to normal position it produces a series of interruptions (break impulses) at its impulse contacts. The line relay 601 of the toll first selector TFS-1 responds to the first series of interruptions by delivering a series of impulses through contacts of the slow-releasing release

relay 602 and contacts of the slow-releasing series relay 603 to vertical magnet 605.

By the operation of vertical magnet 605 the wipers 650 of the selector are raised step by step 5 until they come to rest opposite the desired level of bank contacts. Off-normal contacts 608 and 609 prepare a circuit for the release and rotary magnets 607 and 606, respectively, while off-normal contacts 611 open the initial circuit of 10 the upper winding of the series relay 603 so as to enable relay 603 to restore upon the cessation of the series of impulses being delivered to vertical magnet 605, the lower winding of relay 603 sufficing to maintain the relay operated through- 15 out this series of impulses.

When series relay 603 restores upon the termination of the first digit, it disconnects its own lower winding and the vertical magnet at its inner lower contacts, while at its lower contacts 20 it completes a circuit for rotary magnet 606 through off-normal contacts 609, which circuit includes the contacts of the operated line relay 601 and contacts of switching relay 604. Rotary magnet 606 now operates in a buzzer-like manner to advance the wipers 650 over the terminals 25 in the selected level, the first level in this case leading to a desired toll line selector such as TLS-1, Figs. 2 and 10.

When an idle selector is reached, which selector 30 may be assumed to be the selector TLS-1 of Fig. 10, the test winding (the uppermost winding) of electropolarized switching relay 604 of the selector TFS-1 encounters a negative potential by way of the C wiper 650 and the C terminal 35 1000 of Fig. 10, which negative potential is obtained through off-normal contacts 1014 and the upper winding of vertical-series relay 1003. Upon operating, relay 604 at its lower contacts opens the circuit of rotary magnet 606 to terminate the 40 rotary movement, also opening the circuit of slow-releasing release relay 602. In addition, relay 604 extends the incoming EC lead to the EC wiper 650; makes an independent ground connection to the C wiper 650 through contacts of 45 series relay 603, thereby shunting the test winding of the relay; energizes its middle, holding winding so as to provide a self-locking circuit to the incoming C lead; and it disconnects the incoming talking conductors from line relay 601 and extends them to the negative and positive 50 wipers 650. Line relay 601 now restores and prepares a circuit for release magnet 607. Release relay 602 restores responsive to the operation of relay 604 and the restoration of relay 601. Upon 55 restoring, relay 602 open-circuits the previously shunted test winding (the upper winding) of relay 604; deenergizes the polarizing winding of relay 604; and removes the locally-applied ground potential from the incoming C conductor, leaving this conductor grounded in the cord circuit CC by the contacts of relay 506.

The toll line selector TLS-1, Fig. 10, having been selected by the stopping of wipers 650 on the terminals 1000, vertical-series relay 1003 is 60 energized over the grounded C lead through off-normal contacts 1014, and line relay 1001 is energized over the talking conductors and through the impulse contacts of the calling device. Release relay 1002 operates responsive to the operation of line relay 1001. Also, sequence relay 1004 65 is operated from the C lead through contacts of relay 1003.

With relays 1001-1004 operated, the toll line selector TLS-1 is prepared for operation. Since 70 the toll lines accessible to the toll line selector 75

TLS-1 are in relatively small groups, two-digit numbers are assigned to the group, whereby two or more groups may appear in a single level of bank contacts.

When the second digit in the desired number 5 is called, the calling device causes line relay 1001 to be restored momentarily the desired number of times. Vertical magnet 1009 responds to the resulting impulses delivered by relay 1001 through contacts of the operated relays 1002 and 1003. 10 The lower winding of slow-releasing vertical-series relay 1003 maintains the relay operated after the upper winding has been disconnected at off-normal contacts 1014 upon the first vertical step of the switch. 15

At the end of the series of impulses, vertical-series relay 1003 restores and opens the initial circuit of sequence relay 1004, but this relay remains operated in its locking circuit which includes its own contacts and those of rotary-series 20 auxiliary relay 1006. At its lower armature, relay 1003 transfers the operating circuit from vertical magnet 1009 through rotary-series relay 1005 and contacts of relay 1004 to rotary magnet 1010. 25

When the final digit in the designation of the desired toll-line group is dialed, line relay 1001 delivers impulses through contacts of the operated relay 1002 and through contacts of the restored vertical series relay 1003, and thence by 30 way of contacts to the operated sequence relay 1004 and the winding of rotary-series relay 1005 to rotary magnet 1010. Magnet 1010 is thereby operated to advance the wipers 1050 step by step over the contact sets in the selected level until 35 they come into engagement with the contact set assigned to the first toll line in the group. Slow-releasing rotary-series relay 1005 operates in series with magnet 1010 upon the first rotary impulse. Upon operating, rotary series relay 1005 40 disconnects the C wiper 1050 and operates auxiliary relay 1006. Auxiliary relay 1006 disconnects the B wiper 1050, and it opens the locking circuit of sequence relay 1004 so as to permit this relay 45 to restore and prepare a self-interrupting circuit for magnet 1010 which is to become effective at the end of the digit. The lower contacts of relay 1006 close a new rotary stepping circuit exclusive of contacts of sequence relay 1004.

At the end of the series of impulses, wipers 50 1050 have been advanced until they rest upon the set of contacts assigned to the first toll line in the group, assumed to be terminals 460, Fig. 4. Rotary series relay 1005 restores responsive to the cessation of impulses and it reconnects the 55 C wiper 1050 to the test (uppermost) winding of switching relay 1008, in addition to restoring auxiliary relay 1006 to connect the B wiper 1050 to the test winding of group-busy relay 1007.

The operations that now take place depend 60 upon whether the first toll line in the group is busy or idle. Assuming that this toll line is busy, no circuit exists for operating switching relay 1008; therefore, the self-interrupting circuit for rotary magnet 1010 is not at the lower contacts 65 of switching relay 1008. In this event, upon the restoration of auxiliary relay 1006, rotary magnet 1010 is operated in a circuit which includes the lower contacts of switching relay 1008, contacts of the operated line relay 1001, off-normal 70 contacts 1012, self-interrupting contacts of rotary magnet 1010, and contacts of the restored relays 1004, and 1006. Rotary magnet 1010 thus advances the wipers 1050 step by step over the contacts until an idle toll line is reached, or until 75

the terminals of the final toll line in the group are reached in the event that all of them are busy.

Assuming now that the toll line **TL-1**, Figs. 2 and 4, is idle when the wipers **1050** arrive on terminals **460**, the test winding of switching relay **1008** becomes energized over the C lead through contacts of guard relay **404** and of start relay **408** and through the winding of cut-off relay **409**. Upon operating, relay **1008** opens its lower contacts to terminate the rotary movement and it extends the incoming negative, positive, and EC conductors to the toll line circuit **TLC-1**, in addition to closing a holding circuit for its middle, holding winding, and applying ground potential to the C wiper **1050** through normal contacts of relays **1003**, **1005**, and **1007** in shunt of its test winding so as to guard the toll line from further seizure.

Line relay **1001** restores, and at the end of a momentary interval release relay **1002** restores. The selector remains held by the ground potential supplied over the C lead incoming thereto from the preceding selector.

In the toll line circuit **TLC-1**, cut-off relay **409** operates over the C lead incoming from the C terminal **460**. At its lower contacts, relay **409** opens a point in the start circuit, while at its middle lower armature it opens a point in the circuit through which start relay **406** becomes locked locally in an incoming call, thereby preparing for the transmission of supervisory pulses over the EC lead. At its inner upper armature, relay **410** connects its own winding to the C terminal **450** through contacts of start relays **406**, but this does not place the circuit in calling condition as the C terminal **450** is thereby supplied with ground potential by way of the C terminal **460**. It is to be noted that the EC conductor incoming from EC terminal **460** now extends through the lower winding of start relay **406** to open contacts, while the negative and positive conductors incoming from the negative and positive terminals **460** both extend to ground potential by way of pad-control relay **402**, the negative conductor by way of a winding of the retard coil **405** and a winding of guard relay **404**, while the positive conductor extends by way of the lower winding of retard coil **405** and the winding of ringing relay **401**. This is a condition under which the calling loop tests "dry".

3. Loop-test and automatic ring control

In the equipment of Fig. 5, as soon as she has turned the calling device **CD** off normal for the dialing of the final digit, the operator may release the dial key **K-6**. When the key is released under this condition, nothing results immediately from the release thereof, for the upper contacts of the key are by-passed at contacts of relay **506**, and the lower contacts of the key are by-passed at the off-normal contacts of the calling device **CD**.

When the calling device **CD** reaches its normal position, it opens the circuit of transfer relay **522**, permitting this relay to restore and start a sequence of operations which results in the talking conductors being tested for a looped condition; in an application of potential to the positive talking conductor in order to apply ringing current; and in the operation of the extending relay **505** of the cord circuit **CC-1**, depending upon the absence of negative potential on the negative talking conductor, indicating a "dry" loop.

When relay **522** restores, it prepares to apply a ringing impulse at its inner lower contacts upon

the subsequent restoration of relay **523**; it connects ground through the 20-ohm winding of loop test relay **521** to the negative talking conductor through contacts of the calling device and contacts of the operated dial-connecting relay **506** to test for negative potential; and it opens the initial circuit of the now-locked holding relay **523** and closes a circuit through contacts of relay **523** for the timing relay **524**. Relay **524** is provided with a weighted contact which vibrates for an interval of time after the armature becomes attracted so as to provide an interval of perhaps a second before unlocking relay **525** operates. This restoration of transfer relay **522** and the starting of the timing operation occur immediately following the transmission of the final impulse at the calling device **CD** and therefore before the line relay **1001** has become disconnected upon the operation of switching relay **1008**, previously described. As a result, loop test relay **521** is energized over the negative talking conductor in series with the upper winding of line relay **1001**, and the line relay **1001** is held operated temporarily in this circuit. But, as soon as relay **1008** of the toll-line selector **TLS-1** operates and removes the bridge from across the talking conductors and extends them to the toll line circuit **TLC-1**, as before described, loop-test relay **521** restores and prepares a circuit for the extending relay **505**.

When unlocking relay **525** operates at the end of the timing interval, it opens the locking circuit of holding relay **523**, permitting holding relay **523** to restore. Upon restoring, relay **523** opens a further point in its locking circuit; opens the circuit of relay **524** to permit relays **524** and **525** to restore; and it opens the locking circuit of the slow-releasing dial-connecting relay **506** to permit this relay to restore after a slight interval. At the same time, a circuit is closed through contacts of the restored relays **521** and **523** and through contacts of the still-operated dial-connecting relay **506** for actuating the extending relay **505**. Relay **505** thereupon operates and locks itself through contacts of release-call key **K-2**. In addition, during the interval required for the slow-releasing, dial-connecting relay **506** to restore after its circuit is opened by holding relay **523**, a momentary ring-control pulse is transmitted from the negative pole of the exchange battery through the 100-ohm resistor **526**, and by way of contacts of the now-restored relays **522** and **523**, to the positive talking conductor by way of contacts of the still-operated relay **506**. At the time this application of negative potential to the positive talking conductor takes place, it is to be noted that ground potential is impressed on the negative talking conductor through the 20-ohm winding of loop-test relay **521**. This latter condition prevents any possibility of an undesired operation of guard relay **404** over the negative talking conductor by induction through the condenser associated with the switchboard windings of repeating coil **400**.

It is to be particularly noted that the circuit for initially operating the extending relay **505** includes normally-closed contacts of loop-test relay **521**, whereby extending relay **505** is prevented from operating in the previously-described manner in the event that a line relay is still bridged across the talking conductors, such as may occur when one of the switches of the train is defective and has failed to operate or in the event that the operator has neglected to dial a sufficient number of digits to fully extend a circuit to a called subscriber line or to a toll line.

The disclosed circuit arrangement prevents the extension of the cord circuit to an "undried" loop, as the system requires that such an extension be not made under those conditions, as will be more 5 fully understood as the description progresses. In the event that the extending relay 505 does not operate, the partially-extended connection is cleared out upon the restoration of dial-connecting relay 506 and the consequent opening 10 of the loop and the removal of ground potential from the C lead extending to the associated toll first selector.

In the toll line circuit TLC-1, Fig. 4, the momentary ring-control pulse transmitted by the 15 equipment of Fig. 5 at the end of the dialing operation (the described momentary application of the negative potential to the positive talking conductor) results in the operation of ringing relay 403 through the lower winding of the re- 20 tard coil 405 and contacts of guard relay 404. Upon operating, ringing relay 403 applies ringing current of the chosen frequency to the toll line TL-1 from the common ringing lead 414 in order to signal the operator in the distant 25 Jundiah exchange, to which the toll line TL-1 extends.

4. Controlling the toll-line pads

It is common practice to provide a so-called 30 pad at each exchange terminal of a repeatered toll line, such as the pad 413. This pad is composed of two series, center-tapped resistors and a shunt resistor connected between the center 35 taps in series with an insulating condenser. As is well understood, the purpose of a pad is two-fold: It introduces a definite loss when the toll line is connected through the exchange to a subscriber line, which loss is not present when the toll line is interconnected with another toll line, 40 whereby the transmission level is more nearly uniform independent of the length of the toll connection built up, and it introduces a necessary circuit loss which tends to balance the artificial-line network at the repeater nearest the exchange 45 regardless of the transmission characteristics of the local line.

When the toll line TL-1 is in use and cut-off relay 409 is therefore operated, a circuit is closed through contacts of pad-control relay 402 for 50 the pad-cut-out relay 401 unless pad-control relay 402 is operated to prevent the operation of the pad-cut-out relay. The pad-control relay is arranged to derive current from the switchboard extension of the toll line in a simplex circuit, provided there is a current connection made to the talking conductors connected to the toll line. Each of the circuits used for connecting the toll line with a local line is provided with a 44,000-ohm center-tapped resistor through which 55 current is supplied for operating the pad-control relay. One of these pad-control resistors is connected with the switchboard windings of the repeating coil 300 of the circuit CLR-1, Fig. 1. The current which flows through pad-control relay 402 and supplied through one of the center-tapped resistors above-mentioned is insufficient 60 to operate the guard and ring relays 403 and 404, neither of which is as sensitive as the pad-control relay and each of which receives only one- 65 half the current which flows through the pad-control relay.

The operator at Fig. 5 may actuate the split-answering key K-4 to disconnect the answering end of her cord circuit while she is talking over 70 the toll line TL-1, if desired. Likewise, she may

actuate the split-call key K-5 if she desires to converse over the answering end of her cord without being overheard over the calling end of the cord circuit.

It is to be noted that a 44,000-ohm pad-control 5 resistor is connected with the position talking conductors 512 and 513 to supply a battery potential to the cord circuit while the position talking conductors are connected thereto. This connection insures that the toll-line pad is inserted 10 while the toll operator is conversing over the toll line.

In the event that the first application of ringing current is not successful in securing a response of the distant Jundiah operator, the 15 operator at Fig. 5 may again ring over the toll line by actuating the ringing key K-8 after actuating the split-answer key K-4 to avoid transmitting the ring-control impulse to the C. L. R. circuit of Fig. 3. 20

After the talking key K-3 is restored to permit talking relay 503 to restore, pad-control relay 402 is held operated from the C. L. R. circuit of Fig. 3.

When the connection has been completed by 25 the operator in the Jundiah exchange, the two subscribers may converse as desired.

5. Hookswitch supervision from the local line

Assuming that the local calling subscriber at 30 sub-station A at Fig. 2 desires to attract the attention of the toll operator, he may do so by depressing the hookswitch momentarily one or more times. Each time the hookswitch is depressed, the trunk circuit TC Fig. 2 operates in the well-known manner to reverse the application of potential to the two conductors of the trunk T1, thereby reversing the current flow through the lower windings of relays 303 and 304 in circuit CLR-1. Each time the current flow is reversed, 40 electro-polarized supervisory relay 303 operates to insert the 2,000-ohm resistor 309 in the associated C lead for the duration of the reversal, thereby reducing the current flow sufficiently to permit the marginally adjusted answering supervisory relay 504 to restore. Upon restoring, relay 504 closes a circuit for the answering supervisory lamp 507. When the current flow is reversed back to the direction normally obtaining during conversation, relay 303 is caused to restore 50 and again shunt the resistor 309 out of circuit. When this occurs, answering supervisory relay 504 operates and extinguishes lamp 507. The operator may respond to the flashing condition of lamp 507 by again actuating the talking key 55 K-3 to bring about an operation of talking relay 503 to connect up her headset conductors 512 and 513. When the operator has answered the signal and conversed with the calling subscriber, she may again restore the talking key K-3 to 60 permit relay 503 to restore and disconnect her headset conductors, or she may break down the extended connection and re-extend it in the event that it is found that connection has not been completed to the desired called line. 65

6. Ring-down supervision over the toll line

In the event that the operator in the called Jundiah exchange, desiring to get in touch with the originating toll operator, projects ringing 70 current momentarily over the toll line TL-1 the shaded-pole, alternating-current ring-up relay 407 is actuated to momentarily restore the normally-energized signal relay 406 and thereby close a circuit for the upper winding of the combined 75

start and recall relay 408. Relay 408 closes a locking circuit for its lower winding at its inner-upper contacts over the EC lead in series with the calling supervisory lamp 509. Lamp 509 becomes 5 lighted steadily in this locking circuit to signal the operator. When the operator responds and causes talking relay 503 to operate so as to connect up here headset conductors 512 and 513, the disconnection of calling supervisory lamp 509 10 interrupts the locking circuit and permits relay 408 to clear out.

7. Clearing out the connection

15 When the conversation has been completed, restoration of the receiver at the local calling station results in the previously-discussed operation of the electro-polarized relay 303 to insert the 2,000-ohm resistor 309 in the C lead. Answering-supervisory relay 504 is thereby restored to light the answering-supervisory lamp 507 steadily as a disconnect signal. In order to clear out the calling end of the connection the operator momentarily depresses the non-locking release-answer key K-1, thereby opening the locking circuit of start relay 501. When start relay 501 restores, it removes ground potential at one point from conductor 511 and it opens the circuit of the polarizing and holding winding of 25 switching relay 502, permitting this relay to restore and open a further point in the holding circuit of relay 501, whereby this relay is not re-operated when the key K-1 is permitted to restore.

30 In the C. L. R. circuit of Fig. 3, cut-off relay 302 now restores, again including the 12,000-ohm upper winding of line relay 304 in the holding bridge across the conductors of the trunk T-1 so as to give disconnect supervision to the trunk circuit TC Fig. 2. It is to be noted that start relay 301 is not operated at this time because it is maintained disconnected at its lower contacts of electro-polarized relay 303. As soon as the usual relay operation has taken place in the trunk circuit TC the switches OS-1 and F-2 clear 35 out, and the conductors of the trunk T-1 are disconnected so as to terminate the flow of current thereto. When this occurs, line relay 304 restores. Relay 303 restores when its polarizing circuit is opened by the line relay.

40 Before clearing out the called end of the connection, the operator at Fig. 5 may momentarily project ringing current over the toll line TL-1, as previously discussed, in order to give a ring-off signal to the distant operator. The called end 45 of the connection is cleared out responsive to a momentary depression of the non-locking release-call key K-2. When this occurs, extending relay 505 restores and opens a further point in its previously existing locking circuit, in addition to disconnecting the conductors extending to the toll first selector of Fig. 6. Relay 505 also removes ground potential from conductor 511 to extinguish the busy lamp 508.

50 In the toll first selector TFS-1 Fig. 6, when ground potential is removed from the incoming C lead upon the restoration of extending relay 505 of the cord circuit, switching relay 604, which has been held operated by means of its locking 55 circuit including its middle winding, restores and opens a further point in its previously-existing locking circuit. Relay 604 also disconnects wipers 650, and it closes a circuit at its lower contacts through contacts of relays 601 and 602 and off-75 normal contacts 608 for release magnet 607,

whereby the selector is restored to normal position in the usual manner.

In the toll line selector TLS-1 of Fig. 10, switching relay 1008 restores when the preceding selector clears out as above mentioned. Upon 5 restoring, relay 1008 disconnects the negative, positive, C, and EC wipers 1050. Relay 1008 also closes the release-magnet circuit at its lower contacts so as to operate release magnet 1011 through off-normal contacts 1013 to restore the 10 selector to normal position.

In the toll line circuit TLC-1, the removal of ground potential from the C conductor of the trunk T2 incoming from terminals 460 renders the circuit accessible to the other selectors and 15 permits cut-off relay 409 to restore and place the circuit in normal condition.

8. Overflow condition at the toll first selectors

The handling of overflow conditions at certain 20 of the switching stages will be discussed briefly. In the event that the toll first selector TFS-1 is unable to find an idle trunk on a desired level, the rotation of the wipers as previously described continues until the wipers have been advanced 25 to the overflow position, one step beyond the last trunk. Overflow contacts are provided in the bank of the C wiper 650 and a meter is preferably connected to each of these contacts to record the number of unsuccessful attempts to 30 find an idle trunk in a group. The (upper) test winding of switching relay 604 is actuated in series with this meter and relay 604 operates just as though an idle trunk were found and applies ground potential to the C wiper to bring about an 35 effective operation of the overflow meter. At the same time overflow contacts 610 connect the upper winding of series relay 603 in circuit so as to supply an effective source of operating potential for the test winding of relay 604 in the event that 40 the overflow meter is of relatively high resistance, thereby insuring operation of relay 604 upon the eleventh rotary step. When relay 604 by-passes its test winding to apply ground potential directly to the C wiper, series relay 603 is operated to 45 shift the connection of ground potential to the C wipers so that it includes the middle upper armature of relay 602 instead of contacts of relay 604. By this arrangement, when release relay 602 restores responsive to the operation of relay 50 604 and the restoration of relay 601, ground potential is disconnected from the C wiper 650 so as to leave the overflow meter free for subsequent actuation before the selector TFS-1 restores. Relay 603 remains operated through the 55 upper winding of relay 604.

In addition, overflow contacts 612 connect the associated 60-impulse-a-minute, interrupter lead to the associated EC conductor so as to form a characteristic all-trunks-busy flashing circuit for 60 the calling supervisory lamp 509 when extending relay 505 operates. The selector TFS-1 is cleared out in the hereinbefore-described manner, responsive to the removal of ground potential from the incoming C conductor. 65

9. Overflow condition at the manual-toll-line selectors

Referring now to the manual toll-line selector TLS-1 Fig. 10, arrangements for handling a 70 group busy condition at this selector will now be pointed out.

It has been previously explained that the wipers 1050 of this selector are advanced step by step over the toll lines of the group in search 75

of an idle one in the event that the first toll line of the group is busy. In the event that all of the toll lines in the group are busy, the stepping operation continues until the final toll line of the group is reached. As indicated by the dotted strap connection 421, Fig. 4, the B and C terminals of the last toll line in the group are connected together in order to provide a circuit for operating the group-busy relay 1007 in the event that this last toll line is busy also. If this last toll line of the group is busy, the C lead thereof is grounded, whereby relay 1008 is unable to operate. The test winding of electro-polarized relay 1007 is energized from this ground potential to the C wiper, and by way of the strap indicated at 421. Upon operating, relay 1007 disconnects the C wiper 1050 so as to prevent a subsequent operation of relay 1008 while the wipers are being rotated over toll lines of subsequent groups in the level. By this operation, it is insured that the movement of the wipers will continue until the wipers are rotated into the eleventh-rotary-step position. When this occurs, overflow contacts 1016 operate to insure actuation of switching relay 1008 to terminate the operation of rotary magnet 1010, and to bring about the operation of vertical series relay 1003 so as to deliver a momentary metering impulse as explained in connection with toll first selector TFS-1, Fig. 6. Also, contacts 1015 close to connect the associated signal lead to the EC conductor to produce a busy flashing of the calling supervisory lamp.

This selector is cleared out in the usual manner upon the removal of ground potential from the incoming C lead thereof, permitting relays 1007 and 1008 to restore.

It is to be noted that the upper test winding of relay 1007 is a 1300-ohm winding, while the test winding of relay 1008 is the 740-ohm winding. The 1300-ohm winding of relay 1007 has many more turns than the test winding of relay 1008. Therefore, in the event that the final toll line of the group is being guarded by a relay such as guard relay 404, which opens the C lead for this purpose, and current flows through these two test windings in series upon the last trunk of the group being encountered, the current-flow builds up to an operating value in the winding of relay 1007 before it reaches operating value in the winding of relay 1008. Relay 1007 operates quickly and disconnects relay 1008 before relay 1008 has had time to operate in series with the test winding of relay 1007.

10. Guarding a defective manual toll line

In the event that the toll line TL-1 is seized as previously described and is found to be defective, the operator may cause this toll line to be guarded against further seizure at the Sao Paulo end thereof and cause the test desk to be signalled by throwing the split-answer key K-4 and momentarily actuating the guard key K-7. Key K-7 applies ground potential to the lower talking conductor and applies battery potential through the 100-ohm resistor 526 to the upper conductor. Responsive to this, the lower winding of guard relay 404 becomes energized to actuate the relay. Relay 404 locks itself at its inner-upper contacts through its upper winding in series with lamp 417 at the test panel 416. Also, relay 404 disconnects ringing relay 403; it guards the trunk against further seizure by disconnecting the C lead of the trunk T-2 by means of which the toll line is accessible from the selector; it opens a point in the circuit through which

start relay 408 is actuatable by signal relay 406; and it connects the common guard-tone conductors 415 to the talking conductors of the toll line so as to impress a tone on this toll line which may be heard in the event that the toll line is seized at the distant end thereof, thereby warning an operator who seizes this toll line at the distant end that it is defective and that it should be similarly guarded at the distant end. When the toll line has been repaired, guard relay 404 may be restored by opening its locking circuit at the test panel, whereupon lamp 417 becomes extinguished.

B. CALLING FROM JUNDIAHY TO SAO PAULO

The operations involved in completing a call originated in Jundiahy to a desired line in Sao Paulo will now be explained. For this purpose it will be assumed that the subscriber in Jundiahy is calling the subscriber at sub-station A, Fig. 2, in office 8 of the Sao Paulo exchange. It will be assumed further that the call is received over the toll line TL-1 which terminates in the toll-line circuit TLC-1, Fig. 4.

When the toll line TL-1 is seized in the Jundiahy exchange and ringing current is projected thereover, the shaded-pole, alternating-current ring-up relay 407 is actuated to restore the signal relay 406. Upon restoring, relay 406 closes a circuit for the upper winding of start relay 408. Start relay 408 closes a locking circuit for its upper winding through contacts of cut-off relay 409 so as to remain operated after the ringing current has ceased and the normally-operated relay 406 has been permitted to operate again. As a further result of this operation, start relay 408 disconnects the C lead of the branch trunk T-2 from cut-off relay 409 so as to guard the toll line from seizure by way of the selectors by removing the idle-indicating potential from the C lead. Also, relay 408 applies ground potential to start conductor 412 at its lower contacts so as to start a finder searching for terminals 450, and it places a calling condition on the C terminal 450 and the multiples thereof by connecting cut-off relay 409 to the C terminal 450 through contacts of cut-off relay 409.

It may be assumed that the switchboard position indicated in Fig. 5 is the one pre-selected and that the finder F-1 has been pre-selected by the operator at this position to respond to the next call. Under this condition, the finder F-1 operates as previously described in search of the calling circuit. When wipers 500 contact the terminals 450, a circuit is closed for the test winding of the electro-polarized switching relay 502 over the C wiper 500 and C terminal 450 through the cut-off relay 409, by way of contacts of the cut-off relay and contacts of the actuated start relay 408. Upon operating, relay 502 extends the answering end of the cord circuit through the wipers 500 as in the example previously described, applying a guarding ground potential through the C wiper 500 by way of the 10-ohm upper winding of the now-actuated answering supervisory relay 504.

In the toll line circuit TLC-1, cut-off relay 409 operates when this circuit is found by the finder F-1, responsive to the ground potential applied to the C terminal 450. Upon operating, relay 409 unlocks the energized start relay 408 and opens the start circuit. Relay 409 also closes a point in the circuit of pad-cut-out re-

lay 401, but relay 401 does not operate at this time because pad-control relay 402 is operated over the talking conductors through the simplex circuit originating at the center-tapped resistor associated with the position-talking conductors 512 and 513.

Upon conversing with the toll operator in the Jundiah exchange and learning the destination of the call, the operator at Fig. 5 may restore the talking key K-3 and proceed to associate the calling device CD with the cord circuit CC-1 by an operation of the dial key K-6 as before explained, following which she dials the necessary digits and again restores the key K-6.

Upon referring to the trunking layout in Fig. 2, part 1, it will be observed that the first digit to be dialled is the digit 2 to cause the toll first selector TFS-1 to make connection with a toll office selector such as the toll office selector TOS-1, Figs. 2 and 9.

The toll first selector TFS-1 responds to the first digit 2 by raising its wipers opposite the second level and rotating them in search of an idle toll office selector. Assuming that the toll office selector TOS-1 of Fig. 9 is the first one found to be idle, this selector is seized by way of the terminals 900. Line relay 901 is operated to bring about the operation of release relay 902, and series relay 903 is operated from the grounded C conductor through off-normal contacts 912 to prepare a circuit for vertical magnet 909.

Since the number assigned to the line of substation A is 84161, the digit 2, necessary to extend connection to a toll office selector, is followed by the number 84161.

When the digit 8 is dialled, line relay 901 is restored momentarily eight times, whereby eight impulses are delivered to vertical magnet 909 to bring the wipers 950 opposite the eighth level of bank contacts. When it restores at the end of the series of impulses, series relay 903 disconnects vertical magnet 909 and connects up rotary magnet 910 through off-normal contacts 914 and contacts of the actuated line relay 901 to rotate the wipers 950 across the contact bank in search of an idle inter-office trunk line such as the one extending to the incoming toll thousands selector TMS, Fig. 2, in the called office 8. When this trunk line is reached, the wiper 950 encounters an idle-indicating battery potential on the local C-lead multiple of this trunk, through a resistor (not shown) furnished for this purpose. Switching relay 904 is thereupon operated to apply ground potential directly to C wiper 950 so as to guard the seized inter-office trunk line against further seizure. Relay 904 also closes a locking circuit for its holding winding at its inner upper contacts; it terminates the rotary movement and prepares a connection-holding circuit at its lower armature to be later discussed; and at its two uppermost armatures it disconnects the incoming talking conductors from line relay 901 and extends them, by way of contacts of relays 905 and 908, and wipers 950, to the talking conductors (not shown) of the inter-office trunk line leading to the toll thousands selector TMS Fig. 2. The electro-polarized switch-over control relay 906 has its line winding connected in series with the lower talking conductor, which winding is so poled that the relay is not operated by current flowing over the line in normal direction.

As the succeeding digits are dialled, the connec-

tion is further extended through an operation of the toll thousands selector TMS Fig. 2, the operation of a toll hundreds selector such as THS, and by the operation of a combined toll and local connector such as C-1 to extend the connection to 5 the line of substation A.

Assuming that this line is idle, the toll thousands selector TMS (also referred to as a toll transmission selector) reverses the current flow over the conductors of the inter-office trunk line, 10 thereby bringing about an operation of the electro-polarized switch-over-control relay 906. Upon operating, relay 906 by-passes its line winding so as to remove it from the talking circuit; it connects up the armature of supervisory relay 15 907; and it actuates switch-over relay 905. Relay 905 closes a locking circuit for its lower winding upon operating; it introduces the windings of repeating coil 951 between the incoming talking conductors and the negative and positive wipers 20 950; and it connects the ringing relay 908 to the positive incoming talking conductor by way of the lower left-hand windings of repeating coil 951. Supervisory relay 907 now operates and completes a connection between the grounded incoming C 25 lead and the incoming EC lead, through contacts of the actuated relays 906, 907, 905, and 904, as well as through overflow contacts 916. Ground potential is thus returned on the EC conductor so as to light the calling supervisory lamp 509 in 30 the cord circuit CC-1 when it becomes connected to the EC conductor.

It is to be noted that the loop incoming to the selector TOS-1 is now "dried" and that the holding of connection is now accomplished through 35 the right-hand windings of the repeating coil 951 and supervisory relay 907. The negative incoming conductor extends to the negative pole of the exchange battery by way of the upper left-hand winding of repeating coil 951 and one half of the 40 center-tapped 44,000-ohm resistor, while the incoming positive talking conductor extends to the negative pole of the exchange battery by way of the lower left-hand winding of the repeating coil and the other half of the resistor, in addition to 45 extending to ground by way of the lower left-hand winding of the repeating coil and the 3300-ohm ringing relay 908. Under this condition, loop-test relay 521 in the position equipment becomes restored and permits the extending relay 505 to 50 operate upon the restoration of holding relay 523, which takes place as previously described.

When the automatic ring-control impulse is transmitted (an application of ground potential to the upper conductor through the 20-ohm winding of loop test relay 521 and an application of battery potential through the 100-ohm resistor 526 to the lower talking conductor) ringing relay 908 in the toll office selector TOS-1 is operated momentarily to apply ringing current to the inter-office toll-service trunk and thereby secure the usual intermittent application of ringing current to the called line.

1. Line supervision

The ground potential now placed on the EC lead lights the calling supervisory lamp 509 through contacts of the talking relay 503 to inform the operator of the condition of the extended condition.

2. The called subscriber answers

When the called subscriber answers, the current flow is discontinued over the inter-office toll-service trunk in the usual manner, the connection 75

being held during talking condition from the called line. When this occurs supervisory relay 907 of the toll office selector TOS-1 restores and removes ground potential from the associated EC 5 lead, thereby extinguishing the calling supervisory lamp 509 to give answered supervision.

It is to be noted that supervisory relay 907, upon restoring as above pointed out, closes a holding circuit for the selector by applying 10 ground potential to the C lead thereof through contacts of the actuated relays 904 and 906 whereby the selector is not restored in the event that the operator breaks down the called end of the connection while the receiver is off at the 15 called substation. This provision is made primarily to prevent a release of the toll office selector under this condition, as a release of the selector TOS-1 would unguard the inter-office trunk at a time when the distant terminating selector 20 is held operated locally and is, therefore, unable to release. It is to be noted that this locking of the toll office selector TOS-1 in no way interferes with the release of the toll first selector TFS-1, as the C lead associated with the toll 25 first selector TFS-1 is not extended through the C wiper, but an independent ground connection is made instead to the C wiper 650 for the normal holding of the next succeeding switch.

During conversation, it is to be noted that the 30 pad-control relay 402 is maintained actuated to maintain the circuit of pad cut-out relay 401 open so as to keep the attenuation pad in circuit for the well-known purposes of repeater stabilization and transmission-level uniformity. As previously mentioned, the current supply for maintaining the pad-control relay actuated comes through the 44,000-ohm center-tapped resistor associated with the left-hand windings of repeating coil 951.

40 3. Ring-down supervision from the calling toll exchange

In the event that the calling toll operator desires to signal the operator at Fig. 5 at any time 45 after the connection has been extended, she causes ringing current to be projected over toll line TL-1, thereby bringing about a momentary operation of ring-up relay 407 and a corresponding momentary restoration of signal relay 406. Relay 406 closes the circuit for the upper winding 50 of start relay 408, whereby start relay 408 is momentarily operated. With relays 408 and 409 both operated, the 2000-ohm resistor 410 is inserted in the C lead extending to terminals 450, 55 thereby causing answering supervisory relay 504 to restore, the talking key K-3 being now in restored position.

It is to be noted that start relay 408 does not lock upon operating at this time, as contrasted 60 with its operation under similar circumstances when the call is in the reverse direction. Therefore, relay 408 restores and again excludes resistor 410 from circuit. The answering supervisory relay 404 does not become reoperated when 65 the start relay restores and brings the current flow back to its normal value, as this relay is adjusted so that it will not operate in series with the 500-ohm winding of cut-off relay 409, although it remains operated readily in series with this winding when it has been operated through its own lower winding by way of contacts of the talking key K-3. With relay 504 restored, answering supervisory lamp 507 is lighted to attract the attention of the operator. This lamp becomes 70 extinguished when the operator throws the talk-

ing key K-3 to bring about an operation of talking relay 503.

It will be recalled that answering supervisory relay 504 follows hookswitch supervision when the finder is interconnected with the C. L. R. 5 circuit CLR-1. This is accomplished by virtue of the fact that the 500-ohm winding of cut-off relay 302 is shunted by the 500-ohm resistor 308, whereby sufficient current is permitted to flow to reoperate relay 504 by way of its 10-ohm winding after it has been restored by inclusion of resistor 309. The omission of a similar resistor in shunt of cut-off relay 409 changes the flashing supervision into locked supervision when the finder F-1 is on terminals 450. 15

4. Clearing out the connection

When the called subscriber replaces his receiver, the switch train in the called office causes the current flow to be resumed over the conductors of the inter-office trunk, thereby reoperating supervisory relay 907 to again interconnect the grounded C conductor with the associated EC conductor, thereby lighting the calling supervisory lamp 509 as a disconnect signal. 25

The operator at Fig. 5 may break down the connection by actuating the release keys K-1 and K-2. The finder F-1 and the toll first selector TFS-1 are cleared out as previously described. 30

In the toll office selector TOS-1, relays 904, 905, and 906 restore responsive to the removal of ground potential from the C terminal 900 when the preceding selector clears out. The restoration of relays 904 and 905 breaks the holding circuit of the negative and positive wipers 950 to permit the switches in the called office to restore. Release magnet 911 is operated through off-normal contacts 913 responsive to the restoration of relay 904, whereby the selector is restored 40 to normal position in the usual manner. 40

5. Calling a Sao Paulo manual office

At least one of the offices in the Sao Paulo exchange is a manual office provided with call 45 indicators for displaying called numbers to a call-indicator operator. Although call-indicator positions are equipped to give standard toll supervision, there is an unavoidable delay which occurs before the call-indicator operator can insert the 50 plug into the jack of the called line and thereby cause line supervision to be transmitted back to the involved toll office selector such as TOS-1 Fig. 9. To provide for this special condition, the upper winding of switch-over relay 905 is provided and it becomes connected to the associated incoming EC conductor when switching relay 904 operates. Dial-connecting relay 506 in the cord circuit CC-1 applies ground potential to the EC lead through 1800 ohms. Relay 905 is thereby operated, positively from the toll board cord circuit to bring about the switch-over operation, and thereby permit loop test relay 521 to restore and close the circuit for actuating the extending relay 505. 55

6. Overflow at a toll office selector

In the event that all of the trunks accessible to the toll office selector TOS-1 on the selected level are busy, the wipers 950 are rotated to overflow position. When this position is reached, overflow contacts 916 disconnect the upper winding of switch-over relay 905 to prevent an undesired operation of this relay over the EC lead, while overflow contacts 915 connect the upper 70 75 75

winding of series relay 903 in circuit with the test winding of relay 904 so as to operate switching relay 904 to terminate the operation of rotary magnet 910. Series relay 903 is actuated to shift the C wiper 950 to ground at the contacts of release relay 902, whereby a momentary metering impulse determined by the restoration time of relay 902 is delivered over the C wiper 950. Relays 903 and 904 remain actuated after relays 901 and 902 have restored. A flashing supervisory indication is transmitted back from the common supervisory impulse lead through contacts of the actuated relays 903 and 904 over the EC lead to flash the lamp 509 at the toll board. The selector TOS-1 is cleared out from overflow position when ground potential is removed from its incoming C lead to permit relays 904 and 903 to restore.

20 7. Calls to busy lines

When a line is called at a time when it is in use, the connector through which the connection is attempted finds a busy test condition on the called line. Responsive to this, the apparatus in the toll-service trunking system causes the current flow over the inter-office trunk line to be reversed and to be interrupted at a rate of 120 times a second, which rate is just double that of the rate of flashing when an all-trunks busy or overflow condition is encountered as previously described. In the event that the toll office selector TOS-1 of Fig. 9 is in use in the attempted connection to the busy line, the reversal of current flow brought about when the busy condition is encountered results in the operation of switch-over control relay 906 to bring about the operation of switch-over relay 905 as previously described. Following this, the intermittent operating and releasing of supervisory relay 907 caused by the intermittent current flow over the conductors of the inter-office trunk causes ground potential to be intermittently applied at a rate of 120 times a minute to the associated incoming EC lead. This action results in a characteristic, somewhat rapid, flashing of the calling supervisory lamp such as lamp 509 to notify the operator of the busy condition of the called line.

When the operator breaks down the connection under this condition, the selectors release as before described, as the toll office selector TOS-1 releases between successive operations of supervisory relay 907. The switches in the called office restore responsive to the opening of the loop when selector TOS-1 is cleared out.

55 C. CALLING FROM RIO DE JANEIRO TO CAMPOS

In order to explain briefly the operations involved when a subscriber in Rio de Janeiro desires to be connected with a subscriber in one of the manual exchanges reached over toll lines extending from the Rio de Janeiro exchange, it will be assumed that the subscriber at substation B, Fig. 2, part 2, desires to converse with a subscriber in Campos, reached by way of a group of toll lines such as the toll line TL-5 Figs. 2 and 1.

When the subscriber at substation B removes his receiver, a finder such as F-7 is caused to make connection with his line to connect an office selector such as OS-2. Also, a register sender is connected with the finder selector link, the register sender RS-3 for example. This connection is accomplished by the finder F-6.

When the calling subscriber dials the designation of the Rio de Janeiro toll board the register

7 sender RS-3 causes the office selector OS-2 to trunk the call to the toll board by way of a C. L. R. trunk such as that extending to the C. L. R. circuit CLR-3, whereupon the register sender RS-3 becomes disconnected and is restored to common use. As is indicated in Fig. 20, a call lamp is associated with the jack J-4 of the C. L. R. circuit. Upon noting the lighted condition of this call lamp the operator at the toll board may insert the answering plug of an idle 10 cord circuit into the jack J-4, the answering plug AP of the cord circuit CC-1 for example. When this plug is inserted into jack J-4, the call lamp becomes extinguished responsive to current flow over the sleeve of the jack through the lamp 2001 15 and the associated shunt resistor, while the answering supervisory lamp 2001 does not become lighted at this time.

The operator now manipulates the locking talking key K-9 to bring about an operation of 20 the talking relay 2002. This relay extends the two ends of the cord circuit separately to the position equipment in Fig. 21, the answering end being extended by way of the tip-answer and ring-answer conductors TA and RA, while the 25 calling end is extended by way of the tip-call and ring-call conductors TC and RC. Also, relay 2002 disconnects the sleeve conductor of the plug AP, the lamp 2001, and substitutes the 590-ohm sleeve resistor. This substitution has to do with 30 terminating a locked supervisory condition over a connected toll line upon the response of the operator, as is well known.

In the position equipment PE-2 of Fig. 21, the operator's telephone 2100 is now connected to plug 35 AP of the cord circuit over the conductors TA and RA.

Upon conversing with the calling subscriber and learning that he desires to converse with a subscriber in the Campos exchange, the operator 40 may make the usual tip-busy test by touching the tip of the plug CP to the sleeves of the jacks such as J-3. The tip of this plug is now connected through contacts of the operated relay 2002 and 45 through contacts of the unoperated sleeve relay 2109 to the tip-busy-test wire 2110 extending to telephone set 2100. Assuming that the jack J-4 tests idle, the operator may take the toll line 50 TL-5 for use by inserting the plug CP into the jack J-3. When she does so, sleeve relay 2109 55 operates and disconnects the test conductor 2110 at the same time closing the conductor TC to telephone set 2100.

The operator may project ringing current over the toll line TL-5 by first actuating the split- 55 answer key K-10 and then actuating the ring-ing key K-15 to place a ground potential on the tip conductor and to place a battery potential on the ring conductor, obtained through the resistor 2102. The signalling provisions associated 60 with this toll line may be similar to those disclosed in Fig. 4.

When the Campos operator responds, she may 65 receive the desired number from the Rio de Janeiro operator and proceed to extend the connection to the desired line. It is to be noted that the supervisory lamps 2001 and 2003 are reconnected to the sleeves of the plugs AP and CP respectively when the operator restores the key K-9 to permit the talking relay 2002 to restore.

When the conversation has been completed, the toll operator may receive a disconnect signal at either or both of the lamps 2001 and 2003, whereupon she may take down the connection.

D. CALLING FROM CAMPOS TO RIO DE JANEIRO

Assuming now that a subscriber of the Campos exchange desires to converse with a subscriber in Rio de Janeiro, the call may come into Rio de Janeiro over the toll line TL-5, to the toll line circuit TLC-2, Fig. 20. In this event, the illustrated line lamp becomes lighted as a call signal. Upon noting the lighted condition of this lamp, an operator at the Rio de Janeiro toll board may insert the answering plug of an idle cord circuit, the answering plug AP of the cord circuit CC-2 for example into the jack J-3, thereby causing the call lamp to become extinguished.

The operator manipulates the key K-9 as previously mentioned to associate her telephone 2190 with the circuit through the action of relay 2002. Upon learning the number of the desired subscriber in the Rio de Janeiro exchange, the operator inserts the calling plug CP into an idle jack such as J-5 through which access is had to the toll-service trunking system. When this plug is inserted, the sleeve relay 2011 associated with the jack J-5 operates in series with the sleeve relay 2109 in the position equipment PE-2. Relay 2109 operates as previously pointed out.

Responsive to the operation of relay 2011, a marking condition is placed on the F terminal 2050 in the bank of a finder such as F-4, Fig. 2, and on the multiples of this conductor in the banks of the other finders. At the same time, a circuit is closed through contacts of cut-off relay 2013 for start relay 2010, whereupon this relay operates to cause a finder such as F-4, Fig. 2, to search for the line circuit LC-1. Since the call must be completed through the automatic switches of the Rio de Janeiro exchange, the operator actuates the dial call key K-12 to disconnect conductors TC and RC from her headset and to connect them to the conductors T and R of the digit keys 2100. The operator, however, does not begin to depress these keys in accordance with the desired digits until she is notified to do so by the lighting of the lamp 2104.

When the finder F-4 arrives on the terminals 2050, the movement is arrested in the well-known manner, and cut-off relay 2013 operates to open the start circuit, but the marginally adjusted supervisory relay 2012 is not operated at this time.

The operation of the finder F-4 is accompanied by or followed by an operation of a finder such as F-5 to connect a register sender such as RS-2 to the finder-selector link. When both of these finders have completed their operation, the connection of impulse-receiving relays located in the register sender RS-2 to the tip and ring conductors results in operation of the 15,000-ohm supervisory relay 2013 over the ring conductor R. This relay closes a circuit for the lamp 2014, which lamp becomes lighted to indicate to the operator that she may now proceed to set up the digits in the desired number. In addition to an exchange battery of negative 24-volts, a second or booster battery of positive 60-volts is provided for inter-connection by way of resistors with the digit keys, whereby light and heavy impulses of the two polarities may be transmitted over the two conductors in any one of ten combinations, as is indicated by Fig. 21A. In Fig. 21A, the symbols indicative of impulses have been made light and heavy to correspond to the relative strengths of the transmitted impulses.

After she has depressed the keys successively in accordance with the six digits in the desired

number, the operator may restore the dial call keys K-12, and she may restore the talking key K-9 to permit relay 2002 to restore.

When the connection has been extended to the called line, and in the event that the line tests idle, a supervisory indication is sent back over the sleeve lead of the established connection. This causes increased current flow through the S terminal 2050 and through relays 2013 and 2012. Supervisory relay 2012 now operates and by-passes the 1700-ohm winding of relay 2011 to permit the lamp 2003 to become lighted.

When this lamp becomes lighted, the operator is thereby informed that the connection has been completed to the called line and that the called line is idle. She may start the ringing operation by actuating the split-answer key K-10 and momentarily actuating the ringing key K-15 to apply a ground potential to the ring side of the circuit and a battery potential through the resistor 2102 to the tip side of the circuit.

When the called subscriber answers, the current flow over the sleeve conductor of the established connection is again reduced sufficiently to cause the marginal supervisory relay 2012 to restore and reinsert the 1700-ohm lower winding of relay 2011. When this occurs, supervisory lamp 2003 becomes extinguished.

When the conversation has been completed, and the called subscriber replaces his receiver, the current flow over the sleeve conductor of the established connection is again increased to cause supervisory relay 2012 to operate and light the lamp 2003 through the upper winding of relay 2011. When this occurs, the operator may transmit a ring-off supervisory signal over the toll line TL-5 (by operating split-call key K-13 and ringing key K-15) and take down the connection.

The switches involved are restored to normal condition in known manner when the connection is taken down.

1. Busy signalling

In the event that the called line is busy, a busy-flashing indication is received on the lamp 2003, caused by an intermittent raising and lowering of the sleeve resistance at a rate of 120 impulses a minute. On the other hand, in the event that all the trunks in the desired group are busy and the concerned selector advances to all-trunks-busy condition, a similar flashing condition, but of only sixty impulses per minute obtains.

The partially-established connection is cleared out when the operator takes down her cord circuit.

E. CALLING FROM SAO PAULO TO RIO DE JANEIRO

In order to explain how calls originating in Sao Paulo or reaching Sao Paulo over manual toll lines and directed to Rio de Janeiro are handled, it is assumed that a subscriber in the Sao Paulo exchange calls the toll board over the circuit CLR-1, Figs. 2 and 4, and requests that his line be connected to a desired line of the Rio de Janeiro exchange. It may be assumed that the call is answered by way of the cord circuit CC-1 of Fig. 5.

1. Dialling the Rio de Janeiro toll line number

In order to cause the connection to be completed, the operator brings the calling device CD into the circuit as previously described and dials the trunking digits (4 and 6) assigned to the Rio

de Janeiro exchange, followed by the digits in the number of the desired subscriber line in Rio de Janeiro.

The toll first selector TFS-4 responds to the first digit (4) by raising its wipers opposite the fourth level and bringing them to rest in engagement with the terminals of an idle toll line selector, the terminals 800, for example, of the automatic-toll-line selector TLS-2, Fig. 8. When the toll line selector TLS-2 is seized, line relay 801 is operated over the incoming line conductors, and series relay 803 is operated over the incoming C conductor, through off-normal contacts 811. Release relay 802 is operated by the line relay to complete the preparation of the selector for response to the next digit (6).

When the six interruptions constituting the next digit are produced at the calling device CD, line relay 801 is momentarily restored six times to transmit six impulses to vertical magnet 808.

As soon as off-normal contacts 813 close, as they do upon the first vertical step of the switch, stepping relay 210 is operated through contacts of the actuated series relay 803 and through contacts of the energized vertical magnet 808 to open a point in the automatic vertical stepping circuit of magnet 808. The circuit for stepping relay 210 is closed by the lower armature of relay 803 throughout the directive vertical operation so as to maintain ground potential on the junction of the upper winding of relay 805 and the winding of relay 804 to avoid a possibility of change-over relay 805 operating prematurely as vertical test wiper 821 passes over grounded vertical test contacts. It is to be noted that the lower winding of impulse-series relay 803 receives impulses in multiple with vertical magnet 808 so as to maintain relay 803 actuated during the directive vertical movement.

2. Level hunting

At the end of the series of impulses, wipers 850 are standing opposite the sixth level of bank contacts, and vertical test wiper 821 is standing on the bank contact associated with the sixth level. Series relay 803 restores at the end of the momentary interval for which it is adjusted and prepares an automatic level-hunting circuit for vertical magnet 808, at the same time opening the initial circuit of stepping relay 804. Whether relay 804 restores at this time or not depends upon whether or not all the trunks in the sixth level of bank contacts are in use. If all of these trunks are in use, level-busy relay 822 is in actuated condition and has removed ground potential from the sixth-level test contacts in the banks of all of the wipers such as 821 of the switches having access to the automatic toll line. In this event there is no holding circuit for relay 804 and operating circuit for relay 805 through wiper 821, and relay 804 is restored to deliver an additional impulse to vertical magnet 808, whereby the switch takes an additional vertical step to the next level, whereat the same group-busy test is made, as relay 804 is reoperated by contacts of magnet 808.

Assuming now that there are one or more idle trunks in the called level (the sixth level) relay 822 is not in operated condition when the wipers 70 of the selector come to rest. Under this condition, upon the restoration of series relay 803 and the opening of the initial circuit for stepping relay 804, relay 804 remains operated temporarily in series with the upper winding of change-over relay 805, through wiper 821, the

sixth-level vertical test contact, and through contacts of the non-operated level-busy relay 822. Relay 805 operates in series with relay 804 and closes a locking circuit for its lower winding to ground at contacts of release relay 802. Relay 805 also opens an additional point in the automatic stepping circuit of vertical magnet 808 and completes a self-interrupting circuit for rotary magnet 809. The wipers 850 are thereupon rotated step by step over the sixth level of bank contacts in search of an idle trunk.

Upon the first rotary step, wiper 821 is moved out of engagement with the vertical test bank, whereby the previously closed circuit for relays 804 and 805 in series is opened. Relay 804 restores, but relay 805 is maintained operated in its above-mentioned locking circuit to maintain the circuit of the rotary magnet closed and the circuit of the vertical magnet open.

By the operation of rotary magnet 809, the wipers 850 are rotated step by step over the selected level of bank contacts until an idle toll line is reached.

3. Seizing the repeater IR-2

It may be assumed that the toll line TL-4 associated with the repeater IR-2, Fig. 14, is the first one found to be idle. That being the case, when wipers 850 arrive on terminals 1100, a battery potential is encountered on the C terminal 1100 to energize the test winding (the upper winding) of switching relay 806, which battery potential is obtained through the 250-ohm lower winding of release relay 1105 through contacts of relays 1105, 1125, 1113, 1121, and 1120. Relays 806 and 1105 operate in series over the C lead. Relay 806 opens the circuit of rotary magnet 809 at its lower contacts; by-passes its own test winding to place ground potential directly on the C wiper 850; extends the incoming EC lead to the repeater IR-2; and it disconnects the incoming talking conductors from the windings of line relay 801 and extends them to the repeater IR-2 by way of the negative and positive terminals 1100. Line relay 801 restores responsive to the operation of relay 806, and release relay 802 restores responsive to the operation of relay 806 and the restoration of relay 801. Change-over relay 805 restores responsive to the restoration of release relay 802.

In the repeater IR-2 of Fig. 11, it is to be noted that release relay 1105 has a normally short-circuited 1300-ohm winding which is introduced in series with the lower winding upon the operation of the relay. The operation of relay 1105 is delayed slightly (in order to permit the switching relay 806 of the toll line selector TLS-2 to operate first) by virtue of the circulating current flowing in the short-circuited upper winding of relay 1105 as the flux is built up responsive to current flow through the lower winding of the relay. Upon operating, relay 1105 introduces its 1300-ohm upper winding into circuit; it applies ground potential to the lower terminal of line relay 1103 so as to permit this relay to operate over the talking conductors; and it makes other circuit changes of a preparatory nature, the utility of which will appear as the description progresses.

Line relay 1103 operates over the incoming line conductor responsive to the lower winding thereof being connected up at contacts of release relay 1105, but the differentially-connected cut-off control relay 1102 is not operated at this time. Upon operating, line relay 1103 operates a point

in the circuit of sending relay 1129, and it opens a point in the circuit of preparing relay 1128.

Release relay 1105 also brings about the successive operation of release-pulse timer relays 1106 and 1107. Upon operating, relay 1107 places ground potential on the holding conductor 1150 thereby preparing various operating and locking circuits to be referred to from time to time. In addition, relay 1107 places the supervisory counting relays 1109-1111 under the control of signal-repeating relay 1123; it places a ground potential through contacts of cut-off relay 1101 on the lower armature of line relay 1103 so as to enable the preparing relay 1128 to be actuated when the line relay restores during impulse sending; it removes ground potential from an armature of each of the repeating relays 1123 and 1124 so as to remove the inter-pulse timer relay 1131 from under the influence of these relays.

4. Sending the seizing pulse over the toll line

In order to effect transmission of a seizing impulse over the toll line TL-4, relay 1107 closes a circuit at its lower armature through contacts of sequence relay 1113, contacts of signal-repeating relay 1123, and through contacts of inter-pulse timer 1131 for the supervisory-pulse relay 1127. Upon operating, supervisory-pulse relay 1127 at its lower armature locks itself temporarily to the holding conductor 1150 independent of the contacts of progress-supervisory relay 1113 so as to insure that the concerned relays will go through a prescribed cycle without interference. Relay 1127 closes a circuit for preparing relay 1128 and a circuit for sending relay 1129. Relay 1128 prepares for the transmission of the seizing pulse by opening the talking conductors to prevent the transmission of this pulse to the repeating coil 1175 out to receiving conductors 1182, and it removes ground potential from the direction-transfer conductor 1185 of cable 1200, thereby restoring the normally-energized direction-transfer relay 1202 in order to change over the tone unit TU-2 from receiving to transmitting condition.

Sending relay 1129 connects up the sending conductors 1161 of the cable 1200 to the toll line TL-4 to transmit the seizing pulse over the toll line; it operates sequence relay 1113; it closes a circuit for auxiliary relay 1130 through contacts of supervisory-pulse relay 1127; and it places ground potential on the modulation-cut-off conductor 1167 of cable 1200 so as to present an operation of modulation-cut-off relay 1201 at this time responsive to the operation of sequence relay 1113.

In the tone unit TU-2, Fig. 12, with relay 1202 restored, a 1,000-cycle, one-half volt potential from lead 1242 is impressed on the control grid of the two-way amplifier 1211 causing a 1,000-cycle component to be superimposed on the flow of plate current through plate impedance 1206 from the 130-volt source of plate current. At the same time, the 60-cycle, 40-volt lead 1241 is connected to the suppressor grid (the one adjacent to the plate) of tube 1211 in order to modulate the flow of plate current by the 60-cycle frequency. As a result, a 1,000-cycle current modulated at a 60-cycle rate passes through the plate condenser 1226 to the primary winding of the step-down transformer 1211. Current from the secondary winding of this transformer passes through contacts of the restored direction-transfer relay 1202 to the sending conductors 1161 and then through

contacts of the operated sending relay 1129 to the conductors of the toll line TL-4.

In the repeater IR-2, the seizing pulse is terminated in a manner now to be pointed out:

When auxiliary relay 1130 operates responsive to the operation of sending relay 1129, it closes a circuit for inter-pulse timer relay 1131; relay 1131 operates after a very slight interval and opens the circuit of relay 1127. Relay 1127 restores at the end of a short interval and opens the circuits of relays 1128 to 1130, whereupon relays 1128 to 1130 restore.

Relay 1128 again closes the talking conductors at its two uppermost armatures, in addition to re-operating direction transfer relay 1202 over conductor 1165.

Relay 1129 disconnects sending conductors 1161, and opens the initial circuit of sequence relay 1113, leaving relay 1113 locked to the holding conductor 1150. Relay 1129 also removes ground potential from the modulation-cut-off conductor 1167, permitting modulation-cut-off relay 1201 to operate now through contacts of the actuated sequence relay 1113, contacts of cut-off relay 1101, contacts of the actuated release relay 1105, contacts of answering supervisory relay 1110, and resistor 1142.

Auxiliary relay 1130 opens the circuit of inter-pulse timer relay 1131 and permits that relay to restore after a predetermined interval of time. Upon restoring, relay 1131 reconnects supervisory-pulse relay 1127, but this relay does not reoperate now because its previously closed locking circuit has been opened at its lower contacts and the initial circuit over which it was operated has been opened by contacts of the now-locked sequence relay 1113.

By the foregoing relay operations automatically taking place responsive to the seizure of the repeater IR-2, the repeater has been prepared for the transmission of dial pulses over the toll line TL-4 and a momentary seizing pulse (consisting of 1,000-cycle current interrupted or modulated at a 60-cycle rate) has been transmitted over the toll line TL-4 to Rio de Janeiro to prepare equipment in the distant exchange for the reception of the dial pulses.

Before proceeding with the description of the transmission of the dial pulses to the distant exchange it is thought to be advisable to digress sufficiently to describe the tone unit TU-2 somewhat in detail.

5. The tone unit TU-2

The assemblage of equipment illustrated in Fig. 12 has been termed a tone unit. Other names for this assemblage of equipment have been suggested, including the name "impulse translator." The term "tone unit," however, has been adhered to because the 1,000-cycle frequency at which the dial pulses are transmitted and received over the associated toll line is an audible frequency of a characteristic tone quality.

The tone unit TU-2 includes vacuum tubes 1211, 1212, 1213, and 1214. The tubes 1211 and 1213 are of the type known as 6C6, each being provided with a heater of a nominal rating of 6.3 volts, at which voltage it draws .3 ampere. Tube 1212 is a double-diode tube arranged to function as a differential detector of incoming signals. This tube is of the type known as 6H6, being provided with a two-section heater which requires a potential difference of 6.3 volts to pass .3 ampere through it.

The signal amplifier 1214 is a tube of the type 75

known as 43, having a 25-volt heater which also is rated to draw .3 ampere. The heaters of these tubes are all connected in series, as shown, and they are normally drawing current in circuit 5 with the 4-ohm resistor 1225, through contacts of the normally-actuated key 1231, the connection with the negative pole of the 48-volt exchange battery being made through the 10-ohm test relay 1033. This test relay is normally actuated, but is permitted to restore and close a circuit for the signal lamp 1236 in the event that any one of the tubes is removed from its socket or develops a burned-out or broken heater element. The potential drop along the heater circuit 15 from the negative pole of the 48-volt battery is used at various points for grid-biasing purposes, as will be pointed out.

Tube 1211 is used as a two-way amplifier, being used as an outgoing amplifier in the transmission of signals to the toll line TL-4, as previously described in the case of the transmission of a seizing impulse. This tube is provided with a cathode as indicated, adjacent which is shown the control grid. Adjacent the control grid is 25 the screen grid which is supplied with positive potential from the 130-volt source of plate current through the 50,000-ohm resistor 1227, being by-passed to ground by the .1 mf. condenser 1228. Between control grid and the plate, there is 30 shown the suppressor grid which is connected either to ground potential or to the 60-cycle 40-volt lead 1241, depending upon the actuated or restored condition of relays 1201 and 1202.

For the reception of signals, the primary winding of the 1-3-ratio step-up transformer 1224 is connected to the receiving conductors 1162 through the two illustrated condensers. The secondary winding of this transformer is normally connected to control the potential applied 40 to the control grid of tube 1211, a negative biasing potential of 1.2 volts being applied to the control grid of tube 1211 by virtue of the 1.2 volt drop across the 4-ohm resistor 1225.

With direction-transfer relay 1202 in operated position, as it normally is, the secondary winding of the step-down transformer 1217 is connected across the leads 1243 and 1244. The inductance coil 1223 is connected across the leads 1243 and 1244 in series with the .04 mf. condenser 1222, which condenser is shunted by the indicated trimmer condenser of such capacity as to render the couple series resonant at 1,000 cycles, whereby a relatively high potential is placed on the right-hand anode of the differential detector 1212 by the voltage drop across coil 55 1223 when a 1,000-cycle current is being received.

In order to enable the system to respond to impulses of 1,000 cycles, plus or minus an amount equal to about sixty cycles in order to allow for 60 the reception of 60-cycle-modulated 1,000-cycle impulses, and to cut off sharply when frequencies higher or lower than the allowable band are received, the inductance coils 1219, 1221, and 1223, with their associated tuning condensers are arranged to form what may be termed a triple-peak tuner. This tuner peaks at 900 cycles, at 65 1,000 cycles, and at 1100 cycles. The 1,000-cycle peak is produced by the inductance coil 1223 and its associated condensers, as previously pointed out. The 900-cycle peak and 1100-cycle peak are produced by coil 1221 and its associated condensers, with the assistance of the 1100-cycle shunt-resonant couple formed by inductance coil 1219 and the associated shunt condensers. Coil 70 1221, in series with the tuning condenser 1220

(assisted by the associated trimmer condenser) is resonant at 1100 cycles provided substantially no current is permitted to flow through the shunt condenser 1218, having a capacity of about .01 mf. At 1100 cycles, current is substantially 5 prevented from flowing through condenser 1218 by the shunt-resonant effect of coil 1219 and the associated shunt condensers, as this shunt system is resonant at 1100 cycles. When current is received at some other frequency, however, the 10 shunt-resonant condition is not present at coil 1219 and the associated shunt tuning condensers, permitting current to pass through condenser 1218 by way of coil 1219 and the associated shunt condenser. The value of condenser 1218 is so 15 chosen that it (connected in multiple with tuning condenser 1220 through the system composed of coil 1219 and its associated condensers) makes the coil 1221 have a resonant peak at 900 cycles, in addition to the previously described one at 20 1100 cycles.

The way in which the triple-peak tuning arrangement operated to control the impulse amplifier 1213 by way of the differential detector 25 1212 will now be pointed out:

It is to be noted that the control grid of the impulse amplifier 1213 is normally provided with a negative grid bias of 20.1 volts by virtue of its connection to the heater circuit, which amount represents the drop across the heaters of 1213, 30 1212, and 1211, in addition to the drop across the 4-ohm resistor 1225. This grid bias is supplied to the control grid of tube 1213 through the center tapped .6-megohm resistor comprising sections 35 1229 and 1230. Each section of this resistor is by-passed by .1 mf. stabilizing condenser, as shown. By virtue of the connection of conductor 1244 to the center tap of the grid resistor associated with impulse amplifier 1213, and the connection of the lower terminal of this resistor to 40 the heater circuit at a point of negative 20.1 volts, a potential of negative 20.1 volts is normally maintained on each of the plates of the differential detector 1212. The cathode associated with the plate connected to the 1,000-cycle 45 coil 1223 is also supplied with a biasing potential of negative 20.1 volts, whereby there is normally no biasing potential between the cathode and anode of tube 1212 with respect to coil 1223.

The cathode associated with the double-peak 50 coil 1221 (resonant at 900 cycles and at 1100 cycles) is connected to the heater circuit at a point of negative 1.2 volts potential, whereby the plate connected to coil 1221 is normally 18.9 volts more negative than the associated cathode, 55 by virtue of which fact no current passes through the left-hand portion of the differential detector until the rather substantial adverse bias of 18.9 volts is overcome.

During the reception of a signal, the building 60 up of a 1000-cycle potential across coil 1223 causes current to flow through the associated cathode and anode of tube 1212 in series with the section 65 1229 of the grid resistor. This half-wave-rectified current passes through the upper section 1229 of the resistor and renders the upper terminal of this resistor section more positive than the lower terminal, thereby offsetting to this extent the negative potential normally applied to the control grid of impulse amplifier 70 1213. On the other hand, when the signal contains a sufficient component at 900-cycles or 1100-cycles to cause a sufficient potential to be built up across coil 1221 to overcome the 18.9-volts bias current flows in the left-hand section 75

of the differential detector 1212. This half-wave-rectified current passes through the lower section 1230 of the grid resistor associated with tube 1213, causing the mid-point of this resistor to become more negative than the lower terminal thereof by virtue of the potential drop through section 1230. Therefore, when a signal other than a wanted signal is received and which falls in the neighborhood of 900-cycles or 1100-cycles, the current flowing through coil 1221 and the associated section of the differential detector and obtained through the section 1230 of the grid resistor associated with tube 1213 tends to render the grid of tube 1213 more negative than it normally is, thereby preventing a response at tube 1213 to the signal, even though the signal may contain a sufficient 1000-cycle component to otherwise secure a response.

It is to be noted that a pulse-cut-in relay 1204 is provided to be controlled over pulse-cut-in conductor 1168 from the associated repeater. When the tone unit TU-2 is to be used to receive dial impulses from a distant exchange, relay 1204 is operated to substitute incoming-impulse relay 1203 for retard coil 1207 in the plate circuit of impulse amplifier 1213. The previously mentioned grid bias normally existing on the control grid of tube 1213 is sufficient to block flow of current from the 130-volt source of plate current. However, when a signal is received which causes the potential on the control grid of tube 1213 to be brought down to a negative value of about 16 volts, current starts to flow through the tube, it being noted that the screen grid and suppressor grid of this tube are connected to the plate to secure a triode of the desire characteristics. As the potential of the control grid is rendered still less negative, relay 1203 operates when about 4.5 milliamperes of current are flowing in the plate circuit, about 9 milliamperes being preferable for operating the relay reliably during the reception of dial pulses.

A number of desirable features of operation reside in the tone-unit arrangement, certain of which are as follows:

1. A fairly constant response of incoming impulse relay over a wide range of input voltage is inherent in the disclosed arrangement because of the tendency of the grid-cathode circuit of tube 1213 to draw a grid current when the input signal voltage is sufficiently high to overcome the normal biasing voltage of negative 20.1 volts. This characteristic of the tube imposes a rather definite limit on the response of the relay to a vigorous signal impulse.

2. The coil 1223 and the associated tuning condensers 1222 comprise a resonant couple having the maximum response at 1,000-cycles, but not sharply peaked. The double-peak coil 1220, associated with the left-hand section of the double-diode tube 1212, offers no opposing effect until the previously mentioned biasing potential of 19.9 volts is overcome, thereby affording definite frequency-cut-off points above and below the desired 1,000-cycle resonant point, while there is a rather flat frequency response over the selected band. This band is about 120 cycles wide in order to provide for the reception of 60-cycle-modulated, 1000-cycle signal impulses. These two frequency cut-off limits remain substantially constant independent of input voltage because of the biasing arrangement which is adverse to the flow of current in the left-hand section of differential detector 1212 until it is abruptly over-

3. By arranging that the response curve of the coils 1221 and 1223 intermingle (coil 1221 peaks at 900 and at 1100 but still builds up an appreciable voltage at 1,000 cycles) the voltage built up across the double-peak coil 1221 at the 1,000-cycle signal frequency is sufficient at high input voltage to prevent excessive overloading of tube 1213, thereby further tending to secure a uniform response over a wide limit of input voltage as well as providing for reliable operation of the incoming signal relay 1205 responsive to 60-cycle modulations of the 1,000-cycle signal current.

The signal amplifier 1214 is provided to amplify the 60-cycle modulations received at the plate of impulse amplifier 1213. The control grid 15 of tube 1214 is provided with a normal biasing potential of negative 20.1 volts through the 100,000 ohm grid resistor 1232. At this biasing voltage, substantial plate current flows through the plate circuit of the tube through the plate 20 impedance coil 1208 from the 130-volt source of plate current, the screen grid of this tube being connected directly to the source of plate current while the suppressor grid is connected directly to the cathode, to provide the usual form of pentode 25 operation. The .1 mf. coupling condenser 1231 serves to couple the plate of tube 1213 with the control grid of tube 1214, to transmit the 60-cycle signal impulses to the signal amplifier.

After amplification, the signal impulses pass to 30 the incoming signal relay 1205 by way of the .3 mf. condenser 1234. Condenser 1234 and the winding of relay 1205 are so chosen as to be resonant at about 60 cycles, whereby the incoming signal relay is prevented from responding when 35 the 1,000-cycle dial impulses following each other at about 10 impulses per second are received.

The .006 mf. condenser 1235 is provided to by-pass the amplified, half-wave-rectified 1,000-cycle carrier current from relay 1205, as it is 40 found in practice that otherwise this amplified 1,000-cycle potential is sufficiently high to cause undesired brush discharges.

The tone unit TU-2 having been described somewhat in detail, the description of the establishment of the connection from the calling line 45 in Sao Paulo to the desired line in Rio de Janeiro will be resumed.

6. Sending the dial pulses over the toll line 50

When the calling device CD Fig. 5 is operated for the next digit following the seizure of the toll line TL-4 and the impulse repeater IR-2, Fig. 11, line relay 1103 is de-energised momentarily 55 a corresponding number of times. With relay 1107 now operated as above pointed out, ground potential is extended through contacts of cut-off relay 1101 to the lower armature of line relay 1103. Therefore, upon the first restoration of line relay 1103, a circuit is closed through contacts of line-supervisory relay 1109 for the 400-ohm lower winding of preparing relay 1128. This lower winding of relay 1128 is a very powerful winding effective to operate the relay 1128 very vigorously 60 so as to prepare the necessary circuits for the transmission of the dial pulses over the toll line without unnecessary delay. Preparing relay 1128 cuts off the receiving conductors 1152 at its two upper-most armatures and it removes ground potential from the direction-conductor 1155 so as to permit direction-transfer relay 1202 to 65 restore, which it does with great promptness because of the heavy spring load which it is carrying. With the modulation cut-off relay 1201 now operated over conductor 1167 through the resistor 70 75

1142 as above pointed out, upon the restoration of direction-transfer relay 1202, unmodulated 1,000-cycle current is caused to flow in the sending leads 1161 by virtue of the connection of the 5 1,000-cycle lead 1242 to control grid of tube 1211. Impulse series 1104 is operated in multiple with the lower winding of preparing relay 1128 through contacts of the operated-release relay 1103. Being slow-acting, relay 1104 remains operated throughout the series of impulses. At its 10 lower contacts, relay 1104 extends ground potential through the contacts of the now-operated sequence relay 1113 to the 1800-ohm upper winding of preparing relay 1128 so as to maintain 15 this preparing relay operated continuously throughout the series of impulses.

As a further result of each momentary de-energisation of line relay 1103, a circuit is closed at the inner contacts of this relay (from ground 20 potential obtained from the grounded holding conductor 1150 through contacts of cut-off relay 1101) through contacts of line supervisory relay 1109 and contacts of the operated release relay 1105 for sending relay 1129. Relay 1129 therefore 25 responds to send a momentary impulse of 1,000-cycle current (obtained from the sending lead 1161) over the toll line for each restoration of line relay 1103.

At the end of the series of impulses, series relay 30 1104 is permitted to restore and open the circuit of the upper winding of preparing relay 1128 to permit this relay to restore also. Relay 1128 again permits the direction-transfer relay 1202 to operate and place the two-way amplifier 1211 in 35 condition to receive impulses from over the toll line TL-4.

Each of the remaining digits is transmitted over the toll line TL-4 in this manner.

7. Drying the loop

When the transfer relay 522 in the equipment of Fig. 5 is permitted to restore responsive to the restoration of dial key K-6 and the arrival of the calling device CD in normal position at the 45 end of the final digit, the opening of the positive conductor of the loop and the connection of the negative conductor to ground through loop-test relay 521 results in the unbalancing of the differential cut-off-control relay 1102. Relay 50 1102 thereupon operates and closes a circuit for cut-off relay 1101. When relay 1101 operates it closes a locking circuit for itself through contacts of the operated relay 1101, at the same time disconnecting ground potential from the 55 lower contacts of relays 1103 and relay 1104. Relay 1101 also disconnects the grounded holding conductor 1150 from the inner contacts of line relay 1103; it disconnects resistor 1142 from modulation-cut-off conductor 1167 to restore 60 modulation-cut-off relay 1201 in the tone unit TU-2; it disconnects the line relay 1103 and cut-off-control relay 1102 from in bridge of the incoming talking conductors; and it extends the incoming talking conductors to the left-hand 65 windings of repeating coil 1175, whereby the guard and ringing relays 1125 and 1126 are brought under the control of the talking conductors incoming from terminals 1100.

8. Sending the ring-start impulse over the toll line

When, a moment later, the ring-start impulse is automatically transmitted from resistor 526 through contacts of relay 522, 523, and 506, ring- 70 ing relay 1126 is operated momentarily. Upon

operating, relay 1126 extends ground potential through contacts of signal-repeating relay 1123, through contacts of inter-pulse timer relay 1131 to operate the supervisory-pulse relay 1127. Responsive to the operation of relay 1127, relays 5 1128, 1129, and 1130 are operated. Relay 1128 prepares for the sending of an impulse over the toll line, and relay 1129 connects up the sending conductors 1161. Modulator-cut-off relay 1201 having been restored by relay 1101, a 60-cycle-modulated 1,000-cycle impulse is transmitted. Inner-pulse-timer relay 1131 is operated responsive to the operation of auxiliary relay 1130 to disconnect relay 1127 and thereby terminate the impulse after the delay period of relay 1127 has 15 elapsed. Relay 1131 restores after an interval and reconnects relay 1127.

By the time the relays 1121-1131 have gone through the complete cycle of operation described, the ringing pulse transmitted to ringing 20 relay 1126 has ended and relay 1126 is in restored condition.

The apparatus in and associated with repeater IR-2 remains in this condition until the connection has been extended in the Rio de Janeiro 25 exchange to the called line, at which time a supervisory impulse indicative of this fact is received over the toll line as will be subsequently pointed out.

The way in which the apparatus in the Rio 30 de Janeiro exchange responds to the seizure of the toll line TR-4 in Sao Paulo and to the transmission of the dial pulses and ring-start pulse will now be explained.

9. The coder CR is preselected

It has been pointed out previously that the dial pulses which arrive over the toll line TL-4 from Sao Paulo must be recorded, coded, and be transmitted to a register sender and that this recording and coding for the control of the register senders is accomplished by six coders, one of which is the coder CR Figs. 2 and 16. Because of the minimum delay which is allowable between successive digits, it is necessary that an idle one of these coders be connected immediately to a repeater when the associated toll line is seized at Sao Paulo, which connection is taken care of automatically through the preselector PS Fig. 15. It is assumed that the number one coder (CR), shown in Fig. 16, is preselected by the preselector PS, Fig. 15, at the time the toll line TL-4 is seized in Sao Paulo and the seizing impulse is received in Rio de Janeiro. Under this assumption, preselecting relay 1501 has been operated and is locked in operated condition over its lower winding and guard conductor G, grounded through contacts of relays 1606 and 1605 and the contacts of the make-busy key 1608. With relay 1501 operated, connecting relays CA-1, CB-1, and CC-1, are operated to prepare for the operation of any one of the twenty-five (one for each one of the twenty-five associated toll lines) associated with the number one coder.

10. Seizing the coder CR

Keeping in mind that the tone unit TU-4, Fig. 13, is similar to the tone unit TU-2, Fig. 12, it will be understood that this tone unit is normally adapted for receiving because of the normally grounded condition of direction-transfer conductor 1465 through contacts of preparing relay 1428.

When the 60-cycle-modulated 1,000-cycle seizing impulse is received at the tone unit TU-4, 75

this impulse is amplified and detected, following which it received further amplification so that it operates the relay in the tone unit TU-4 corresponding to the incoming signal relay 1205 of the tone unit TU-2. The signal relay makes an application of ground potential to signal-in conductor 1463, thereby momentarily operating signal-repeating relay 1423. Signal-repeating relay 1423, whose lower armature is normally 10 grounded through contacts of relay 1407, closes a circuit for inter-pulse-timer relay 1431. Relay 1431 operates but produces no useful result at this time. A branch circuit, however, extends through contacts of relays 1417 and 1405 to im- 15 pulse series relay 1404. Relay 1404 operates to prepare a circuit for relay 1419. Signal-repeating relay 1423 also opens the circuit of the slow-acting incoming-release relay 1421, and closes a circuit (from ground through contacts of guard 20 relay 1425) which extends, through contacts of the normally-operated slow-acting incoming release relay, 1421, and through contacts of the non-operated relay 1407, to selector-seizing relay 1420. Relay 1420 is a differential, stored- 25 energy counting relay of the type disclosed in application Serial Number 78,221, filed by Merton R. Miller on May 6, 1936. A relatively strong current flow takes place through the lower winding of relay 1420, while the reverse current- 30 flow through the upper winding of this relay is reduced somewhat by the associated 300-ohm series resistor. As a result, energy is stored in the lower winding of relay 1420, but the relay does not operate as long as the circuit remains 35 closed through the two mutually opposing windings in parallel.

When the momentary seizing impulse is terminated and signal-repeating relay 1423 restores, the stored energy in relay 1420 causes 40 this relay to operate as the result of induced current flowing through the two windings in series when the initial circuit is opened. Upon operating, relay 1420 closes a locking circuit for both its windings in series, aiding to ground at 45 contacts of the normally operated slow-acting release relay 1421. At the same time, the associated resistor is disconnected so that the relay does not draw excessive holding current. Relay 1420 places ground potential on holding conductor 1450; it places ground potential on the incoming-control conductor 1451; and it makes 50 other circuit changes which will be discussed separately hereinafter.

In order to effect the seizure of the preselected coder of Fig. 16, selector-seizing relay 1420 closes 55 a circuit for the lower winding of loop-test relay 1419 through contacts of the still-operated slow-acting series relay 1404. Relay 1419 thereupon operates and prepares a locking circuit for its 60 winding through the upper contacts of selector-seizing relay 1420, at the same operating coder-seizing relay 1437 from the grounded holding conductor 1450, whereupon coder-seizing relay 1437 operates and locks itself to conductor 1450 through contacts of switch-over relay 1427. Coder-seizing relay 1437 connects the tip and 65 ring conductors T and R of the cable C-1 to the tip and ring conductors T and R extending to the line circuit of Fig. 19; it transfers the tip and ring conductors associated with the upper winding of loop-test relay 1419 from the tip and ring conductors extending to the line circuit of Fig. 19 and connects them to the pulse conductor P of cable C-1, respectively, the ground 70 potential being applied to the transferred ring 75

conductor through contacts of ringing-prepare relay 1415, and contacts of supervisory relay 1422, from the grounded incoming control conductor 1451. Relay 1437 at its upper contacts places ground on the operating conductor O of the cable C-1, thereby extending an operating potential through the upper winding of the differential cut-off relay CO-1 and way of contacts of the operated connecting-relay CA1 to the connecting relay IC1 for inter-connecting the toll line with the first of the six coders. Cut-off relay CO-1 is a differential relay which does not operate from the current flowing in its lower winding from the operating conductor O as long as current flows in its upper winding through 10 a relay, such as IC1, shunted by the associated 2,000-ohm resistor. Relay IC1 operates through the 100-ohm upper winding of relay CO-1 and prepares a locking circuit for itself which becomes closed upon the subsequent restoration 15 of relay 1601. Relay IC1 also further extends the tip and ring conductors T and R of the cable C-1 to the tip and ring conductors T and R of the coder link CL-1. Relay IC1 also extends the pulse conductor P of the cable C-1 to the pulse 20 conductor P of the coder link CL-1, extending to battery through contacts of relay 1603 by way of the ten-ohm winding of the marginal transfer relay 1604 and the 400-ohm winding of pulse relay 1605. Relays 1604 and 1605 thereupon operate in series over this circuit, in series with the upper winding of the still-operated loop-test relay 1419, the inner terminal of the upper winding of which is now supplied with ground potential as previously mentioned, through the upper 25 contacts of the relay, contacts of switch-over relay 1417, contacts of the operated coder-seizing relay 1417, contacts of ring-prepare relay 1415, contacts of supervisory relay 1422, the incoming control conductor 1451, grounded at the lower 30 contacts of selector-seizing relay 1420. Loop-test relay 1419 is maintained operated in this circuit by means of its 300-ohm upper winding to maintain the loop closed. 35

Pulse relay 1605 closes a circuit for release relay 1606, and relay 1606 prepares a circuit extending to priming relay 1608 and a circuit extending to impulse-series relay 1607, preparatory to the reception of digit impulses received over the toll line by the repeater of Fig. 14 and relayed to the coder CR. 40

Pulse relay 1605 and release relay 1606 remove ground potential from the guard conductors G, thereby opening the locking circuit of preselecting relay 1601. Relay 1601 thereupon restores to 45 permit the next coder to become preselected and to permit relays CA1, CB1, and CC1 to restore. Relay IC1 now becomes locked through contacts of the restored relay 1601. With relay IC1 locked operated and relay CC1 restored, the differential 50 cut-off relay, becoming unbalanced, operates by means of its lower winding and remains operated to maintain the extension of conductor O of cable C-1 disconnected, thereby preventing a second-coder from being seized thereover. 55

11. Guarding the toll line in Rio de Janeiro

As a further result of its previously-mentioned operation selector-seizing relay 1420 places a battery potential, obtained through the illustrated 70 200-ohm resistor, on the sleeve conductor S extending to the jacks J-2 which outgoing toll calls are made over the toll line TL-4, thereby causing this jack to provide a tip-busy test so as to mark it engaged at the toll board. 75

12. Taking a toll office selector for use

In order to prepare for the extension of the connections in number, supervisory relay 1422 is connected at contacts of selector-seizing relay 1420 to the sleeve lead S extending through contacts of signal relay 1902 to the start relay 2021 of the line circuit LC-2 Fig. 20. Start relay 2021 is operated in series with the marginal supervisory relay 1422, but relay 1422 is not operated at this time because of the inclusion of the 1700-ohm lower winding of start relay LC-2 in the circuit. Relay LC-2 closes a circuit through contacts of cut-off relay 2023 for the common start relay 2010 in order to start a finder such as the finder F-4 Fig. 2, part 2, searching for the terminals 2008, of which the terminal S together with the multiples thereof in the banks of the other finders, is marked as calling by the negative potential impressed thereon through the windings of relays 2012 and 2013.

The searching of a finder such as F-4 and a finder such as F-5, Fig. 2, take place while digits are being received over the toll line TL-4 from the Sao Paulo exchange.

13. Cutting in the incoming impulse relay

Loop-test relay 1419 also places a ground potential on the pulse-cut-in conductor 1466, leading through the illustrated cable to the tone unit TU-4, Fig. 13, thereby bringing about the operation of the pulse-cut-in relay therein corresponding to pulse-cut-in relay 1204 of the tone unit TU-2. This relay operates and places in circuit the associated incoming-impulse relay, corresponding to incoming impulse relay 1203 of the tone unit TU-2.

Loop-test relay 1419 also operates auxiliary relay 1418 to open a point in the circuit of switch-over relay 1417, and to connect up time-pulse lead 1468 to the time-pulse relay 1432 to provide for a clearing out of the circuit in the event that no dialing occurs, as will be discussed subsequently. At its lower contacts relay 1418 extends ground potential (obtained from the grounded-incoming control conductor 1451 through contacts of supervisory relay 1422) through contacts of relays 1411, 1410, and 1409 to the windings of relay 1409, thereby causing energy to be stored in the windings of this differential, stored-energy counting relay to prepare for the subsequent operation thereof.

14. Receiving the digit pulses: Disconnecting the ring-down lead

When the impulse constituting the digits in the Rio de Janeiro number of the called subscriber are received, these impulses come into the tone unit TU-4 through the receiving leads 1462. As will be explained more fully in connection with a call in the reverse direction and affecting the fully-disclosed tone unit TU-2 for each dial pulse of unmodulated 1,000-cycle current received over lead 1462, the relay in the tone unit TU-4 which corresponds to relay 1203 of the tone unit TU-2 transmits a momentary impulse over the dial-in conductor 1464 to the incoming-repeating relay 1424. The first time it responds, incoming-repeating relay 1424 closes a circuit for the two-step ring-control relay 1416. This relay operates and closes its lightly-adjusted locking contacts indicated by the letter "X" so as to close a locking circuit for its two windings in series. No current flows through the upper winding of the relay for the time being, however, because of the fact that this winding is provided

with ground potential at both terminals thereof until incoming-repeating relay 1424 next restores. Upon this restoration, ring-control relay 1416 is operated through its second step, breaking a further point in its initial-energizing circuit. Relay 1416 disconnects the associated ring-down lead RD extending to the incoming line circuit of Fig. 19, whereby the bringing in of a signal at lamp 1901 is prevented. Relay 1416 also prepares a circuit 1417 for ring-prepare relay 1415, to be subsequently discussed.

As a result of each momentary operation of incoming repeating relay 1424, the circuit extending over the pulse lead P as previously traced to the pulse relay 1605 of the coder CR is broken at the upper contacts of relay 1424. The maintenance of loop-test relay 1419 in operated condition during the series of impulses is insured by the closure of a circuit for the lower winding of this relay at contacts of slow-releasing impulse-series relay 1404, which relay is operated through the lower contacts of relay 1424 and remains operated throughout the series of impulses.

At the end of the series of impulses, incoming-repeating relay 1424 comes to rest in a de-energized condition and impulse-series relay 1404 restores and opens the circuit of the lower winding of loop-test relay 1419, leaving this relay operated only over the loop impulse circuit extending over the pulse lead P of the cable C-1 to the coder of Fig. 16.

Each subsequently received series of impulses is repeated into the coder CR in the same way.

15. Counting the digit pulses

In the coder CR—Fig. 16, with release relay 1606 held operated by pulse relay 1605, a holding ground potential is maintained on holding conductor 1608 and a positive holding potential is placed on conductor 1654 at the lower contacts of release relay 1606 from the positive terminal of the 60-volt battery by way of the illustrated 150-ohm protective resistor. This additional holding conductor is provided because relays of the digit-storage device DS-1 to DS-6 Fig. 16, part 2, must be provided with a holding potential of either of two polarities in order that the holding current will agree in polarity with the actuating current supplied, as will subsequently be brought out.

When a received digit is relayed to the coder CR (as a momentary interruption of the pulse lead P) relays 1604 and 1605 restore. Pulse relay 1605 is immediately reoperated over the pulse lead P when this lead is again closed, but marginal transfer control relay 1604 usually does not reoperate during the receipt of a series of pulses because of the relatively small number of turns constituting its 10-ohm winding, but it reoperates at the end of the series of pulses.

When pulse relay 1605 restores the first time, it closes a circuit through contacts of release relay 1606 for the slow-releasing impulse-series 1607. Relay 1607 is thereby operated upon the receipt of the first impulse of the series and it remains operated throughout the series. Series relay 1607 prepares a circuit for digit-transfer relay 1617, and it places a ground potential on conductor 1650, thereby closing a circuit for the lower winding of the differential, stored-impulse counting relay 1621 of the group of counting sequence relays 1621-1626, there being one for each of the six digits in a received number.

Upon each restoration of relay 1605 a circuit is closed through contacts of the operated-release

relay 1606 for the priming relay 1608, associated with the counting relays 1611-1614 which are arranged to operate in a reflexed counting circuit to count and store an indication of an impulse series containing any number of impulses from one to ten. The first time it operates, priming relay 1608 closes a locking circuit for itself in series with the 90-ohm upper winding of counting relay 1611, to conductor 1650, grounded at contacts of impulse series relay 1607.

When pulse relay 1605 restores at the end of the first impulse, it breaks the initial circuit of priming relay 1608, but priming relay 1608 remains operated momentarily in its locking circuit through the upper winding of counting relay 1611. Relay 1608 is given what is known as a stiff adjustment (heavy restoring spring tension) but this spring tension is insufficient to restore the relay immediately following the opening of its circuit at the pulse relay 1605 because of the large amount of stored energy represented by the flow of current in relay 1608. A large part of this stored energy is dissipated in the operation of counting relay 1611.

When relay 1611 operates, it closes a locking circuit for itself at its inner lower contacts to the grounded holding conductor 1650, which locking circuit includes contacts of relays 1615, and 1614, in addition to the normally-closed contacts controlled by the inner lower armature of relay 1615. The locking contacts are the first of the contacts of relay 1611 to become actuated, whereby the relay is quickly locked energized independent of its actuating winding. As the relay 1611 is actuated still further, it breaks its initial actuating circuit and then transfers the actuating conductor associated with priming relay 1608 to the next and succeeding counting relay 1612. Since relay 1608 is almost ready to let go because of the relatively great restoring spring tension, this relay restores when its circuit is transferred from one counting relay to the next, as the actuating circuit of the counting relay being operated is broken before the locking circuit of the priming relay is transferred to the next succeeding counting relay. During this transferring operation all current flow must cease in the winding of the priming relay and this relay restores before the current flow can be re-established upon the transfer of the circuit to the next succeeding counting relay.

In order that the complete operation of the counting relays and the associated switching relays 1615 and 1616 be understood, their operation in response to a series of ten impulses will be explained. It may be kept in mind that priming relay 1608 is operated each time pulse relay 1608 restores, and that upon operating it closes a locking circuit for itself in series with the connected counting relay.

The encircled numbers 1 to 4 adjacent relays 1611 to 1614, respectively, indicate that these relays respond to the first four impulses; the encircled numbers 5 to 8 indicate that these relays respond again to the next four impulses; and the encircled numbers 9 and 10 indicate that relays 1611 and 1612 respond for the third time to the ninth and tenth impulses respectively.

Upon the termination of the second impulse, the upper winding of counting relay 1612 is energized in the locking circuit of priming relay 1608. Relay 1612 closes a locking circuit for itself in multiple with the lower winding of counting relay 1650, transferring the circuit to the next succeeding counting relay 1613.

At the end of the third next pulse the reoperated priming relay 1608 remains locked momentarily in series with the upper winding of counting relay 1613, and this counting relay operates and locks itself to conductor 1650 through the lower contacts of relays 1615 and 1614 and through additional contacts of relay 1615.

At the end of the fourth impulse the upper winding of relay 1614 is operated in series with priming relay 1608, and relay 1614 locks itself through contacts of relay 1615 to conductor 1650, at the same time opening its own initial circuit and the locking circuit of relays 1611-1613. Relays 1611-1613 now restore, leaving relay 1614 locked operated. Upon the restoration of relay 1611, the lower winding of switching relay 1615 is connected in multiple with the locking winding of relay 1614, whereupon relay 1615 operates and locks itself directly to conductor 1650. At the same time preparing new locking circuits for relays 1611-1613, and shifting the locking circuit of the lower winding relay 1614 so that it includes the upper contacts of relay 1612.

Relays 1611-1614 having responded respectively to the first four impulses, and switching relay 1614 having operated, relays 1611-1613 are now in restored condition and enable them to respond to the next three impulses of the series.

Responsive to the fifth impulse, relay 1611 is re-operated, at which time it closes a locking circuit for itself through contacts of the actuated switching relay 1615 and contacts of the restored relay 1613.

When it is reoperated at the end of the sixth impulse, relay 1612 closes a locking circuit for its lower winding in parallel with that of relay 1611, and it breaks the locking circuit of relay 1614 at its upper contacts, permitting this relay to restore.

When relay 1613 reoperates at the end of the seventh impulse, it closes a locking circuit for itself through contacts of the actuated relay 1615, at the same time preparing a circuit at its middle upper armature for relocking counting relay 1614. Relay 1613 also shifts the locking circuit of relays 1611 and 1612 at its lower armature so that they remain locked through the lower contacts of the restored relay 1614, through the inner armature of the operated relay 1615, to the grounded conductor 1650, through the middle armature of the operated relay 1613.

When 1614 operates at the end of the eighth pulse, in addition to closing a locking circuit for its lower winding, it breaks the locking circuit of relays 1611 and 1612 to enable them to restore preparatory to responding to the ninth and tenth pulses. Upon restoration of relay 1611, a circuit is closed at the upper contacts of this relay through the upper contacts of the actuated relays 1613, 1614, 1615 for energizing relay 1616 in multiple with the locking winding of relay 1614. Relay 1616 closes a locking circuit for itself at its upper contacts, while at its inner lower contacts it prepares a new locking circuit for relays 1611 and 1612.

Relay 1611 is reoperated at the end of the ninth pulse of the series, and relay 1612 is re-operated at the end of the tenth impulse, each relay closing a locking circuit for itself to conductor 1650 through the inner lower contacts of relay 1616.

16. Storing the received digits

Whatever the number of impulses contained in the first series, corresponding to any digit value

from 1 to 0, the appropriate combination of counting relays 1611 to 1614 and switching relays 1615 and 1616 is operated in the hereinbefore described manner to prepare circuits over the 5 A-B code conductor 1651 and over the C-D code conductor 1652 for transferring the temporarily-stored digit value to the first of the six storage devices DS-1 to DS-6, Fig. 16, part 2. The transferring of the stored digits takes place 10 only after all of the impulses have arrived and after relays 1604 and 1605 have become operated steadily. At this point the slow-operating transfer relay 1617, which cannot become operated during an impulse series because of its slow-operating characteristics, operates to effect the transfer. The operation of relay 1617 occurs before the slow-releasing impulse-series relay 1607 has had time to restore responsive to the termination of the impulse series. Relay 1617 makes a multiple ground connection to conductor 1650 so as to maintain this conductor grounded during the transferring operation. Upon the closure of the lower contacts of relay 1617 the transfer takes place over the code conductor 1651 and 1652 20 through contacts of relays 1621 to 1625 to the pairs of relays A and B, and C and D of the digit-storage device DS-1. These four relays are arranged to be operated in any one of ten combinations to register any one of ten digit values. The combinations in which the relays are 30 A to D of the digit-storage device DS-1 are operated to store any one of ten digit values are indicated in Fig. 16B, the four central columns of this table indicating the relays A, B, C, and D, respectively, of the digit-register, DS-1.

In order to enable relays A and B of the digit-storage device DS-1 to be selectively operated over the A-B code conductor 1651, relay A is a positive-polarized sensitive relay while relay 40 B is a non-polarized marginal relay. Similarly, the relays C and D may be selectively operated over the C-D conductor 1652 because relay C is a positive-polarized sensitive relay while relay D is a non-polarized marginal relay. Relays A 45 and C are electro-polarized relays of the well-known three-pole Pye relay construction. The polarizing windings of these relays are connected directly between the negative pole of the exchange battery and the now-grounded holding conductor 1600, whereupon these relays become 50 polarized upon the seizure of the coder. As is well known, one of these relays will remain operated from its polarizing winding alone, once it has been operated responsive to current flow in 55 its line winding.

When it is desired to operate relay A over conductor 1651 without operating relay B, a light positive impulse is transmitted through contacts of digit-transfer relay 1617 through a 1450-ohm 60 resistor from the positive pole of the 60-volt battery, while an impulse is transmitted from the positive pole of the 60-volt battery through the 150-ohm resistor when it is desired to transmit a heavy positive impulse in order to operate relays 65 A and B together. On the other hand, when it is desired to operate relay B without operating relay A, a heavy negative impulse is transmitted from the negative pole of the exchange battery by way of the 30-ohm resistor through contacts 70 of digit-transfer relay 1617. The marginally-adjusted relay B is operated responsive to this impulse because of the high current value, while relay A does not respond because of the reversed polarity. In a similar way, by transmitting light 75 and heavy impulses of the desired polarity relays

C and D are selectively operated, or are operated both together over the C-D code lead 1652.

The table shown in Fig. 16A lists the counting relays and switching relays 1611-1616 at the heads of respective columns. The digit-values 1-9 and 0 are contained in the vertical column at the left of the table, and an X is placed in each relay column opposite the various digit values to show the combination of relays operated for a series of impulses corresponding to any digit 10 value from 1 to 0. The two final double columns of this table show the impulses transmitted over the code conductor 1651 and 1652. By way of example, it is to be observed that when the digit 15 received is the digit 1 only relay 1611 of the relays 1611-1616 is operated, and upon the subsequent operation of digit-transfer relay 1617 a light positive impulse is transmitted over conductor 1651 while a heavy negative impulse is transmitted over conductor 1652. Code table 20 16-B shows that under this condition polarized relay A is operated responsive to the light positive impulse received over conductor 1651, while the marginal non-polarized relay D is operated 25 responsive to the heavy negative impulse received over conductor 1652.

When impulse-series relay 1607 restores at the end of the time interval for which it is adjusted, the circuit of digit-transfer relay 1617 is opened, and this relay restores after a slight interval. Upon restoring, digit-transfer relay 1617 disconnects code leads 1651 and 1652, at the same time removing ground potential from conductor 1650. At this point the operated ones of the relays 1611-1616 clear out. A further result of the removal of ground potential from conductor 1650 30 is the operation of the differential stored-energy counting relay 1621 from the energy stored in its lower winding, the discharge operating circuit including the two windings in series and the illustrated 300-ohm resistor. Upon operating, relay 1621 closes a locking circuit for its two windings in series to the now-grounded conductor 1662, grounded by virtue of its connection to the grounded holding conductor 1600 through contacts of escapement relay 1631. At the same time, relay 1621 prepares a locking circuit for 35 the next succeeding relay 1623 to the grounded holding conductor 1600; it disconnects the normally-connected 300-ohm resistor as a current-saving measure, and to enable the relay to restore quickly, it extends actuating conductor 1650 to the junction of the windings of relay 1622; and it disconnects the code conductors 1651 and 1652 40 from the relays of the digit-storage device DS-1 and extends them to the similar digit-storage device DS-2, indicated by a broken-line rectangle. 45

17. Transferring the stored digits

In a similar way the succeeding digits are temporarily stored on the storage relays 1611-1616 and are transferred through the operation of digit-transfer relay 1617 to the digit-storage devices DS-2 to DS-6, the sequence relays 1622-1626 operating, respectively, at the end of the transfer of the succeeding digits. 50

It will be recalled that finders such as F-4 and F-5, Fig. 2, part 2, are started into operation responsive to the receipt of the seizing impulse at the repeater IR-4 to associate a toll office selector such as TOS-2 with the incoming toll line and to associate a register sender such as RS-2 with the finder-selector link. As soon as these finders have completed their operation 55 70 75

and have connected a group of four receiving relays (similar to the relays of the relay group RG, Fig. 17, to the tip and ring conductors thus closed from the selected register sender to the tip and ring conductors T and R of the coder link CL-1, Fig. 16, the ground potential thus impressed on the ring conductor R through two of the code-receiving relays in series is sufficient to actuate the high-resistance 11,300-ohm start relay 1636 in series with the associated 4,000-ohm resistor. The current which flows through the start relay at this time is insufficient to operate the relays in the register sender connected to the ring conductor and to interfere with their proper restoration when operated. When it operates, start relay 1636, extends ground potential from the grounded holding conductor 1600 to conductor 1660. Under the condition, as soon as the second digit of the number has been received and stored, ground potential from the grounded conductor 1660 is extended through contacts of the actuated sequence relays 1622 and 1621 to conductor 1661. Conductor 1661 is now extended to pulse relay 1635 through contacts of the actuated pulse-length timer relay 1633, as relay 1633 becomes operated upon the seizure of the coder and the application of ground potential to holding conductor 1600. When pulse relay 1635 operates, it locks itself to conductor 1661 independent of the contacts of the timer relay 1634; it connects conductor 1660 temporarily to the grounded conductor 1600 independent of the contacts of start relay 1636 so as to maintain this connection in the event that relay 1636 restores during transmission of the pulse. Pulse relay 1635 also opens the circuit of the slow-acting pulse-length timer relay 1633 and closes a circuit for space-timer relay 1634.

As its main function, pulse relay 1635 connects the tip and ring conductors T and R associated with the digit storage devices DS-1 to DS-6 to the tip and ring conductors T and R of the coder link CL-1 in order to transmit an impulse over each of these conductors of a polarity and strength determined by the combination of the relays A to D of the digit storage device DS-1 which are energized. Upon noting the interconnection of conductors 1656 to 1659 through the contacts of relays A to D of the digit-storage device DS-1 with the associated conductors T and R, it will be seen that this digit-storage device prepares for the transmission of the same combination of pulses over the conductors T and R that it receives over the code conductors 1651 and 1652 from the pulse-counting 1611-1616. This is shown further in the code table 16-B. The stored combination of code pulses is therefore transmitted through the lower contacts of pulse relay 1635 upon its above-mentioned energization.

When pulse-length timer relay 1633 restores responsive to being disconnected by pulse relay 1635, it disconnects pulse relay 1635 to terminate the pulse. Upon restoring, pulse relay 1635 opens a further point in its circuit so that now it is disconnected also at contacts of the space timer relay 1634, which relay is slow-acting and is adjusted to introduce the desired space between impulses.

Also, upon the restoration of relay 1635, a circuit is closed through contacts of the operated space-timer relay 1634 and through contacts of relays 1631 and 1632 for the winding of escapement relay 1631. Upon operating, escapement relay 1631 locks itself to the holding con-

ductor 1600, at the same time opening its initial circuit. Relay 1631 prepares a circuit for escapement-control relay 1632, to be closed upon the reoperation of pulse relay 1635.

At its upper contacts, escapement relay 1631 applies holding potential to locking conductor 1633 at the same time removing holding potential from conductor 1662. When this occurs, sequence relay 1621 restores as it was previously locked to conductor 1662. Upon restoring, relay 1621 transfers the locking circuit of sequence relay 1622 to conductor 1663, now maintained grounded through contacts of the operated escapement relay 1631. In addition, when it restores, relay 1621 transfers the associated tip and ring conductors T and R from the contacts of the relays of the digit-storage device DS-1 to the prepared contacts of the digit-storage device DS-2, in preparation for the transfer of the second stored digit of the desired number to the waiting register sender.

Pulse-length timer 1633 is reoperated upon the restoration of pulse relay 1635 to prepare a circuit for reoperating pulse relay 1635 upon the restoration of space timer relay 1634. Therefore, when the slow-acting space timer 1634 restores it again connects pulse-relay 1635 to the grounded conductor 1661 (which conductor is now grounded only in the event that the third digit of the number has been received and stored on the digit-storage device DS-3 and the upper contacts of relay 1623 are therefore closed). When pulse relay 1635 reoperates, it transmits the prepared code combination set up on the digit-storage device DS-2 in addition to opening the circuit of pulse-length timer 1633 and closing a circuit for the timer 1634.

With escapement relay 1631 operated, upon the operation of pulse relay 1635, a circuit is closed for the upper winding of escapement-control relay 1632. Escapement-control relay 1632 operates and prepares a self-locking circuit for its lower winding, and it transfers the circuit of escapement relay 1631 so that it extends through contacts of the operated relays 1632 and 1635 to conductor 1600. Under the condition, when pulse relay 1635 restores responsive to the restoration of pulse-length timer 1633 it again opens the circuit of space timer 1634 and reoperates pulse-length timer 1633, in addition to which it closes a new locking circuit for the lower winding of escapement-control relay 1632, at the same time opening the initial circuit of the upper winding of this relay and opening the transferred circuit of escapement relay 1631. Escapement relay 1631 is thereby permitted to restore and transfer ground potential from conductor 1663 back to conductor 1662. When this occurs, the second-digit sequence relay 1622, associated with digit-storage device DS-2, which has been locked to conductor 1663 following the restoration of relay 1621, restores and thereby transfers the associated tip and ring conductors T and R from the contacts of the digit-storage device DS-2 to the contacts of the digit-storage device DS-3. At the same time, relay 1622 shifts the locking circuit of the next succeeding sequence relay 1623 so that it includes the now-grounded escapement conductor 1662.

It is to be noted that the circuit of pulse relay 1635 is controlled over conductors 1660 and 1661 by the relays 1621 to 1626 so that relay 1635 is not permitted to transfer the first stored digits to the register sender until two-digits have been stored, as evidenced by the actuation of the first

two sequence relays 1621 and 1622. When the first stored digit has been transferred and relay 1621 has been restored, the conductors 1660 and 1661 are not joined together to permit a reoperation of pulse relay 1635 to effect the transfer of the second stored digit until the third sequence relay 1623 becomes operated when the third digit is received and stored in the digit-storage device DS-3. Similarly, the transfer of succeeding digits to the waiting register sender is delayed in this manner, always keeping at least two digits behind the storing operation. This arrangement is made necessary only because the same relays (1621-1626) are used as sequence relays in the control of the successive storing of the digits and are subsequently restored successively to act as sequence relays in the successive transfer of the digits to the waiting register sender. However, when the final digit has been stored on the digit-storage device DS-6, relay 1626 directly joins conductors 1660 and 1661 together so as to permit all of the remaining stored digits to be transferred at the speed of transfer determined by spacing introduced by the pulse-length timer 1633 and the space timer 1634, as previously discussed. It will be understood, of course, that escapement relay 1631 is operated through contacts of space timer relay 1634 upon the restoration of pulse relay 1635 following the transfer of each alternate digit and is controlled by the escapement control relay 1632 so that it restores responsive to the restoration of pulse relay 1635 at the end of each succeeding digit (second, fourth, and sixth), whereby the relays 1621-1626 are successively permitted to restore or "escape".

At the end of the transfer of the sixth and last stored digit, the restoration of pulse relay 1635 results in the previously mentioned closure of the locking circuit for the winding of the previously-operated escapement control relay 1632 and of the opening of the transferred holding circuit of relay 1631, permitting escapement relay 1631 to restore and transfer ground potential from escapement conductor 1663 to escapement conductor 1662. When this occurs, the final sequence relay 1626 restores and disconnects conductor 1660 from conductor 1661 to avoid a reoperation of pulse 1635, upon restoration of space timer relay 1634.

The register sender RS-2 Fig. 2, part 2, having received the full number of digits now advances its sequence switch (not shown) to disconnect the incoming tip and ring conductors from the code-receiving relays. When this occurs, start relay 1636 restores and thereby opens an additional point in the circuit of pulse relay 1635 preventing further operation of this relay during the instant call.

18. Storing the ring-start impulse

In the repeater IR-4, when the 60-cycle-modulated 1000-cycle ring-start impulse is received over the toll line following the receipt of the final digit, signal-repeating relay 1423 is operated over signal-in lead 1463 from tone unit TU-4, Fig. 13. Signal-repeating relay 1423 incidentally operates series relay 1404 operated at its lower contacts, while it closes a circuit through contacts of the operated incoming release relay 1421, contacts of the non-operated release-pulse timer relay 1407, contacts of the actuated selector-seizing relay 1420, and through contacts of the actuated ring-control relay 1417 for the ring-prepare relay 1415. Relay 1415 thereupon operates and locks itself to conductor 1450, at the

same time preparing a circuit for ringing relay 1414.

In order to prevent the transfer of any indication which may have been set up on the counting relays of Fig. 16, part 1 in the event that incoming repeating relay 1424 follows the 60-cycle modulations, ring-prepare relay 1415 at its lower contacts introduces the 1,000-ohm resistor 1441 in the ground supply lead of the loop pulse circuit extending the coder CR. When this resistor is introduced, the marginally-adjusted 10-ohm transfer-control relay 1604 restores, but the loop current remains above the operating value for pulse relay 1605. As a result of the restoration of relay 1604, the slow-acting digit-transfer relay 1617 is unable to operate and connect up the code conductors 1651 and 1652. By this arrangement, the unnecessary storing of a false digit indication in the storage device DS-1 following the previously described restoration of all of the sequence relays 1621-1626 is prevented. This provision may be of even greater utility in the event that it is later desired to arrange the automatic switching apparatus in Rio de Janeiro in a manner similar to that disclosed in connection with the apparatus in Sao Paulo so that connections may be dialed through the automatic switches in Rio de Janeiro to a desired toll line, in which event numbers containing less than six digits will be used and the false digit registration would thereby otherwise be transferred to one of the succeeding digit-storage devices and cause a false setting which would most likely result in a misdirection of the call.

It may be pointed out that it is not permissible to open the pulse circuit to the coder entirely at this point and thereby prevent the transfer above referred to from taking place, as this would permit release relay 1606 to restore and clear out the coder, which clearing-out operation may under certain circumstances occur before all of the numbers have been transferred to the register sender. In addition, if the coder were permitted to clear out at this stage before the coder-seizing relay 1437 of the repeater IR-4 is restored, the coder would be subject to seizure from another repeater while it is still connected to the repeater IR-4.

19. Transmitting the line-supervisory pulse

The circuits associated with the repeater IR-4 remain unchanged with the ring-start indication stored in the operated ring-prepare relay 1415, until the connection has been extended to the desired line and a line supervisory signal has been received. When this occurs, the current flow is increased through cut-off relay 2023 and supervisory relay 2022 of the line circuit LC-2 sufficiently to enable supervisory relay 2022 to operate and increase the current flow through the start relay 2021 by-passing its 1700-ohm lower winding. When this occurs, supervisory relay 1422 operates responsive to the increased current. Upon operating, relay 1422 transfers ground potential from the front contact of the lower armature of counting relay 1410 to the back contact. One immediate effect of this operation is the opening of the circuit previously existing through the lower contacts of the actuated auxiliary relay 1418 and extending through contacts of relays 1411, 1410, and 1409 to the windings of line-supervisory relay 1409. When this circuit is opened, relay 1409 (being of the differential, stored-energy type of counting relay previously discussed) operates and closes a locking circuit

for its two windings, series aiding to holding conductor 1450. Relay 1409 disconnects the 600-ohm Losser resistor 1423 from across the right-hand windings of repeating coil 1475 preparatory to the establishment of a talking circuit through the repeater; it breaks the circuit at its lower armature normally established through the 500-ohm resistor 1442 and the 10,000-ohm resistor 1446 for maintaining pad-control relays 1433 operated, whereupon pad-control relay 1433 restores and permits pad-cut-off relay 1434 to be operated from holding conductor 1450; and it prepares an operating circuit conductor to the windings of counting relay 1410 so as to permit this relay to respond to the next impulse.

Upon the above operation of a supervisory relay 1422, the removal of ground potential from the conductor connected to the back contact of its armature results in the opening of the loop circuit extending through the upper winding of loop test relay 1419 over the pulse lead to the coder of Fig. 16. Loop-pulse relay 1419 restores almost immediately because it is only slightly slow-releasing. Relay 1419 removes ground potential from the pulse cut-in relay 1466 so as to remove the incoming impulse relay in the tone unit TU-4 from circuit. Auxiliary relay 1418 now restores to prepare a circuit for switch-over relay 1417.

As a further result of the operation of supervisory relay 1422 a circuit is closed through contacts of the non-actuated answer-supervisory relay 1410 by way of contacts of signal-repeating relay 1423, and contacts of inter-pulse timer relay 1531 for supervisory-pulse relay 1427. Relay 1427 brings about an operation of preparing relay 1428, sending relay 1429 and auxiliary relay 1430. Preparing relay 1428 disconnects the receiving conductors 1462 from the toll line TL-4 and removes ground potential from direction-transfer conductor 1465 so as to condition the tone unit TU-4 for transmitting a 60-cycle-modulated 1,000-cycle impulse over toll line TL-4 to the Sao Paulo exchange. This impulse comes out of the tone unit TU-4 over the sending leads 1461 and is relayed to the toll line TL-4 through contacts of the operated sending relay 1429.

Preparing relay 1428 also closes a circuit for switch-over relay 1417 through contacts of relays 1420 and 1418. Relay 1417, among other things, locks itself to conductor 1450, and disconnects series relay 1404.

It is to be noted that the contact associated with the inner armature of auxiliary relay 1430 is grounded through contacts of the non-operated relays 1407 and 1426. Ground potential impulse is therefore extended by the inner armature of relay 1430, through contacts of the non-operated relays 1411 and 1410, and contacts of the operated relay 1409 to the two windings of relay 1410. Energy is therefore stored in this differential counting relay preparatory to its operation when its initial circuit is opened.

Auxiliary relay 1430 operates inter-pulse-timer relay 1431 to disconnect supervisory-pulse relay 1427. When relay 1427 restores, it permits relays 1428, 1429, and 1430 to restore. Relay 1430 opens the circuit of slow-acting inter-pulse timer relay 1431 and the circuit of slow-acting release relay 1404. Upon the restoration of auxiliary relay 1430, counting relay 1410 is operated by virtue of its stored energy to lock itself to conductor 1450 through contacts of unlock relay 1412 and to prepare a circuit for the next succeeding counting relay 1411. Relay 1410 also disconnects the

circuit of supervisory pulse relay 1427 from the now-grounded front contact of the armature of the actuated supervisory relay 1422 and transfers it to the ungrounded back contacts of this armature, thereby preventing a reoperation of supervisory-pulse relay 1427 when inter-pulse timer relay 1431 restores responsive to the restoration of auxiliary relay 1430.

As a further result of its above operation during the transmission of the line-supervisory pulse, switch-over relay 1417 partly extends the talking circuit at its uppermost armatures, and it breaks the locking circuit of coder-seizing relay 1437. Coder-seizing relay 1437 restores and disconnects the conductors O, T, P, and R of the cable C-1 from the repeater IR-4, thereby terminating the association between the coder CR and the impulse repeater IR-4. When this occurs, cut-off relay CO-1 in the preselector PS, Fig. 15, restores, but nothing occurs as a result of this restoration because relay CA1 has been restored as previously pointed out to disconnect relay CO-1 from relay IC1.

20. Clearing out the coder CR

In the coder CR, when pulse relay 1605 restores responsive to the operation of supervisory relay 1422, previously described, series and priming relays 1607 and 1608 are incidentally operated and the circuit of release relay 1606 is opened. At the end of the interval for which it is adjusted, relay 1606 restores and removes ground potential from holding conductor 1600 and the energizing potential from the special locking conductor 1654, thereby permitting all of the energizing potential from the special locking conductor 1654 thereby permitting all of the energized relays of the coder CR to restore. Relays 1607 and 1608 restore responsive to the restoration of release relay 1606. Ground potential is now reestablished on the guard lead G of the coder CR, thereby preparing for the reoperation of two-step preselecting relay 1501 as explained in a subsequent portion of this description.

21. Releasing the stored ring-start pulse

In the repeater IR-4, switch-over relay 1604 also opens the locking circuit of the slow-releasing ring-prepare relay 1415 and closes a circuit through contacts of relay 1415 for ringing relay 1414, whereby relay 1414 is momentarily operated. Relay 1414 opens the tip and ring conductors extending to the automatic switch train and places a battery potential on the tip conductor through the 500-ohm resistor 1444, at the same time applying ground potential to the ring conductor R to avoid undesired inductive relay operation from taking place over the ring conductor R. Responsive to this temporary application of potential to the tip conductor T, the automatic ringing on the called line is started in the usual manner. With switch-over relay 1417 operated and coder seizing relay 1437 restored, the talking circuit is extended from the toll line, through repeating coil 1475 to the line circuit LC-2, Fig. 20. Pad-control relay 1433, whose local operating circuit was opened upon the operation of line-supervisory relay 1409, is now operated in a simpler circuit over the extended talking conductors to disconnect pad-cut-out relay 1434. Relay 1434 again introduces the pad 1460 to adapt the toll line for interconnection with a subscriber line.

22. Receiving the line supervisory pulse

In the Sao Paulo exchange, the 60-cycle modulated 1,000-cycle line supervisory impulse transmitted from the repeater IR-4 in Rio de Janeiro passes the receiving leads 1162, through the receiving transformer 1224 of the tone unit TU-2, through the two-way amplifier tube 1211, the transformer 1217 and by way of the triple-peak tuner (including coils 1219, 1221, and 1223) and through the differential detector 1212 to the impulse amplifier 1213. From this amplifier, the detected and amplified signal pulse passes through the signal amplifier 1216 and is received at the incoming signal relay 1205. Relay 1205 extends ground potential over the signal-in conductor 1163 to operate the signal-repeating relay 1123. Relay 1123 closes a circuit (from ground obtained through contacts of guard relay 1125) extending through contacts of the operated release-pulse timer relay 1107 and by way of contacts of relays 1111, 1110, and 1109 to the line supervisory relay 1109. This relay stores energy when the impulse is received. Being one of the stored-energy differential counting relays, this relay operates when the impulse is terminated. Upon operating, relay 1109 closes a locking circuit for both of its windings, series aiding, also disconnecting the associated 300-ohm resistor. Relay 1109 disconnects the 600-ohm lower resistor 1143. Relay 1109 also places a supervisory ground potential on the incoming EC lead 1100, through contacts of the non-operated relays 1108 and 1110, in addition to transferring the operating lead to the answer-supervisory relay 1110. The ground potential placed on the incoming EC lead is extended back through the operated toll line selector TLS-2 of Fig. 8 and through the operated toll first selector TFS-1 of Fig. 6 to light supervisory lamp 509. By the lighted condition 40 of this lamp, the operator at the switchboard position of Fig. 5, is informed that the connection has been extended to the called line and this line is idle and has been seized. The automatic ringing over the called line having been 45 started as previously pointed out, the operator is not required to manipulate her ringing key for this purpose.

23. Answer supervision

When the called subscriber answers, the well-known supervisory action takes place in the train of switches in the called exchange to cause the current flow through relays 2023 and 2022 of the line circuit LC-2, Fig. 20, to be again reduced 55 sufficiently to permit supervisory relay 202 to restore. When this takes place, the 1700-ohm lower winding of relay LC-2 is reinserted in the circuit, bringing about a restoration of supervisory relay 1422. Counting relay 1410 having been operated coincident with the transmission back to the calling exchange of the line-supervisory signal, upon the restoration of supervisory relay 1422 ground potential is extended 60 through the back contacts of the armature of this relay and through the front contact of the operated lower armature of relay 1410 to supervisory-pulse relay 1427, by way of contacts of relays 1423 and 1431. As a result, relays 1427-1430 are caused to operate as previously 65 explained to effect the transmission of a supervisory pulse and to bring about the operation of the inter-pulse timer relay 1431 to restore relays 1427-1430. In order to make record in the repeater IR-4 of this transmission and to pre-

vent a reoperation of the relays 1427-1430 after they have been restored, auxiliary relay 1430, extends a ground potential through contacts of relay 1411, by way of contacts of the actuated relay 1410, to the differential, stored-impulse-counting relay 1411. Relay 1411 is therefore operated upon the restoration of auxiliary relay 1430 to lock itself to lead 1450 through contacts of unlock relay 1412. Relay 1411 also closes a circuit for the slow-operating unlock 1412, whereby relay 1412 is operated to unlock and restore relays 1410 and 1411. Upon the restoration of relay 1411, relay 1412 is again permitted to restore and to reprepare locking circuits for relays 1410 and 1411. Relay 1410 again extends the operating conductor through contacts of the operated relay 1409 to its own winding so as to permit it to be reoperated pursuant to the counting of further supervisory pulses. By virtue of the restoration of relay 1410 (supervisory relay 20 1422 being restored) ground potential is disconnected at the lower armature of this relay from the circuit of supervisory-pulse relay 1427, whereby a further operation of this supervisory-pulse relay is prevented at this time.

In the calling Sao Paulo exchange, when this answering supervisory signal is received, and signal-receiving relay 1123 operates, relay 1123 closes a circuit through contacts of the operated line-supervisory relay 1109 for the windings of 30 answer-supervisory relay 1110. Upon the operation of relay 1110, which relay locks itself operated through contacts of unlock relay 1112, ground potential is disconnected from the incoming EC lead, thereby extinguishing the supervisory lamp 509 at the toll board, and informing the toll operator that the call has been answered.

Conversation may now take place over the established connections.

24. Disconnect supervision

When the conversation has been terminated and the subscriber in the Rio de Janeiro exchange replaces his receiver, the response of the switch train in the Rio de Janeiro exchange is 45 to again increase the current flow over the sleeve conductor of the established connection sufficiently to bring about the reoperation of supervisory relay 2022 of the line circuit LC-2, Fig. 20. When this occurs, supervisory relay 1422 of the repeater IR-4 is again operated. At this time, the operation of this relay closes a circuit through contacts of the restored relay 1410 for the supervisory-pulse relay 1427 to cause a supervisory pulse to be transmitted over the toll line TL-4 55 to give disconnect supervision in the called office. Coincident with the transmission of this supervisory pulse, counting relay 1410 is reoperated to shift the circuit of supervisory-pulse relay 1427 from the front contact to the back contact 60 of the armature of supervisory relay 1422, whereby relay 1427 is not reoperated again when inter-pulse timer relay 1431 restores responsive to the restoration of auxiliary relay 1430.

It will be understood, of course, that in the 65 event that the subscriber on the called line in Rio de Janeiro, desired to signal the toll operator and operate his hookswitch up and down a few times that the hookswitch supervision is transmitted over the toll line TL-4 by successive operations of supervisory pulse relay 1427, which operation will be covered more completely in the portion of the description hereinafter given which relates to the transmission of flashing signals indicative of a busy condition.

In the Sao Paulo exchange, the supervisory pulse is received as before, and signal-repeating relay 1123 is caused to operate temporarily as a result thereof. Upon operating, relay 1123 closes a circuit through contacts of the operated answer-supervisory relay 1110 for disconnect supervisory relay 1111. Energy is stored in this relay when the pulse is received, with the result that the relay operates fully when the pulse is terminated, locking itself operated through contacts unlock relay 1112 to the holding conductor 1150. Relay 1112 is operated to unlock and restore supervisory relays 1110 and 1111. Relay 1112 is restored to reprepare locking circuit for relays 1110 and 1111 when relay 1111 restores. With answer-supervisory relay 1110 now restored, ground potential is reapplied to the incoming EC lead, through contacts of the operated line-supervisory relay 1109. The calling supervisory lamp 509 at the toll board is thereby relighted as a disconnect signal.

25. Clearing out

The operator may clear out the connection 25 by depressing the release keys K-1 and K-2 causing the cord circuit CC-1 of Fig. 5 and the toll first selector TFS-1, Fig. 6, to clear out as previously described.

In the toll line selector TLS-2, Fig. 8, when 30 ground potential is removed from the C terminal 800 upon the release of the toll selector TFS-1, switching relay 806 restores and disconnects the wipers 850, at the same time closing a circuit at its lower contacts, through contacts of the restored relays 801 and 802, and by way of off-normal contacts 812, for release magnet 810. By the operation of magnet 810, the wipers 850 are restored to normal position in the usual manner.

40 In the repeater IR-2 of Fig. 11, release relay 1105 restores responsive to the removal of ground potential from the C terminal 1100 when the preceding toll-line selector TLS-2 clears out. Upon the restoration of relay 1105, relay 1106 of the release-pulse timer (composed of relays 1106 and 1107) deenergizes and permits its weighted armature to vibrate with decreasing amplitude, whereby the slow-acting relay 1107 is held operated for a period of perhaps a second, 45 at the end of which time it restores, when the amplitude of vibration of the weighted armature of relay 1106 has substantially attenuated. During the interval required for relay 1107 to restore after the circuit of relay 1106 is opened, a prolonged release pulse of 60-cycle modulated 1,000-cycle current is transmitted over toll line TL-4 to bring about the clearing out of equipment in the distant Rio de Janeiro exchange.

50 It is to be noted further that release relay 1105 disconnects its windings from the incoming C lead upon restoration and maintains them disconnected as long as the sequence relay 1103 is held operated from conductor 1150, which conductor is maintained grounded as long as 55 release-pulse timer relay 1107 remains operated. In this way, the toll line TL-4 is maintained guarded at the Sao Paulo end until the prolonged release signal being sent is terminated.

Upon the restoration of release relay 1105, and 60 while the relay 1107 is still operated, ground potential, through contacts of relay 1107, is extended through contacts of the restored release relay 1105 to energize the upper winding of preparing relay 1128 and to energize sending relay 1129. 65 Upon the operation of relay 1128, direction-trans-

fer lead 1165 is ungrounded to permit direction-transfer relay 1202 to restore and thereby impress 60-cycle modulated 1,000-cycle current on the sending leads 1161, modulation-cut-off relay 1201 having been restored upon the described 5 operation of cut-off relay 1101 at the termination of the dial-pulse transmission. Upon the operation of sending relay 1129 the sending leads 1161 are connected to the conductors of the toll line TL-4 to transmit the prolonged release 10 pulse over the toll line.

At the end of the time interval determined by the adjustment of relays 1106 and 1107, relay 1107 restores and reopens the circuit of relays 1128 and 1129, thereby permitting these relays 15 to restore. Relay 1128 again places ground potential on direction-transfer conductor 1165 to reoperate direction-transfer relay 1102 and thereby place the circuit apparatus in condition for receiving impulses over the toll line TL-4. Relay 1107 also removes ground potential from the holding conductor 1150, permitting relays 1109 and 1113 to restore.

The repeater IR-2 is now in normal condition, and is marked idle at the C terminal 1100 25 and multiples thereof by the reconnection of release relay 1105 to the C lead upon the restoration of sequence relay 1113.

In the Rio de Janeiro exchange, when the prolonged releasing pulse is received, the relay 30 in the tone unit TU-4, Fig. 13, corresponding to relay 1205 of the tone unit TU-2, Fig. 12, makes a correspondingly prolonged application of ground potential to the signal-in conductor 1463 to operate signal-repeating relay 1423 for 35 sufficient length of time to permit incoming-release relay 1421 to restore. Ring-prepare relay 1415 is incidentally operated at this time, but is again restored without an operation of ringing relay 1414 taking place. Upon restoring, incoming release relay 1421, in addition to disconnecting the front contacts of the inner lower armature of signal-repeating relay 1423, to restore ring prepare 1415, breaks the locking circuit of selector-seizing relay 1420, thereby permitting 40 this relay to restore. Upon restoring, selector-seizing relay 1420 removes ground potential from the incoming control conductor 1451, whereupon ring-control relay 1416 restores. In addition, relay 1420 removes ground potential at one point 45 from holding conductor 1450 and otherwise prepares for clearing out the repeater. Upon the restoration of signal-repeating relay 1423 at the end of the release pulse, ground potential is removed entirely from holding conductor 1450, permitting the locked switch-over relay 1417 to restore. Incoming release relay 1421 reoperates when its circuit is reclosed upon the restoration 50 of relay 1423 and it again prepares a locking circuit for selector-seizing relay 1420. Inter-pulse 60 timer relay 1431, held operated throughout the time that relay 1423 is operated, restores upon the restoration of relay 1423. Line-supervisory relay 1409 restores upon the removal of ground potential from holding conductor 1450. At its 55 lower contacts it again closes a local circuit for pad-control relay 1433, thereby again holding this relay locally operated.

The repeater IR-4 is now completely cleared out.

When the sleeve lead S extending to the line circuit LC-2 of Fig. 20 is opened at contacts of selector-seizing relay 1417, start relay 2021 of the line circuit LC-2 restores permitting relays 2022 and 2023 to restore and permitting the operated 75

train of switches to restore and free the called line.

26. Preventing hookswitch interference

5 Tests of the equipment herein illustrated revealed that the induced impulses generated across the talking conductors upon the occasion of the called subscriber "flashing" his hook-switch are of sufficient intensity to cause momentary paral-
10 yzation of the two way amplifier (such as 1211, Fig. 12) tube in tone unit TU-4. During such periods of momentary paralization, the passage of amplified signal current received over the toll line to the incoming-signal relay (corresponding to relay 1205) ceases. As a result, hookswitch flashing by the called subscriber during the receipt of the prolonged release pulse interfered with the clearing-out operation as it altogether, by permitting momentary restoration of the in-
15 coming signal and signal-repeating relays. In order to overcome this possibility, relay 1431 has been arranged to be operated by signal-repeating relay 1423 and is provided with contacts for opening one of the talking conductors extending 20 to the switch train. With this provision the dis-
cussed induced surges are kept away from receiving conductors 1462 during the receipt of the release pulse. It was found to be unnecessary to open both talking conductors.
25

30 A similar arrangement is provided in the im-
pulse repeater IR-2, Fig. 11, involving relay 1131 and its upper contacts.

Certain features of the concerned equipment which were not particularly brought out in the foregoing description of the setting up of the connection from Sao Paulo to Rio de Janeiro will now be covered.

27. Overflow at the selector TLS-2

40 The operations involved when an overflow condition is encountered at an automatic-toll-line selector, such as the selector TLS-2, Fig. 8, will be explained:

In the previous description of the operation of 45 this toll-line selector in a call through the toll-board apparatus of Fig. 5 to Rio de Janeiro, it was brought out that the toll-line selector TLS-2 is a level-hunting selector, so arranged that it may automatically elevate its wipers one or more 50 additional steps to enable trunks leading from succeeding levels to be reached in the event that all of the trunks in the first level of a multi-level group are in use. As explained, this automatic operation is under the control of the change-over 55 relay 805 and vertical test wiper 821. In the event that all of the trunks leading from the sixth level for example, are in use, level-busy relay 822 is energized over conductor 823 in a chain circuit including contacts of chain relays 60 such as relay 1135, Fig. 11. Under this condition, wiper 821 is unable to find ground potential to actuate change-over relay 805. Therefore, the vertical magnet 808 is again operated to raise the wipers of the selector to the next level. The 65 seventh level also is provided with a level-busy relay, as is indicated by the broken-line to ground, extending from the seventh contact in the bank of vertical test wiper 821. No level-busy relay is provided, however, for the eighth level, as this 70 level is the final level of the number-six trunk group. The eighth contact in the bank of vertical test wiper 821 is directly grounded, whereby an actuating circuit for change-over relay 805 is always closed when the selector is brought to 75 the eighth level in its level-hunting operation.

The wipers are rotated over the terminals of the eighth level to search for an idle trunk as previously described.

In the event that no idle trunk is found in this final level of the group, the wipers of the selector continue to be rotated until they pass into over-flow position, one step beyond the final contact set. When this position is reached, overflow contacts 815 are closed to provide a reoperating circuit for the upper winding of series relay 803, 10 through the upper winding of switching relay 806 to ground on the incoming C lead. Relay 805 is thereby actuated also. The stepping circuit of rotary magnet 809 is opened at the lower contacts of switching relay 806, as well as at contacts of 15 series relay 803.

Line and release relays 801 and 802 restore responsive to the operation of relay 806, but switching relay 806 is maintained operated in the lock-
10 ing circuit established for its middle winding 20 from the incoming C lead, maintained grounded by the preceding selector. Series relay 815 re-
mains operated from the grounded incoming C lead in series with the upper winding of switch-
ing relay 806 and through the actuated overflow 25 contacts 814.

During the time required for slow-acting re-
lease relay 805 to restore after its circuit is opened by switching relay 806, a meter-operating pulse is transmitted through contacts of relays 802 and 30 803 to the C wiper 850. Supervisory pulses are transmitted back over the incoming EC lead through overflow contacts 814 to inform the calling toll operator of the group-busy condition.

When the preceding switch restores and re-
moves ground potential from the incoming C lead, 35 relays 803 and 806 are permitted to restore, whereupon the selector is cleared out by the usual operation of release magnet 810.

28. The preselector PS

Referring again to the preselector PS, Fig. 15, the operation of this preselector and its coopera-
10 tion with the associated repeaters will be ex-
plained more completely. It was brought out in 15 the previous explanation that, with the relays of the preselector in the condition shown in the drawing (common relays 1507 and 1508 in ener-
gized condition), preselecting relay 1501 is held 20 locked over the normally grounded guard lead G of the coder CR-1, and relays CA1, CB1, and CC1 are held operated by relay 1501. It was fur-
ther pointed out that the placing of a ground potential on the operate conductor O of the cable 25 CI results in the closure of a circuit through the upper winding of the differential cut-off relay CO-1 for the connecting relay IC1, and that the differential action of the two-windings when sup-
plied with ground potential at their junction pre-
vents relay CO-1 from operating as long as 30 current is being supplied through its upper winding to a relay such as IC1. It will be recalled that responsive to the operation of relay IC1 cer-
tain relays in the coder CR, Fig. 16, operate 35 with the result that the idle-indicating ground potential is removed from the guard lead G, there-
by opening the locking circuit of the two-step 40 pre-selecting relay 1101. Upon the restoration of preselecting relay 1501, the self-prepared lock-
ing circuit is completed for the winding of IC1 45 through the inner contacts of this relay, by way of the chain circuit including all of the preceding 50 relays associated respectively with the other toll lines of the group, the twenty-fifth of these re-
lays being relay 25C1. Relay 1501 also reopens 55 70 75 80 85 90 95 98

one point in the circuit of master relay 1507, leaving this relay operated through contacts of such of the remaining five relays (including relay 1506) as are still in operated condition. Also, 5 upon the restoration of preselecting relay 1501, relays CA1, CB1 and CC1 are released, so as to disconnect the operating conductors of the twenty-five associated repeaters from the twenty-five relays associated with the coder link CL-1. At 10 the same time, ground potential is extended through the lower contacts of preselecting relay 1501 and through contacts of the next operated one of the preselecting relays to energize the next 15 succeeding group of connecting relays associated with an idle coder.

When this operation has progressed until each of the first five preselecting relays has been restored, and relay 1506 is the only one of these relays remaining operated, the chain circuit is 20 extended through contacts of the operated relay 1506 to operate connecting relays CA6, CB6, and CC6. These relays are then operated to connect up the twenty-five operating leads to the twenty-five relays associated with the coder link CL-6 25 and including relays IC6 to 25C6. The preselector remains in this condition until the next call is received and the sixth coder is taken for use through the coder link CL6 by an operation of one of the twenty-five relays such as 1C6 and 30 25C6, followed by an operation of the associated one of the twenty-five relays CO-1 to CO-25.

Keeping in mind that the time consumed by the transmission of digits to the coder and the transfer of these digits to the register sender is 35 only a small fraction of the time ordinarily consumed in a toll connection, it will be understood that it is extremely likely that one or more of the five preceding coders has been freed by the time the sixth coder is taken for use. In order 40 to again preselect such coders as are free, master relay 1507 restores when all of the preselecting relays 1501 to 1506 are in normal position. Upon restoring, relay 1507 extends energizing potential to the inefficient upper winding of each of the 45 relays 1501 to 1506 pursuant to the complete re-operation of each of these relays which is associated with an idle coder. The 600-ohm upper windings of relays 1501 to 1506 develop only enough magnetic pull to cause the first step contacts of these two-step preselecting relays to 50 close. The other armature contacts are not affected by energization of the upper winding of the relay alone. At relay 1510, for example, the closure of the first-step inner lower contacts 55 closes a circuit for the 2,000-ohm efficient lower winding of relay 1501, provided there is an idle-indicating ground potential on the associated guard lead G as a result of the coder CR being in idle condition. Under this condition, relay 1501 60 operates fully and again reoperates relays CA1, CB1, and CC1. A similar operation takes place at the preselecting relay associated with other idle coders. The master relay 1507 is now re-operated to deenergize the upper windings of the 65 relays 1501 to 1506 and thereby permit any relay operated through its first step only to restore.

It is to be noted that the slow-acting all-links-busy relay 1508 is normally energized under the control of master relay 1507. Ordinarily, when 70 relay 1507 is restored to cause a pre-selecting operation to take place as described, relay 1507 is reoperated almost immediately by one or more of the relays 1501 to 1506 performing its pre-selecting operation. However, when all of the coders are in use at the same time, as may happen occa-

sionally, relay 1507 is not operated immediately but remains restored until one of the coders becomes idle. Under this condition, the busy-connecting relays CAB, CBB, and CCB are operated upon the restoration of all-links-busy relay 1508. 5 Under this condition, with these relays in actuated condition, the twenty-five operating leads are extended to the twenty-five busy-connecting relays 1CB to 25CB, whereby the appropriate one of these relays is operated in the event that a call is 10 received while all the links are busy.

As soon as a link becomes idle, a relay such as 1501 is operated fully over the associated guard lead G to cause this link to become preselected and to reoperate relay 1507. Immediately upon 15 the operation of relay 1507, relay 1508 is reoperated to restore the busy-connecting relays CAB, CBB, CCB. It is to be noted that alarm conductor 1509 is maintained grounded to give an appropriate alarm signal throughout the time 20 that all links are busy and all-links-busy relay 1508 is in a restored condition.

In order to explain certain provisions residing partly in the preselector PS and partly in the associated repeaters, it will now be assumed that 25 a call is received over the toll line TL-4 at the repeater IR-4 at a time when all of the coders are in use and consequently when relay 1508 is in a restored condition and relays CAB, CBB, and CCC are operated. Under this condition, all of 30 the preselecting relays such as 1504 and 1506 are in a restored condition and the associated groups of three connecting relays are also likewise in a restored condition.

29. Overflow condition at the coders

35

When the seizing impulse is received at the repeater IR-4, under the condition of all the coders being busy, relay operations previously described takes place. Briefly, the slow-acting impulse series 1404 is operated through contacts of the signal-repeating relay 1423 to prepare a circuit for loop test relay 1419; selector-seizing relay 1420 stores energy responsive to the operation of signal-repeating relay 1423 preparatory to operating when relay 1423 restores. Selector-seizing relay 1420 operates fully upon the restoration of relay 1423 and completes the circuit of loop test relay 1419 before relay 1404 restores. Relay 1419 40 closes a circuit for auxiliary relay 1418 and this relay operates to open a point in the circuit of switch-over relay 1417. In addition, supervisory relay 1422 is connected to the associated sleeve conductor S pursuant to the described connecting up of a first selector and a register sender to 45 enable the connection to be extended. Coder-seizing relay 1437 is operated through contacts of loop-test relay 1419 to lock itself energized through contacts of switch-over relay 1417.

By the operation of coder-seizing relay 1437, the 60 operating conductor O in the cable C-1 is grounded to effect the operation of a connecting-relay to connect the repeater with a pre-selected coder. At this time, since all the coders are in use and relays CAB, CBB, and CCB are in operated conditions, the grounding of conductor O in cable C-1 results in the closure of the circuit through the upper winding of the differential cut-off relay CO-1 for the number one busy-connecting relay 1CB. Upon operating, relay 1CB 70 closes a locking circuit for itself directly to the locking conductor L of the cable C-1, which is an extension of the incoming control conductor 1451, now grounded at contacts of the energized selector-seizing relay 1420. When this locking circuit 75

is closed, the upper winding of cut-off relay CO-1 is short-circuited, permitting the relay to energize by means of its lower winding and disconnect the extension of the operating conductor.

5 Busy-connecting relay ICB also connects the busy-flash lead 1510 to the sleeve conductor S of the cable C-1, whereby ground impulses are, at the rate of 60 impulses a minute, placed on the sleeve conductor S thereby causing supervisory relay 1422 to operate and restore 60 times a minute. These impulses are preferably of such short duration that the application of ground potential to the sleeve conductor S to operate supervisory relay 1422 is of insufficient duration to bring about 10 the restoration of start relay 2021 of the line circuit LC-2 which start relay is short-circuited each time ground potential is applied to the sleeve conductor S. This condition is not difficult to obtain; it is a well-known fact that a short-circuited relay is slow in restoring.

Since no holding circuit is closed over the pulse conductor P of the cable C-1 for the upper winding of loop-test relay 1419, relay 1419 restores following the restoration of impulse-series relay 25 1494, shortly after the termination of the seizing pulse. Upon restoring, relay 1419 opens the initial circuit of the now-locked coder-seizing relay 1437; removes ground potential from the pulse-cut-in conductor 1466 extending to the tone unit TU-4; 30 and it permits auxiliary relay 1418 to restore and thereby permit supervisory relay 1409 to operate, relay 1409 having had its energy-storage circuit closed upon the operation of relay 1418. Relay 1418 also prepares a circuit for switchover relay 35 1417 to become closed as soon as the first of a succession of busy-flash supervisory pulses are transmitted over the toll line TL-4.

When it operates over the sleeve lead S of the conductor C-1 from impulse conductor 40 1510, associated with the preselector PS, supervisory relay 1422 extends ground potential from the grounded incoming-control conductor 1451 through contacts of the non-operated relay 1410 to the supervisory pulse relay 1427, 45 causing relay 1427 to respond and bring about the previously described operation of relays 1428, 1429 and 1430 to transmit 60-cycle modulated supervisory pulse back over the toll line TL-4, which pulse is terminated responsive to the operation of inter-pulse timer 1431 by relay 1430. 50 Responsive to the operation of preparing relay 1428, switchover relay 1417 is operated to close a locking circuit for itself and to break the locking circuit of coder-seizing relay 1437 and thereby restore this relay. Cut-off relay CO-1 in the preselector PS restores at this point because operating condenser O of the cable C-1 becomes ungrounded, but relay ICB remains locked energized over the locking conductor L in the 55 cable C-1, to maintain supervisory relay 1422 connected to pulse lead 1510. Counting relay 1419 receives a pulse from the contacts of auxiliary relay 1430, whereby this relay is operated upon the restoration of relay 1430 to disconnect the circuit of supervisory-pulse relay 1427 from the front contacts of the armature of supervisory relay 1422 and transfer it to the back contact. If the supervisory relay 1422 is now in restored condition of relay 1410 results in the preparation of a new circuit for supervisory pulse relay 1421. This circuit, however, is held open for a pre-determined length of time by the inter-pulse timer relay 1431, which is provided to introduce a spacing between transmitted impulses 70 sufficient to allow the impulse-counting opera-

tions at both ends of the toll line to be kept in step.

When slow-acting inter-pulse-timer relay 1431 restores following the restoration of auxiliary relay 1430, relay 1427 again operates and locks itself to the holding conductor 1450 to transmit a further supervisory pulse. During the transmission of this additional impulse, counting relay 1411 has its circuit closed through contacts of the operated relay 1410 with the result that it 10 operated when auxiliary relay 1430 restores at the end of the impulse. As previously explained, upon the operation of relay 1411, unlocking relay 1412 operates to restore relays 1411 and 1410, and relay 1410 prepares for the transmission of 15 further supervisory impulse over the toll line upon the following momentary supervisory relay 1422, from busy-flash lead 1510. Supervisory relay 1422 being operated and released at the rate of 20 sixty times a minute, 120 supervisory pulses a minute, are transmitted over the toll line TL-4, as one supervisory impulse is transmitted each time relay 1422 is operated and another is transmitted each time this relay is restored.

In the Sao Paulo exchange, when signal-repeating relay 1123 responds to the first of these supervisory pulses and then restores, line supervisory relay 1109 operates and locks itself; answering-supervisory relay 1110 is operated responsive to the next supervisory pulse; disconnect supervisory relay 1111 is operated responsive to the third supervisory pulse to restore itself and answering supervisory relay 1110 by the action of unlock relay 1112, following which relays 1110 and 1111 are caused to respond to alternate 35 pulses, relay 1110 being restored each time relay 1111 operates.

Upon the response of line-supervisory relay 1109, the circuits passing through the contacts of the line relay 1103 are opened. At the same 40 time, relay 1109 disconnects the line relay bridge and closes the talking conductors through to the windings of repeating coil 1175, removing the 600-ohm artificial losser bridge 1143. Line relay 1103 is thereby restored, but it causes no harm 45 upon its restoration because the circuits controlled thereby have been opened by relay 1109. In this way, the current flow in the loop-dialing circuit is suspended immediately upon receipt of the first of the series of busy-flashing supervisory 50 pulses.

Assuming that the call is coming from the toll board apparatus of Fig. 5 by way of the selectors of Figs. 6 and 8, when the operator has completed the dialing of the digits and has restored 55 the dial key K-6, loop-test relay 521 is unable to operate because the loop is now dry, and a negative ring-starting pulse is automatically transmitted over the positive talking conductor as previously described, in addition to which extending relay 505 operates to extend the circuit, including the connecting-up of the calling supervisory lamp 509. With the talking circuit now closed through, in the event that the operator has left her talking key K-3 operated and has 60 her head-set conductors thereby connected to the talking conductors of the link, she hears the 60-cycle modulated 1,000-cycle tone pulses being transmitted over the toll line, thereby being audibly informed of the busy condition. On the 65 other hand, if the operator has restored her talking key K-3 to disconnect her head-set conductors, the calling supervisory lamp 509 is connected to the EC lead of the established connection, and this lamp is flashed because of the inter- 70 75

- mittent current flow produced over the EC lead as a result of the operation of answering-supervisory relay 1110 responsive to alternate pulses and its restoration responsive to the action of 5 relays 1111 and 1112 as a result of each next succeeding supervisory impulse.
- When the operator depresses the release-call key and brings about the restoration of extending relay 505, toll first selector TFS-1 and toll-line selector TLS-2 clear out in the hereinbefore described manner, as a result of which release relay 1105 in the impulse repeater IR-2 restores to permit the repeater to clear out and to cause a prolonged release signal to be transmitted over the toll line TL-4 to clear out the distant end of the connection in the manner hereinbefore described. It is to be noted that the incoming signal pulse does not interfere with the starting of the transmission of the prolonged release pulse over the toll line TL-4, as the two-way amplifier 1211 is transformed from an incoming amplifier to an outgoing amplifier upon the release of direction-transfer relay 1202, upon the operation of preparing relay 1128.
- 25 In the impulse repeater IR-4, in the event that a supervisory impulse is being transmitted from Rio de Janeiro to Sao Paulo over the toll line TL-4 at the time transmission of the release pulse starts, the release pulse is not immediately registered until supervisory pulse relay 1427 restores and permits preparing relay 1428 to restore and again ground the direction-transfer relay 1465 to set the two-way amplifier in the tone unit TU-4 into receiving position.
- 35 When this occurs, signal-repeating relay 1423 operates and opens a point in the circuit of supervisory pulse relay 1427 to maintain this relay disconnected throughout the remainder of the release pulse irrespective of further operation of supervisory relay 1422. Relay 1423 also closes a circuit for inner pulse timing relay 1431 which operates and further opens the circuit of supervisory pulse relay 1427. The relay equipment for transmitting the release pulse is purposely 40 adjusted so that the release pulse is sufficiently long to bring about the releasing operation, even though shortened somewhat when it is started while an impulse is being received over the toll line in the reverse direction. Incoming release relay 1421 restores responsive to the prolonged operation of signal-repeating relay 1423 and thereby breaks the locking circuit of selector-seizing relay 1420. Selector-seizing relay 1420 restores and removes ground potential from the incoming control conductor 1451. When this occurs, the locking conductor L of the cable C-1, being an extension of conductor 1451, the locked busy-connecting relay 1CB, Fig. 15, releases. Therefore, no further supervisory signals are received over the sleeve conductor S of the cable C-1. Also, the removal of ground potential from the incoming control conductor 1451 results in there being no longer any potential available for the operation of supervisory pulse relay 1427, regardless of the relative positions of the lower armatures of relays 1422 and 1410.
- At the end of the releasing signal, signal-repeating relay 1423 restores and completes the removal of ground potential from holding conductor 1450, whereupon switchover relay 1417 restores and disconnects supervisory relay 1422 from the sleeve conductor S extending to the line circuit LC-2, Fig. 20. The line circuit 75 LC-2 is thereupon permitted to clear out and

allow the seized toll first selector and register sender to be freed.

30. Overflow at a selector level

In the event that an overflow or all-trunks-busy condition exists at a selected level of the rotary selector switches in Rio de Janeiro during a call incoming over toll line TL-4, the selector being operated is driven to overflow position, following which the current flow over the sleeve conductor of the established connection and through the S terminal 2000 (or multiple thereof) associated with the line circuit LC-2 is alternately increased and decreased at the usual rate of sixty times a minute. In this way, supervisory relay 2022 is alternately operated, and restored, causing the current flow over the sleeve conductor S extending to supervisory relay 1422 to be alternately increased and decreased. In this way, the alternate operation and restoration of supervisory relay 1422 is secured, resulting in the transmission of the group-busy supervisory pulses as previously explained.

31. The called line is busy

When the called line is busy, the result is the same (supervisory pulses are transmitted over the sleeve lead of the established connection) except that the rate of impulsion is 120 a minute instead of sixty a minute, whereby the operator is enabled to distinguish between a busy line and a busy trunk group.

32. The allotter AL

Referring again to the allotter AL, Fig. 17, referred to incidentally in connection with the description of the finder F3, the operation of the allotter AL will be more fully described.

The preselecting relays 1705 and 1709 are associated, respectively, with five finders, such as the finder F3, with which preselecting relay 1705 is associated. With all of these relays in operated position as shown, the incoming start lead 6 extends to the finder F3 through the contacts of relay 1705. When this finder is taken for use, relay 1705 is unlocked and restored by the action of connecting relay 1701, transferring the starting lead through contacts of the next preselecting relay 1706 to its associated finder. Similarly, relay 1706 is unlocked and restored when the associated finder is taken for use.

When all of the finders have been taken for use, and relay 1709 restores, the circuit of relay 1710 is completely opened, whereupon meter 1711 is actuated to record the number of times that master relay 1710 is operated. This meter may be provided with retarding action, whereby it responds only when all finders are busy and the reoperation of relay 1710 is therefore delayed.

When it restores, relay 1710 energizes the upper winding of preselecting relays 1705 to 1709. As in the case of preselecting relays 1504 and 1506 of the preselector PS, relays 1705 to 1709 are two-step relays which are operated only sufficiently to close their locking contacts when energized from the inefficient upper winding alone. With the locking contacts (the lower contacts) of relays 1706 to 1709 closed, each of these relays which is associated with an idle finder operated fully over the associated test lead, such as the test lead 1730 of the finder F3. When any of these relays operates fully to preselect the associated finder, it reoperates the master relay 1710, whereby any of the relays only partly operated to become restored.

F. CALLING FROM SAO PAULO TO CAMPOS

In order to explain how connections are routed from the Sao Paulo toll board through the Rio de Janeiro toll board to toll lines radiating from the Rio de Janeiro exchange, it will be assumed that the toll operator in Sao Paulo is called upon to complete a connection to a line of the Campos exchange. As is indicated in Figs. 1 and 2, calls may be extended from the Rio de Janeiro exchange to Campos by way of a group of toll lines of which the toll line TL-5 Figs. 1, 2, and 20, is one.

15 1. Seizing and ringing over the toll line TL-4

In order to secure extension of the connection to the toll board in Rio de Janeiro, the Sao Paulo operator dials the digits 4 and 6 (see Fig. 2, part 1) necessary to extend connection to the Rio de Janeiro exchange, whereupon she restores her dial key to permit the automatic ringing impulse to be transmitted. As will be explained herein-after, the transmission of ringing current following the seizure of one of the Sao Paulo to Rio de Janeiro toll lines without the interposition of further dial pulses results in the signalling of the operator at the Rio de Janeiro toll board.

It may be assumed that the connection is extended through the link circuit of Figs. 5 and 6 by way of toll line selector TLS-2 to the toll line TL-4 by way of the impulse repeater IR-2 of Fig. 11. This repeater responds to its seizure in the previously described manner and transmits the seizing pulse to the repeater IR-4 with results as hereinbefore described.

When the dial key K-6 is restored, after the dialling of the digits 4 and 6, the connection of the ground connected loop test relay 521 to the negative talking conductor, coupled with the opening of the positive talking conductor results in the described operation of the differential cut-off-control relay 1102 and the operation of cut-off relay 1101 to render the trunk "dry" and to lock itself energized through contacts of relay 1107. Then, loop test relay 521 being permitted to restore upon the drying of the loop extending relay 505 is operated. Ringing relay 1126 responds to the automatically transmitted momentary ringing impulse and closes a circuit at its inner lower armature through contacts of signal-repeating relay 1123 and contacts of inter pulse timer relay 1131 for supervisory pulse relay 1127. Relays 1127-1131 are caused to go through their described cycle of operations to secure the transmission of a 60-cycle modulated 1,000-cycle ringing impulse over the toll line TL-4, cut-off relay 1101 having restored modulation-cut-off relay 1201. The relay in tone unit TU-4 corresponding to incoming impulse relay 1203 of the tone unit TU-2 remains operated rather steadily, as it cannot follow the 60-cycle modulations.

In the impulse repeater IR-4, incoming repeating relay 1124 operates responsive to the ringing pulse before the retarded signal-repeating relay 1423 operates. Upon operating, relay 1424 closes a circuit for the lower winding of the two-step ring control relay 1416 and this relay closes a locking circuit for its two windings in series, which locking circuit does not become effective immediately because the same potential is supplied to both terminals of the upper winding of this relay as long as relay 1424 remains steadily operated. Because the 60-cycle modulations is impressed on the incoming signal, incoming repeating relay 1424 may vibrate somewhat, under

certain line conditions, for which reason a copper collar is provided on the upper end of the core of ring-control relay 1416 to delay the operation of this relay somewhat until after signal-repeating relay 1423 has had time to operate and transmit a signal over the ring-down lead RD extending to the line circuit of Fig. 19.

2. Seizing the line circuit of Figure 19

A signal impulse is transmitted (upon the operation of signal-repeating relay 1423) through contacts of the operated incoming release relay 1421, contacts of the non-operated relay 1407, contacts of the operated selector-seizing relay 1420, normally-closed contacts of ring-control relay 1416, and thence over the ring-down lead RD to transfer relay 1901. Transfer relay 1901 thereupon operates and closes a locking circuit for itself in series with signal relay 1902, to the grounded locking conductor 1451, an extension of incoming control conductor 1451 of the associated repeater. Signal-relay 1902 does not operate however until the original impulse is terminated.

Upon the termination of the signal, repeating relays 1424 and 1423 restore. Relay 1423 terminates the impulse being delivered over the ring-down lead RD, and relay 1424 permits the locked ring-control relay 1416 to operate through to its second step and thereby open its locking circuit, at the same time transferring the ring pulse lead from the ring-down lead RD to the ring prepare relay 1415.

3. Signalling the called operator

In the line circuit of Fig. 19, signal relay 1902 operates in series with transfer relay 1901 upon the termination of the ring-down impulse. Relay 1902 operates to signal the operator by closing a lighting circuit of the line lamp 1907 through contacts of cut-off relay 1903. The delayed closing of the signal circuit for the delayed action of relay 1902 is provided in order that the operator be not unintentionally signalled in the event that the toll line TL-4 is seized at the distant end and is immediately freed, following which a release signal is automatically transmitted over the toll line to clear out the repeater IR-4. Signal relay 1902 does not operate to signal the operator under this condition as incoming control conductor 1451 becomes ungrounded during the transmission of the releasing impulse to thereby open the locking circuit of signal relay 1902.

As a further result of its operation, signal relay 1902 transfers the sleeve conductor S at the repeater from the sleeve conductor extending to the line circuit LC-2, Fig. 20, and connects it to ground through contacts of sleeve relay 1905. By this operation, start relay 2021 of the line circuit LC-2 is permitted to restore, whereby the incoming selector and associated register sender are freed in the event that they have become connected with the line circuit.

4. Line supervision

In the repeater IR-4, supervisory relay 1422 is now operated over the sleeve lead responsive to the ground potential placed thereon by signal relay 1902. The previously described relay operation now takes place pursuant to placing the repeater in line-supervisory condition and to the transmission of a 60-cycle modulated line-supervisory pulse back over the toll line TL-4. Switch-over relay 1417 is operated during the transmission of the supervisory pulse and coder-seizing relay 1437 is restored. Relay 1409 is

operated immediately, and relay 1410 is operated at the termination of the supervisory pulse.

The line-supervisory pulse transmitted back over the toll line TL-4 causes the described operation to take place in the impulse repeater IR-2 and to cause the supervisory lamp 509 of the cord circuit CC-1 to become lighted in the event the operator has restored talking key K-3.

It may be assumed that the operator at the toll-board position of Fig. 20 responds to the lighted condition of line lamp 1907 by inserting the answering plug AP of the cord circuit CC-2 into the jack J-1. When this occurs, the 1800-ohm upper winding of sleeve relay 1905 is energized over the sleeve of the plug and jack in series with lamp 2001, but the lamp does not become lighted at this time because of the small amount of current which flows. Sleeve relay 1905 closes a circuit for its cut-off relay 1903, which relay operates to extinguish the lamp 1907 at the same time locking itself energized to ground at contacts of signal relay 1902.

5. Answer supervision

Sleeve relay 1905 also removes ground potential from the associated sleeve conductor extending to supervisory relay 1422, which relay is restored to cause an answering supervisory pulse to be transmitted back over the toll line TL-4 to give the calling operator dark-lamp answered supervision when she restores her talking key.

The operator at the switchboard position of Fig. 20 throws her talking key 2002 to associate her headset with the cord circuit CC-2 upon answering the call, whereby the center tapped 44,000-ohm resistor 2101 becomes effective to supply sufficient current to the talking conductors to maintain pad-control relay 1433 operated after its local circuit has been opened at the lower contacts of relay 1409 upon the previously-described response of this relay.

6. Extending the connection to Campos

Upon learning that the connection is to be extended to the Campos exchange, the operator may insert the calling plug CP of the cord circuit CC-2 into the jack of an idle toll line, the jack J3 of the toll line TL-5 for example. The operator may now actuate the split-answer key K-10 and the ringing key K-15 to cause the toll line circuit TLC-2 to send ringing current over the toll line TL-5 to signal the Santos operator. When the Santos operator responds the Rio operator may restore her talking key K-9 to permit the talking relay 2002 to restore and disconnect her position equipment from the cord circuit. The Sao Paulo operator may now converse directly with the Campos operator, which latter operator may extend the connection to the desired line.

Pad-control relay 1433 restores when the operator at Fig. 20 restores her talking key, whereupon pad-cut-out relay 1434 removes pad 1460 to adopt the toll line TL-4 for tandem working with another toll line.

7. Recalling the Rio de Janeiro toll operator

In the event that the Sao Paulo operator desires to recall the Rio de Janeiro toll operator she momentarily actuates her ringing key and thereby causes a momentary application of 60-cycle modulated 1,000-cycle current over the toll line TL-4, resulting in a momentary operation of signal repeating relay 1423. Ring-prepare relay 1415 is thereupon operated to prepare a circuit for ringing relay 1414, which circuit is closed

momentarily through contacts of the slow-acting ring-prepare relay 1415, upon the restoration of relay 1423, whereby ringing relay 1414 is momentarily operated. Ground potential is thereby momentarily removed from the re-ring conductor RR, extending to the line circuit of Fig. 19. The short circuit is thereby momentarily removed from the upper winding of rering relay 1904, permitting this relay to operate in series with the associated 1,000-ohm resistor. At its lightly adjusted lower contacts, rering relay 1904 locks its 15-ohm lower winding energized, through the 85-ohm lower winding of sleeve relay 1905 and the lamp 2001, while at its upper contacts it opens circuit of its upper winding. Lamp 2002 is lighted in series with the 15-ohm and 85-ohm lower windings of relays 1904 and 1905, respectively, as a recall signal.

When the operator responds to the lighted lamp by throwing her talking key K-9 to operate the talking relay 2002, lamp 2001 is disconnected and the associated sleeve lead is transferred to include the illustrated 590-ohm sleeve resistor. By this transfer, the current-flow over the sleeve conductor is reduced sufficiently to enable the locked rering 1904 to restore and open its locking circuit, but sleeve relay 1905 is held operated through its 1800-ohm upper winding.

8. Disconnect and recall supervision

When the conversation has been completed, the operator at Rio de Janeiro may receive disconnect supervision from the Santos exchange by virtue of a lighted condition of the calling supervisory lamp 2003. She may then take down the connection whereupon the removal of the plug from the jack J1 results in the restoration of sleeve relay 1905, to transmit a disconnect signal to the Sao Paulo operator through the described actions initiated by supervisory relay 1422.

The Rio de Janeiro operator may, of course, "flash" signal the Sao Paulo operator by removing and reinserting the plug in the event that she wishes to recall the originating operator.

Alternately, the Rio de Janeiro operator may actuate her ringing key to cause ringing relay 1426 to actuate to transmit a 60-cycle-modulated pulse over the toll line to signal the originating operator. It is to be noted that the supervisory pulse relay is cut off and restored by inter-pulse timer relay at the end of the predetermined short interval, even though ringing relay 1426 is held operated for a much longer interval. This arrangement prevents the sending of a pulse long enough to restore incoming-release relay 1121.

In the event that the ringing relay is still operated when inter-pulse timer 1421 restores, relays 1427 to 1431 go through one or more additional cycles of operations, sending a corresponding number of additional signals over the toll line.

Relays 1410 and 1411, assisted by unlock relay 1412, count the transmitted pulses, relay 1410 being restored at the end of an odd numbered series of pulses, and operated at the end of an even-numbered series of recall pulses. Therefore, in the event that the series contain an odd number of ringing pulses, relay 1427 is reoperated at the end thereof (through contacts of the operated supervisory relay 1422 and contacts of the restored counting relay 1410) to send an additional supervisory pulse over the toll line to restore the repeater IR-2 to a state of answered supervision. Relay 1410 is reoperated incidental to the transmission of this additional coordinating pulse.

9. Clearing out

The Sao Paulo operator may be the first to take down the connection. When this occurs, a prolonged release impulse is transmitted over the toll line TL-4 from Sao Paulo to the Rio de Janeiro exchange. Upon the operation of signal-repeating relay 1423 at this time, ring-prepare relay 1415 is operated through contacts of ring-control relay 1416 to prepare for the operation of ringing relay 1414, but relay 1414 is not operated at the end of this pulse because incoming-release relay 1421 restores and opens the circuit of ring-prepare relay 1415 at its lower armature at the same time that it opens locking circuit of selector-seizing relay 1420 at its upper armature. Relay 1415 therefore restores and opens the circuit of ringing relay 1414 while the releasing impulse is still being received. Selector-seizing relay 1420 also disconnects supervisory relay 1422 to prevent reoperation of start relay 2021 when the line circuit of Fig. 19 clears out.

When relay 1420 removes ground potential from incoming-control conductor 1451, relays 1901 and 1902 are permitted to restore. Upon the restoration of signal relay 1902 cut-off relay 1903 is unlocked and permitted to restore, and a ground potential is applied to the sleeve of jack J-1 at the contacts of relay 1902, through the 85-ohm lower winding of sleeve relay 1905, in multiple with the 1800-ohm upper winding of this relay, thereby increasing the current flow over the sleeve of the plug and jack sufficiently to light the answering supervisory lamp 2001 as a disconnect signal.

When the operator withdraws the answering plug AP from the jack J-1, sleeve relay 1905 restores.

G. CALLING FROM RIO DE JANEIRO TO SAO PAULO

In order to explain how connections are completed opposite direction over the toll lines between Rio de Janeiro and Sao Paulo, it may be assumed that a call is received at the toll board position of Fig. 20, intended for a subscriber of the Sao Paulo exchange. It may be assumed further that the call is received through the C. L. R. circuit CLR-2, and that the operator answers this call by inserting the answering plug AP of the cord circuit CC-2 into the jack J4, throwing her talking key K-9 to operate the talking relay 2002. In order to extend the connection to a toll line leading to the Sao Paulo exchange, the operator may apply the usual tip busy test to the jacks such as J-2 of Fig. 19 until an idle one is found.

1. Seizing the toll line TL-4

It may be assumed that the operator finds that the jack J2 is idle and inserts the calling plug CP therein. When this occurs, a battery potential is thereby applied through the sleeve of the jack J2, whereby the sleeve relay 1435 of the repeater IR-4 is operated over the sleeve conductor S of the jack J2, ground potential being normally applied to the sleeve conductor of this jack from contacts of the normally operated incoming release relay 1421, by way of the 1700-ohm upper winding of sleeve relay 1435 and contacts of the non-operated relay 1420. Upon operating, sleeve relay 1435 closes a circuit through contacts of line-supervisory relay 1409 for start relay 1436. At its upper group of contacts, start relay 1436 disconnects the tip and ring conductors T and R with the jack J2 from the toll line TL-4 and transfers them, through the code con-

ductors 2 and 4 of the cable 1700, to contacts in the bank of the finder F-3, Fig. 17, and multiples thereof in the banks of the other finders. At the same time, the pulse conductors 1 and 2 of the cable 1700 are connected to the talking conductors section associated with line relay 1403 preparatory to pulse transmission. In addition, start relay 1436 places an idle-indicating potential on the cut-off conductor 5 of the cable 1700, obtained through the 400-ohm winding of release relay 1405, normally shunted by the illustrated 200-ohm resistor. Start relay 1436 also applied ground potential to start conductor 6 of the cable 1700, by way of contacts of release-pulse-timer relay 1407.

2. Starting the finder F-3

Assuming that the relays of the allotter AL, Fig. 17, are in the condition shown, the application of ground potential to start conductor 6 of cable 1700 results in the closure of a circuit through contacts of the operated allotter relay 1705 and through interrupter contacts of stepping magnet 1704 for the stepping relay 1703 of the finder F-3. At the same time, the inefficient 600-ohm upper winding of the two-step connecting relay 1701 is energized to operate relay 1701 through its first step only. When operated through its first step only, relay 1701 applies ground potential to the junction of the windings of test relay 1702, thereby extending ground potential through the 500-ohm lower winding of this relay to the cut-off wiper 5 of the finder F-3.

When stepping relay 1703 operates, it closes a circuit for stepping magnet 1704, whereupon magnet 1704 operates preparatory to advancing the wipers 1-5 of the finder F-3. Magnet 1704 also opens the circuit of stepping relay 1703, permitting this relay to restore to open the circuit of the stepping magnet. The stepping magnet thereupon restores and advances the wipers of the finder F-3 one step, at the same time reconnecting relay 1703 for further operation. This interaction of relay 1703 and magnet 1704 continues until the wipers of the finder F-3 arrive upon the set of terminals allotted to the repeater IR-4 and connected therewith through the cable 1700.

When the wipers of the finder F-3 arrive upon the terminals assigned to the repeater IR-4, the 500-ohm lower winding of test relay 1702 is energized over the cutoff wiper 5 of the finder F-3, and over the cutoff conductor 5 of the cable 1700, through the 400-ohm winding of release relay 1405, shunted by the associated 200-ohm resistor. Upon operating, test relay 1702 disconnects ground potential from the circuit of stepping magnet 1704, thereby preventing a further advance of the wipers. Relay 1702 also shunts its 75-ohm upper winding around the 500-ohm lower winding to increase the ground potential applied through cut-off wiper 405 to the bank terminal on which this wiper is standing and the multiples thereof whereby the repeater IR-4 is marked busy to the remaining finders. Test relay 1702 also applies ground potential to the holding conductor 1723, whereupon the efficient lower winding of connecting-relay 1701 is energized to operate relay 1701 fully. Upon fully operating, relay 1701 opens the locking circuit of allotter relay 1705, whereupon relay 1705 restores and transfers the start conductor to the next finder. With this locking circuit open, relay 1705 can not be re-operated to preselect the finder F-3 until after

the finder has been freed and relay 1701 is restored.

- Relay 1701 also connects up the relays of the relay group RG to the code conductors 2 and 4 of the cable 1700 by way of wipers 2 and 4 of the finder F-3, and it connects up the tip-pulse and ring-pulse wipers 1 and 3 of the finder F-3 to the normally closed impulse contacts of interrupter relay 1838. When this occurs, line relay 10 1403 of the repeater IR-4 energizes through contacts of the energized start relay 1436, over the pulse conductors 1 and 3 of the cable 1700, and by way of the wipers 1 and 3 of the finder F. Upon operating, line relay 1403 opens its contacts preparatory to transmitting controlling impulses, as determined by the setting to be taken on by the register sender of Fig. 18.
- Release relay 1405 of the repeater energizes over the cut-off conductor 5 of the cable 1700 20 responsive to the operation of test relay 1702 of the finder F-3 in placing the 75-ohm upper winding in shunt of the 500-ohm lower winding. Upon operating, relay 1405 disconnects the 200-ohm resistor from the shunt of its winding and 25 places a shunt around contacts of sequence relay 1413 so as to maintain its own circuit intact after sequence relay 1413 has operated. Relay 1405 also closes a circuit for relay 1406 of the release-pulse-timer pair, whereupon relay 1406 operates 30 and closes a circuit for relay 1407. Relay 1407 disconnects the front contacts of the inner lower armature of signal-repeating relay 1423 from the windings of the selector-seizing relay 1420 and transfers them to the conductor which controls 35 the supervisory relays 1409 to 1411; it applies ground potential to holding conductor 1450; it removes ground potential from the start conductor 6 of the cable 1700; and it makes other circuit changes having to do with the adaptation 40 of the two-way repeater for outgoing operations.

3. Transmitting the seizing pulse

Relay 1407 closes a circuit through contacts of relays 1413, 1423, and 1431 for supervisory-pulse 45 relay 1427. Relay 1427 locks itself to conductor 1450 and brings about the operation of relays 1428 to 1430 pursuant to the transmission of a 60-cycle-modulated 1000-cycle seizing pulse over the toll line TL-4. Relay 1431 is operated to 50 disconnect the slow-acting relay 1427, whereby relays 1427 to 1421 are restored and the seizing pulse is thereby terminated.

Sequence relay 1413 is operated by sending relay 1429 to lock itself to conductor 1450 and 55 open the initial circuit of relay 1427 to prevent a reoperation of relays 1427 to 1431.

Sequence relay 1413 also extends modulation-cut-off conductor 1467 to resistor 1422 to secure an operation of the modulation-cut-off relay of 60 the tone unit TU-4 in preparation for the transmission of unmodulated dial pulses over the toll line. In addition relay 1413 prepares to disconnect the actuated release relay 1405 from cut-off conductor 5 of cable 1700, and it places the upper 65 winding of preparing relay 1428 under the control of impulse-series relay 1404.

4. Lighting the key pilot lamp

As a result of the previously-mentioned connection of the relays of the relay group RG Fig. 17 to the code conductors 2 and 4 of the cable 1700 through contacts of connecting relays 1701 and wipers 2 and 4 of the finder F-3, the group RG is impressed on the tip-code conductor 2 of the 75 cable 1700, and the ground potential through

relays D and C of group RG is impressed on the CD code conductor 4. Since these code conductors are now extended through contacts of the jack J-2 and calling plug CP contacts of the energized talking relay 2002 to the tip-call and ring-call conductors TC and RC of the position equipment Fig. 21, the relays of the relay group RG are not under the control of the digit keys 2100, connected thereto through contacts of the actuated dial-call key K-12. The ground potential impressed on the ring conductor RC of the position equipment through the windings of code relays C and D of the relay group RG Fig. 17, results in an energization of the 15,000-ohm winding of key pilot relay 2103. Relay 2103 is 10 operated, but the code relays C and D of the relay group RG are not materially affected at this time because of the relatively small amount of current which flows through the 15,000-ohm winding of relay 2103. Relay 2103 lights the key 20 pilot light 2104, thereby informing the operator that she may start to depress her digit keys 2100 in accordance with the digits in the desired number. Under the assumption that the call is for the line of the sub-station A Fig. 2, whose number is 84161, the operator sets up this number on her digit keys 2100, prefixed by the digits 2, necessary to extend connection to a toll office selector such as the toll office selector TOS-1 Figs. 2 and 9. The complete number, then, set up 25 digit-by-digit on the key 2100 is 284,161. The prefix digit 2 may be regarded as indexing the Sao Paulo exchange.

5. Setting up the number 284,161

35

When the digit-2 key 2100 is depressed, a heavy negative impulse is transmitted over the associated ring conductor through the lower contacts of the key from the negative pole of the 24-volt current source, through the 30-ohm protective resistor. At the same time, a heavy negative impulse is transmitted over the tip conductor from the same source, through the upper contacts of the digit-2 key. This is in accordance with the code table of Fig. 21A, wherein it is to be noted 45 that a heavy negative impulse is transmitted over each of the conductors for the digit 2.

In the relay group RG of Fig. 17 the 50-ohm marginally-adjusted relay B operates over the tip-code conductor 2 of the cable 1700 because the 50 impulse being transmitted is heavy, but the associated positive-polarized relay A is not operated because the impulse being transmitted is a negative impulse. At the same time, marginal relay C operates over the ring conductor because the impulse being received is heavy, but positive polarized relay C does not operate because the impulse being received is negative.

By the operation of marginal relays B and D of the relay group RG, circuits are closed through 60 contacts of relays 1825, 1824, 1823, 1822, and 1821 for the relays B and D of the digit-storage device DS-1 of the register sender RS-1 Fig. 18. Upon the operation of relays B and D, the apex of the contact pyramid controlled by the 65 relays A to D of the digit-storage device DS-1 is connected to the digit-2 of conductor of the digit conductors 1 to 9 multiplied to the digit-storage devices DS-1 to DS-6 and connected to the contacts of the impulse counter illustrated 70 in the lower part of Fig. 18, part 2.

Upon their operation, relays B and D of DS-1 close locking circuits for themselves through the winding of incoming distributor relay 1821, through contacts of output distributor relays 75

1831 to 1836 to the holding conductor 1722, grounded at contacts of the energized test relay 1702.

Relay 1821 remains short-circuited as long as 5 the digit key is held depressed. When this key is restored, and relays B and D of the relay group RG are permitted to restore, the initial circuit of relays B and D of the digit-storage device DS-1 are opened, whereupon relay 1821 energizes in 10 the locking circuit of these relays to disconnect the conductors A to D controlled by the relays RG, Fig. 17, from the relays of the digit-storage device DS-1 and transfer them to the similar relays of the digit-storage device DS-2 to enable 15 the second digit to be set upon the second digit-storage device.

6. Starting the sender

Relay 1810 also places ground potential on the 20 interrupter-start lead 1810, thereby starting the interrupter composed of relays 1837-1839 into operation pursuant to the re-transmission of the stored digits. By this arrangement, registration of the succeeding digits and the retransmission 25 of stored digits may proceed at the same time.

When the second digit 8 is brought into the relay group RG of Fig. 17, through the depression of the digit-8 key 2100, only the positive-polarized relay C operates, whereby the C relay of the digit- 30 storage device DS-2 is operated to connect up the digit 8 multiple conductor, thereby registering the digit 8 as the second digit. Input distributor relay 1822 is operated when this key is released, whereupon it transfers the control conductors to the digit-storage device DS-3 and makes a further ground connection to the interrupter-start lead 1810.

In a similar manner, the remaining digits (4, 1, 6, and 1) are stored on the digit-storage devices 40 DS-3 to DS-6; respectively.

7. Extinguishing the key pilot lamp

When input-distributor relay 1826 operates upon the termination of the registration of the 45 final digit 1, it disconnects ground potential from the relays of the group RG, in addition to placing an additional ground potential on the start lead 1810. When the relays A to D of the group RG are disconnected, the high-resistance pilot 50 relay 2103 associated with the digit keys 2100 restores and permits the lamp 2104 to become extinguished, thereby indicating to the operator that the maximum number of digits have been stored in the register-sender RS-2 and at the 55 depression of a further digit key at this time will be ineffective to cause a further digit to be stored. This arrangement is of particular utility in calls requiring that more than six digits be set up, such as calls to the Campinas and Santos exchanges, Fig. 1, which are trunked through the Sao Paulo exchange, thereby requiring additional digits. This contingency will be discussed subsequently.

The calling operator may now restore keys 60 K-12 and K-9 and await a line-supervisory signal.

8. Retransmitting the stored digits

When ground potential is first placed on start 70 conductor 1810 (by relay 1821), relays 1828 and 1829 are successively operated to connect locking conductor 1812 to holding conductors 1722. Also, interrupter relay 1837 operates and makes an additional application of ground potential to 75 this conductor 1810, whereby a cycle of opera-

tions of relays 1831-1839, when started, is carried to completion. Relay 1837 operates relay 1838, and relay 1838 operates relay 1839. Relay 1839 breaks the circuit of relay 1837 and permits it to restore. Upon restoring, relay 1831 permits 5 relay 1838 to restore; relay 1838 permits relay 1839 to restore; and relay 1839 reconnects relay 1837 to the start conductor to permit another cycle to start.

During the time that the interrupter relay 10 1838 is in operated condition, the tip-pulse and ring-pulse conductors 1 and 3 of the cable 1700 are disconnected from each other at the upper contacts of relay 1838, permitting line relay 1403 of the impulse repeater IR-4 to restore momentarily. 15

Also, each time relay 1838 operates, it closes a circuit for priming relay 1850, associated with counting relays 1851 to 1860 constituting the impulse counter for counting the transmitted impulses and terminating them when the number transmitted coincides with the value of the digit registered. Priming relay 1850 operates and closes a locking circuit for itself through contacts of relays 1851 to 1860, contacts of digit-stop 20 relay 1840 and the lower winding of counting relay 1851, to the grounded counting-relay-locking conductor 1811, grounded by virtue of its connection with the grounded holding conductor 1722; through contacts of the nonoperated relays 1840 and 1841. Conductor 1722' is an extension of the holding conductor 1722, grounded at contacts of test relay 1702. 25

No current flows in the locking circuit of priming relay 1850 as long as the initial circuit 30 of this relay remains established. But, when relay 1838 restores and thereby terminates the first pulse being delivered at its upper contacts to the line relay of the repeater, relay 1851 operates to connect up the digit-1 conductor to the lower winding of start relay 1840, whereby the digit is terminated immediately in the event that its value is 1. In the assumed example, the first digit has a value of two and the digit-1 conductor is not connected up. 35

Relay 1851 also closes a locking circuit to the locking conductor 1811 for its upper winding to maintain the relay operated independent of the lower winding, and it transfers the locking circuit of priming relay 1850 from its own lower 40 winding to that of relay 1852. As previously explained (in connection with the similar arrangement involving priming relay 1608, Fig. 16, part 1, and the associated counting relays), priming relay 1850 is caused to release responsive to the 45 cessation of current flow which takes place when its circuit is transferred and before the current-flow can be built up to holding value through the winding of the next counting relay 1852.

Upon the next cycle of operation of interrupter 50 relays 1847 to 1839, another pulse is transmitted at the upper contacts of relay 1838 to the line relay of the repeater to again momentarily restore the line relay, and priming relay 1850 is again operated. This time, because counting 55 relay 1851 is in operated condition, the locking circuit for priming relay 1850 is established through counting relay 1852. As a result, counting relay 1852 is operated at the end of the second transmitted impulse. Upon operating, relay 1852 transfers the locking circuit of priming relay 1850 to the third counting relay 1853. When this takes place, priming relay 1850 is again restored as previously explained. Relay 1852 also locks itself energized at its upper 60

70

75

contacts to conductor 1811, while at its lower contacts it connects up the energized digit-2 conductor, energized by virtue of the operated condition of the B and D relays of the digit-storage device DS-1 previously explained. The energized condition of the digit-2 conductor results in the closure of a circuit for the lower winding of digit-stop relay 1840. At its upper contacts, digit-stop relay 1840 places a shunt around the upper contacts of interrupter relay 1838, thereby preventing the transmission of a further impulse (circuit-opening) upon the next operation of interrupter relay 1838. The series of impulses constituting the digit-2 is thereupon terminated.

15 Digit-stop relay 1840 also locks itself to the branch holding conductor 1722' through contacts of restart relay 1843. Relay 1840 also prepares a counting circuit for the lower winding of distributor-control relay 1842, at the same time extending ground potential (from the grounded branch holding conductor 1722' through contacts of the non-operated distributor-control relay 1841) to output-control conductor 1723. The extension of ground potential to conductor 1723 results in the 20 operation of priming relay 1827 associated with the counting relays 1831—1836 constituting the output distributor. Upon operating, priming relay 1827 locks itself in series with the upper winding of output distributor relay 1831 to the 25 grounded conductor 1812, grounded by virtue of its connection with the grounded holding conductor 1722 through the lower contacts of the operated sender-supervisory relay 1829. This locking circuit is closed preparatory to the operation of output distributor relay 1831 when the impulse to the priming relay 1827 is terminated.

In order to clear out the impulse counter, digit-stop conductor 1840 disconnects ground potential from locking conductor 1811, associated with 30 counting relays 1851 to 1860, whereupon any operated ones of these relays becomes unlocked and restores. With all of these counting relays now in restored condition, and with relay 1840 locked operated, a locking circuit for priming relay 1850 is prepared through the lower winding of the distributor control relay 1841. Therefore, upon the 35 next operation of relay 1838 (no impulses transmitted at the upper contacts of relay 1838 at this time because these contacts are shunted at the upper contacts of relay 1840) priming relay 1850 locks itself in series with the lower winding of distributor-control relay 1841, whereby relay 1841 operates upon the next restoration of relay 1838. Upon operating, relay 1841 locks itself to holding conductor 1722' at its inner upper contacts; it prepares a circuit for the lower winding of space-stop relay 1842 to enable this relay to operate at the end of the predetermined inter-digit space or interval; it prepares a new circuit 40 through contacts of the non-operated relay 1842 for starting the operation of the counting chain to count a predetermined number of operations of the interrupter to time the inter digit spacing; and it disconnects ground potential from the output-control conductor 1723' and consequently from the output control conductor 1723. When this occurs, output-distributor relay 1831 operates in circuit with the locked timing relay 1827. At its lower contacts, relay 1831 closes a locking circuit for its lower winding to the locking conductor 1812; it transfers the locking circuit of priming relay 1827 to the next succeeding output distributor relay 1832, whereupon priming relay 1827 restores; and at its upper armature it disconnects ground potential from the locking cir-

cuit of input distributor relay 1821 and from the apex of the contacts pyramid of the digit-storage device DS-1 and transfers it to the apex of the contact pyramid associated with the digit-storage device DS-2. When this occurs, the digit-storage device DS-1 is rendered ineffective to exert further control over the associated digit-stop conductors. At the same time the input distributor relay 1821 restores since its circuit is opened, and the energized relays B and D of the device DS-1 restore also, as their locking circuit is opened.

With digit-stop and distributor control relays 1840 and 1841 locked operated and with counting relays 1851 to 1860 restored, the next time priming relay 1850 is operated by interrupter relay 1838, it locks itself again in series with the lower winding of relay 1851, since locking conductor 1811 has again been joined to holding conductor 1722 at the upper contacts of distributor-control relay 1841. As a result, relay 1851 operates upon the following restoration of relay 1831 and prepares a circuit for relay 1852. The succeeding counting relays are operated successively responsive to successive operations of priming relay 1850 until the space-stop relay 1842 is caused to operate. The point at which space-stop relay 1842 is operated depends upon the position of the jumper 1807. As shown, jumper 1807 interconnects the terminal 1801, associated with space-stop relay 1842, and terminal 1804 connected to the upper winding of counting relay 1854. Under this condition, when the fourth of the counting relays (1854) operates and locks itself, a circuit is closed through jumper 1807 and contacts of the operated relay 1841 for the lower winding of space-stop relay 1842 to energize this relay preparatory to starting the transmission of impulses for the second stored digit. It is to be observed that jumper 1807 may be connected to either of the terminals 1802 and 1803 if a lesser spacing between impulse series is desired, and that it may be connected to either of the terminals 1805 and 1806 if a greater spacing between impulse series is desired.

Upon operating, space-stop relay 1842 closes a locking circuit for its upper winding, at the same time preparing to operate the restart relay 1843 upon the next operation of priming relay 1850. In addition, relay 1842 again disconnects the locking conductor 1811 from holding conductor 1722' thereby permitting the operated ones of the counting relays 1851—1860 to again restore. With all of these counting relays restored, and with relays 1840—1842 operated, upon the next operation of priming relay 1850 a locking circuit is closed for this priming relay in series with the lower winding of restart relay 1843. Therefore, when the interrupter relay 1838 next restores and breaks the initial circuit of priming relay 1850, relay 1843 operates in the locking circuit of the timing relay and closes a locking circuit for its upper winding to conductor 1722' through contacts of each of the relays 1840—1842. Relay 1843 also breaks the circuit of its lower winding to permit timing relay 1850 to restore, and at its inner upper contacts it breaks the locking circuit of the relays 1840—1842, to permit all of these relays to clear out. When relays 1840—1842 restore, they disconnect the grounded holding conductor 1722' from conductor 1724, thereby permitting restart relay 1843 to restore. The shunt is removed from the sending contacts (the upper contacts of relay 1838) upon the restoration of digit-stop relay 1840.

With relays 1840—1843 again restored, and with relays 1851—1860 also all in restored condition, the sending apparatus may now retransmit and count the impulses constituting the second stored digit of the desired number.

Since the second digit registered is the digit 8, eight impulses are transmitted at the upper contacts of relay 1838, by which time seven of the counting relays (1851—1857) have been operated, 10 and the locking circuit of priming relay 1850 includes the eighth relay 1858. Then, when relay 1838 falls back to terminate the eighth transmitted impulse of the series and at the same time opens the initial circuit of priming relay 1850, 15 counting relay 1858 operates in the locking circuit of relay 1850 and connects up the eighth digit-stop conductor to the circuit of digit-stop relay 1840. Digit-stop relay 1840 is energized with the results hereinbefore described, which at 20 this time includes the operation of output-distributor relay 1832 through contacts of the operated relay 1831 to clear out the relays of the digit-storage device DS—2 and the input distributor relay 1822, and to extend energizing potential 25 to the contacts of the relays of digit-storage device DS—3.

In a similar manner the digits stored on the digit-storage devices DS—3 to DS—6 are retransmitted with suitable spacing between the impulse 30 series constituting the digits.

When output distributor relay 1836 operates at the end of the retransmission of the sixth and last stored digit, it locks itself to conductor 1812 as in the case of the preceding output distributor 35 relays, at the same time opening the locking circuit of the input distributor relay 1822 associated with the sixth digit-storage device. Relay 1826 restores and removes ground potential from start conductor 1810 to terminate the operation of the 40 interrupter relay 1837 to 1839. Relay 1826 also reapplies ground potential to the relays of the relay group RG so as to permit these relays to be again controlled from the key set to set up additional digits in the event that the number being 45 dialled contains more digits than the six which the register sender may record at one time.

Sender supervisory relay 1828 restores when ground potential is removed from start conductor 1810 and opens the circuit of the slow-restoring 50 sender supervisory relay 1829. Relay 1829 restores after a short interval to remove ground potential from locking conductor 1812 to permit the output-distributor relays 1831—1836 to restore again. With these output-distributor 55 relays 1821—1826 having been restored incidental to the retransmission of the digits, the registering portion of the sender is now in condition for the reception of further digits in the event that further digits are required.

60 9. Repeating the digit pulses

The way in which the digit pulses transmitted to line relay by the register sender are repeated over the toll line TL—4 will now be explained.

65 The first time line relay 1403 restores, the lower armature thereof, being grounded through contacts of release, pulse timer relay 1407, closes a circuit through contacts of line supervisory relay 1409 for the 400-ohm lower winding of preparing relay 1428, whereupon preparing relay 1428 disconnects receiving conductors 1462 from the toll line TL—4 and at the same time removes ground potential from direction-transfer conductor 1465 to permit the direction-transfer 70 relay in the tone unit TU—4 corresponding to the 75

transfer relay 1202 of the tone unit TU—2 to restore and thereby cause unmodulate 1,000-cycle potential to be impressed on the sending leads 1461. At the same time, impulse-series relay 1404 is operated through the lower contacts 5 of line relay 1403, through contacts of the non-operated line supervisory relay 1409, and through contacts of the actuated release relay 1405. Being slow-acting, series relay 1404 remains operated until the end of the series of impulses. Relay 1404 closes a circuit at its lower contacts, 10 through contacts of the actuated sequence relay 1413, for the upper winding of preparing relay 1428 to maintain relay 1428 operated continuously throughout the series of impulses. 15

As a result of each restoration of the series, line relay 1403 closes a circuit at its inner contacts, through contacts of the non-operated line supervisory relay 1409 and contacts of the actuated release relay 1405, for sending relay 1429. 20 Sending relay 1429 is thereby operated momentarily each time the line relay restores, to connect the sending conductors 1461 (on which the 1,000-cycle dial potential is impressed by the tone unit TU—4) to the toll line TL—4. In this way, 25 the pulses (interruptions) delivered to line relay 1403 are repeated as pulses of 1,000-cycle current to the toll line TL—4.

At the end of the series of pulses, line relay 1403 comes to rest in an operated condition; sending relay 1429 comes to rest in a restored condition; and slow-acting series relay 1404 restores after a slight interval to permit preparing relay 1428 to restore.

Each of the other series of impulses is repeated 35 to the toll-line TL—4 in the same way.

10. Completing the connection in Sao Paulo

The way in which the apparatus in the Sao Paulo exchange responds to the seizing pulse and 40 to the subsequent trains of dial pulses to extend the connection to the desired line will now be pointed out.

When the 60-cycle-modulated, 1,000-cycle seizing pulse is received over the toll line TL—4, from 45 the Rio de Janeiro exchange, it passes into the tone unit TU—4 through the receiving conductors 1162 and causes an actuation of the incoming signal relay 1205 to place momentarily ground potential on the signal-in conductor 1163. Signal-repeating relay 1123 is thereby operated 50 momentarily to close a circuit through contacts of release-pulse timer relay 1107 and through contacts of selector-seizing relay 1120 for the lower winding of the two-step selector-seizing relay 1120. The lower winding of relay 1120 is relatively inefficient, whereby the energization on which results is sufficient only to close the lightly-adjusted inner upper contacts of the relay. At 55 these contacts, a locking circuit for both windings of the relay in series is closed, but no current flows through the upper winding of the relay for the moment, as ground potential is applied to both terminals of the upper winding. Relay 1123 also operates slow-acting relay 1104 to prepare a circuit for loop-test relay 1119. When the restoration of signal-repeating relay 1123 occurs, current flows through the two-windings of relay 1120 in series in the locking circuit, energizing the relay sufficiently that it operates fully. Upon 60 operating fully, selector-seizing relay 1120 grounds the incoming control conductor 1151; it disconnects the lead controlled by the signal-repeating relay 1123 from the junction of its windings and extends it to ring-control relay 1116; it prepares 65 70 75 70 75

a circuit for switch-over relay 1117; it places ground potential on holding conductor 1150; it disconnects the C terminal 1100 and its multiples from the idle-indicating battery potential normally placed thereon through the lower windings of release relay 1105 and substitutes a guarding ground potential, whereby the toll line is guarded from seizure by way of the switches having access thereto in Sao Paulo and the chain relay 1135 is operated; it places ground potential on the C conductor of the trunk T4, extending to the toll first selector TFS-2, Fig. 7, to provide a holding circuit for this selector when it becomes operated; it connects supervisory relay 1122 to the EC lead of the trunk T4; and it closes a circuit for the lower winding of loop-test relay 1119 through contacts of the slow-releasing relay 1104; actuated temporarily as previously mentioned by signal-repeating relay 1123.

20 Loop-test relay 1119 closes a circuit at its lower contacts for relay line-supervisory relay 1109, preparatory to an operation of 1109 when relay 1119 restores. Relay 1119 also closes a circuit from the ground holding conductor 1150 for auxiliary relay 1118. Relay 1118 disconnects the EC lead of the trunk T4 from the upper winding of supervisory relay 1122 and extends it to ground on the holding conductor 1150, by way of the lower winding of the toll-to-toll relay 1108 for a test purpose which is involved only on toll calls completed automatically through the Sao Paulo exchange from one toll-dialling line to another, as hereinafter described. In addition, auxiliary relay 1118 bridges the upper winding of loop-test relay 1119 across the talking conductors of the trunk T4 through contacts of the incoming repeating relay 1124. The upper winding of loop-test relay 1119 becomes energized in this bridge circuit in series with the line relay (not shown) of the toll first selector TFS-3 Fig. 7. This toll first selector, which is similar to the toll first selector TFS-1 in Fig. 6, is prepared for operation responsive to the energization of its line, release, and series relays, corresponding respectively to the line, release, and series relays 601, 602, and 603 of the selector TFS-1, Fig. 6. Loop-test relay 1119 is thereby held operated by means of its upper winding after series relay 1104 has restored and opened the circuit of the lower winding of the relay.

50 In order to make provisions for the addition of an answering jack or the equivalent thereof at the toll board or at a special intercepting position, ring-down lead 1136 is provided. This lead is connected to contacts of the signal repeating relay 1123 through contacts of the actuated selector-seizing relay 1128, upon the operation of auxiliary relay 1118, whereby this lead becomes energized in the event that the Rio de Janeiro operator actuates her ringing key following the seizure of the toll line and before she has set up the digits of the desired number.

60 In order to provide for the reception of the dial pulses, auxiliary relay 1118, places ground potential on the pulse-cut-in conductor 1166 at its lower contacts, from the grounded incoming control conductor 1151, through contacts of the toll-to-toll relay 1108. Pulse-cut-in relay 1204 in the tone unit TU-2 is thereupon operated to substitute the incoming impulse relay 1203 for the place impedance coil 1207 in the plate circuit of impulse amplifier 1213.

70 When the pulses of the first series arrive, incoming impulse relay 1203 is momentarily operated upon the reception of each pulse. Each

time it operates, relay 1203 momentarily applies ground potential to dial-in lead 1164, thereby momentarily operating incoming-repeating relay 1124. Each time it operates, relay 1124 closes a circuit momentarily for slow-acting impulse-series relay 1104 at its lower contacts, whereby relay 1104 is operated upon the receipt of the first impulse of a series and remains operated throughout the series of impulses to close a local holding circuit for the lower winding of loop test relay 1119 to maintain this relay actuated locally while the impulses are being delivered to the switch train. Upon the first operation of incoming repeating relay 1124 a circuit is closed at the inner lower contacts thereof for ring-control relay 1116 from the grounded holding conductor 1150 through contacts of relays 1101, 1103, and 1109. Ring-control relay 1116 thereupon operates and closes a locking circuit for itself independent of the contacts of incoming-repeating relay 1124, while at its lower armature it actuates the slow-releasing ring-prepare relay 1115 to prepare for the subsequent operation of ring relay 1114 when the connection has been extended to the called line.

25 At its upper contacts, incoming repeating relay 1124 breaks the control bridge established across the talking conductors of the trunk T4 each time it operates. In this way, each impulse received by incoming repeating relay 1124 is repeated as a 30 momentary break impulse in the circuit of the line relay of the connected selector. Since the first digit received is the digit two, represented by two impulses, the toll first selector TFS-2, Fig. 7, is caused to raise its wipers 750 opposite 35 the second level of bank contacts and rotate them in search of an idle toll office selector, the toll office selectors being accessible from the second level of the toll second selectors as explained hereinbefore and as illustrated in Fig. 2, part 1. 40 It may be assumed that the toll office selector TOS-1 Figs. 2 and 9 is selected, by way of the terminals 900. The toll office selector TOS-1 is prepared for operation by the previously described energization of line, release, and series 45 relays 901, 902, and 903.

When the impulse series is terminated, incoming repeating relay 1124 comes to rest in a restored condition, again closing the control bridge at its upper contacts. Loop-test relay 1119 is 50 maintained operated through its upper winding after series relay 1104 has restored at the end of the series and opened the holding circuit of the lower winding.

55 In a similar manner, each of the subsequently received series of impulses results in the operation of series relay 1104 throughout the series and in the repetition of each of the impulses of the series at the upper contacts of incoming repeating relay 1124.

The toll office selector TOS-1 responds as previously described to the office digit 8 in the desired number to select a trunk line leading to a toll thousands selector in the called office (see Fig. 2, part 1); the seized toll thousand selector responds to the thousands digit 4 of the desired number to extend connection to a toll hundreds selector; the toll hundreds selector responds to the hundreds digit 1 to extend connection to a combination toll and local connector; and the seized connector responds to the tens and units digits 6 and 1 to extend connection to the desired line of substation A, Fig. 2.

60 Assuming that the line of substation A is idle, upon the termination of the final digit of the 75

number, the current reversal which takes place over the inter-office trunk as a result of the extension of the connection to an idle line brings about the operation of the electro-polarized 5 switch-over control relay 906 in the toll office selector TOS-1, following which supervisory relay 907 is operated. At the same time, switch-over relay 905 is operated to close the holding circuit over the inter-office trunk and to introduce 10 the repeating coil 951 and thereby "dry" the talking conductors incoming to the toll office selector TOS-1. At the same time, ground potential is applied to the EC lead incoming to the toll office selector TOS-1 by supervisory relay 15 907.

11. Automatic ring-start

With impulse series relay 1104 of the repeater IR-2 in a deenergized condition following the repeating of the final series of pulses, loop test 20 relay 1119 is held operated solely by the flow of current through its upper winding. Therefore, when the toll office selector TOS-1 of Fig. 9, responds to the line supervisory condition received from the called office, and dries the talking conductors as above pointed out, loop-test 25 relay 1119 restores. Upon restoring, relay 1119 at its lower contacts disconnects ground potential (obtained from holding conductor 1150 through contacts of relays 1101, 1103, and 1109) 30 from the control conductor leading through contacts of relays 1111, 1110, and 1109 to line-supervisory relay 1109. Relay 1109 is thereupon operated, being a differential stored-energy counting relay as previously explained. Upon operating, 35 relay 109 opens the local circuit of pad-control relay 1133 to enable the pad-control relay to be controlled over the extended connection according to whether the connection is completed in the same exchange or is switched through to 40 another exchange. Relay 1109 also opens the locking circuit of ring-control relay 1116, previously closed from the holding conductor 1150 through contacts of relays 1101 and 1103. When this occurs, ring-control relay 1116 restores and 45 opens the circuit of slow-acting ring-prepare relay 1115, thereby closing a circuit momentarily through contacts of the slow-releasing relay 1115 for ringing relay 1114. Ringing relay 1114 is thereby operated momentarily to place negative 50 potential on the positive talking conductor leading to the toll office selector, whereby ringing relay 908 therein is momentarily operated to project ringing current over the inter-office trunk line to start the ringing operation.

55 12. Line supervision

As a further result of its restoration, loop-test relay 1110 permits auxiliary relay 1118 to restore and close a circuit through contacts of the actuated relay 1120 for the upper winding of supervisory relay 1122, from the EC lead of the trunk T4, now extending to and grounded in the toll office selector TOS-1 of Fig. 9 through contacts of the operated supervisory relay 907. Supervisory relay 1122 is thereupon operated to secure the transmission of a supervisory impulse back over the toll line TL-4 to the calling Rio de Janeiro exchange. At the same time, auxiliary relay 1118 prepares a circuit for the upper winding of switch-over relay 1117; it places ring-control relay 1116 under the control of signal-repeating relay 1123; and it removes ground potential from pulse-cut-in conductor 1166 to permit pulse-cut-in relay 1204 to restore and substitute impedance coil 1207 for the incoming-im-

pulse relay 1203. By this arrangement, impulse of 1,000-cycle voice current which may pass over the toll line TL-4 during conversation do not affect incoming impulse relay 1203. Relay 1203 is removed from circuit instead of the alternative and perhaps simpler method of opening the dial-in lead 1164. The method illustrated is the one preferred, as otherwise frequent and erratic operation of the incoming impulse relay during conversation may cause excessive wear of the relay, 10 in addition to making an unnecessary chattering noise.

Upon the previously-mentioned actuation of supervisory relay 1122, a circuit is closed from the grounded incoming-control conductor 1151, 15 through contacts of the non-actuated relay 1110, and by way of contacts of relays 1123, and 1131, for the supervisory-pulse 1127. As a result, relays 1128, 1129, and 1130 are operated to bring about the transmission of a 60-cycle modulated 20 1,000-cycle pulse over the toll line TL-4 to the calling exchange, the energizing battery potential having been removed from modulation cut-off conductor 1167 at the lower contacts of relay 1109, to permit relay 1201 and restore and connect up the modulation conductor 1241. Direction-transfer relay 1202 is restored to adapt the two-way amplifier 1211 for outgoing operation, when preparing relay 1128 removes ground potential from direction-transfer conductor 1165. 30

Coincidental with the transmission of the line-supervisory pulse over the toll line, preparing relay 1128 completes the prepared circuit through contacts of the operated selector-seizing relay 1120 and through contacts of the restored auxiliary 35 relay 1118 for switchover relay 1117. Relay 1117 thereupon operates and locks itself to the grounded holding conductor 1150. At the same time, sequence relay 1113 is operated by sending relay 1129 to lock itself to conductor 1150, but the operation of relay 1113 is merely incidental at this time.

With relays 1107 and 1126 in restored condition, there is ground potential present on the lower armature of the sending auxiliary relay 1130. 45 Therefore, at the lower armature of relay 1130 a circuit is closed through contacts of the non-operated relays 1111 and 1110 and contacts of the operated relay 1109 for the windings of the differential, stored-energy counting relay 1110, 50 whereby this relay is prepared to operate upon the termination of the transmitted supervisory pulse.

Inter-pulse timer relay 1131 is operated by auxiliary relay 1130 to disconnect the slow-acting 55 supervisory pulse relay 1127. Relay 1127 is thus permitted to restore and bring about the restoration of relays 1128-1131. Upon the restoration of relay 1130 the initial circuit of relay 1110 is opened, permitting this counting relay to operate fully and transfer the circuit of supervisory-pulse 1127 from the front contact of the armature of supervisory relay 1122 to the back contact thereof, whereby no further supervisory pulse is transmitted until supervisory relay 1122 again 60 restores.

Upon the previously-mentioned operation of relay 1117, taking place during the transmission of the supervisory pulse, impulse-series relay 1104 is disconnected from in multiple with the winding 70 of inter-pulse-timer relay 1131; the talking conductors are extended; an additional application of ground potential is made to the C lead of the trunk T4; and the lower winding of supervisory relay 1122 is disconnected from in multiple with 75

the ring-start relay 1114. By the connection of the lower winding of the supervisory relay 1122 in multiple with winding of ring-start relay 1114 a local operation of supervisory relay 1122 is secured which is of utility when calls are extended to outgoing manual toll lines, as will be pointed out hereinafter. In a call such as the one now being described, supervisory relay 1122 is operated through its upper winding over the EC lead of the trunk T4 before the lower winding of the relay becomes momentarily energized in multiple with the winding of ring-start relay 1114 when the relays 1114—1116 are controlled as previously described to transmit a ring-start pulse, responsive to the restoration of loop-test relay 1119.

The 60-cycle-modulated, 1,000-cycle line-supervisory pulse transmitted over the toll line TL-4 is received at the tone unit TU-4, with the result that signal-repeating relay 1423 is momentarily operated over the signal-in conductor 1463. Upon operating, signal-repeating relay 1423 closes a circuit, through contacts of the normally-operated incoming-release relay 1421, and through contacts of the actuated release-pulse-timer relay 1407 for the windings of the differential-counting, line supervision relay 1409. As a result, relay 1409 is energized when this pulse is terminated to close the series-aiding locking circuit for its two windings and to disconnect the associated 300-ohm resistor. Relay 1409 opens the local circuit previously existing through resistors 1442 and 1440 for the pad-control relay 1433 to enable this relay to be controlled subsequently over the incoming talking conductors; it opens points in the circuits controlled by the energized line relay 1403 so that this relay may now be restored without any adverse effect; it closes a new circuit for the operated release relay 1405, to ground at contacts of the operated sleeve relay 1435, thereby applying ground potential to cut-off conductor 5; it disconnects start relay 1436 to permit it to restore; and it disconnects the line relay 1403 from in bridge of the incoming talking conductors, at the same time closing points in the talking circuit and disconnecting the 600-ohm losser resistor 1443.

13. Freeing the register sender RS-1

Upon the restoration of start relay 1436 responsive to the operation of relay 1409, the cut-off conductor 5 of the cable 1700 is opened, permitting test relay 1702 to restore. Upon restoring, test relay 1702 removes ground potential from the holding conductor 1722 to permit the register sender RS-1 of Fig. 18 to clear out. Connecting relay 1701 restores when ground potential is removed from conductor 1722 and disconnects the wipers of the finder F-3 at its lower contacts, relay 1701 again applies ground potential to test lead 1730 to indicate to the allotter AL that the finder F-3 and the associated register sender are available for further use.

In the repeater IR-4, with the start relay 1436 restored and line supervisory relay 1409 operated, the tip and ring conductors of the jack J-2 are extended through contacts of the restored relay 1436 and through contacts of the operated relay 1439 to the switchboard windings of repeating coil 1475.

As a further result of the operation of line supervisory relay 1409, the 100-ohm lower winding of sleeve relay 1435 is placed in shunt of the 1700-ohm upper winding, thereby increasing the

current flow over the sleeve of the jack J-2 and of the calling plug CP sufficiently to enable the calling supervisory lamp 2003 to become lighted, thereby giving the operator line supervision to inform her that the connection has been completed to the line and that the line is idle. It is to be noted that the operator is not required to actuate her ringing key to transmit a starting impulse of ringing current, as the ringing operation has been started upon the automatic transmission of the starting pulse effected by ringing relay 1114 of the repeater IR-2 as previously pointed out. If this feature is not desired, it may be eliminated by disconnecting the inner lower contacts of incoming repeating relay 1124, in which case ring-control relay 1126 does not become operated as the result of the receipt of dial pulses at the repeater IR-2. In this event, the operator at the position of Figs. 20 and 21 actuates her ringing key after she receives the line supervision to cause relays 1114—1116 to go through momentary cycle of operation to project a starting impulse of ringing current. After the automatic ringing operation has been started, in the event that the operator maintains her talking key actuated, the operator is able to hear the usual ring-back tone customarily transmitted during the automatic ringing operation.

14. Answer supervision

30

When the called subscriber replies and the current-flow over the trunk extending to the called office is discontinued as a result, supervisory relay 907 of the toll office selector TOS-1, Fig. 9 restores and removes supervisory ground potential from the incoming EC lead, whereupon supervisory relay 1122 of the repeater IR-2 restores and closes a circuit for the supervisory-pulse relay 1127 through contacts of the operated counting relay 1110. Relay 1127 operates to cause relays 1128—1130 to operate pursuant to the transmission of a 60-cycle-modulated answering-supervisory pulse, followed by the operation of inter-pulse timer relay 1131 to disconnect relay 1127 and permit relays 1127—1131 to restore. Auxiliary relay 1130 closes a circuit through contacts of the operated relays 1109 and 1110 for operating the counting relay 1111 upon the termination of this pulse. Unlocked relay 1112 responds to the operation of relay 1111 by opening the locking circuit of relays 1110 and 1111 to permit both of these relays to restore. Relay 1110 is thereby restored coincidental with the transmission of the answering supervisory pulse to prevent an immediate reoperation of supervisory pulse relay 1127 and to prepare for the reoperation of this relay when supervisory relay 1122 is reoperated.

In the Rio de Janeiro exchange, upon the receipt of the answer-supervisory pulse, signal-repeating relay 1423 closes a circuit through contacts of relays 1411 and 1410 and through contacts of the actuated line supervisory relay 1409 to the windings of answer-supervisory relay 1410. As a result relay 1410 operates upon the termination of this pulse to prepare a circuit for disconnect supervisory relay 1411 and to disconnect the 100-ohm lower winding of sleeve relay 1435 from in shunt of the 1700-ohm upper winding, whereby the current flow over the sleeve conductor of the connection is sufficiently reduced that calling supervisory lamp 2003 of the cord circuit CC-2 does not receive sufficient current to light it. Therefore, with the talking key K-9 restored, the operator at the position of Fig. 20 receives dark-lamp answer supervision at the lamp 2003. 75

15. Disconnect supervision

When the called subscriber replaces his receiver and thereby causes the supervisory relay 907 to reoperate and apply potential to the associated 5 incoming EC lead, supervisory relay 1122 of the impulse repeater IR-2 is reoperated to close a circuit through contacts of the restored counting relay 1110 for supervisory pulse relay 1127. A 60-cycle-modulated 1,000-cycle disconnect supervisory impulse is thereby transmitted over the toll line TL-4 and coincidental therewith an impulse is delivered through contacts of the operated relay 1109 for reoperating counting relay 1110 whereby reoperation of relay 1127 at the end 10 of the cycle of operation of relays 1127-1131 is prevented.

In the Rio de Janeiro exchange, signal-repeating relay 1423 responds to the disconnect supervisory pulse by closing a circuit through contacts 20 of the operated relays 1409 and 1410 for disconnect-supervisory relay 1411. Relay 1411 operates unlock relay 1412 to unlock and restore relays 1411 and 1410. Relay 1410 reconnects the lower 25 winding of sleeve relay 1435 in shunt of the upper winding of this relay, thereby again closing a lighting circuit for lamp 2003. This lamp becomes lighted as a disconnect signal.

16. Recalling the called subscriber

30 In the event that the operator wishes to recall the called subscriber after he has replaced his receiver, she may actuate the split-answer key K-10 (with the talking key K-9 operated) and then actuate the ringing key K-15 to apply a battery potential momentarily to the tip conductor TC, which is extended through the tip of the calling plug CP to the tip conductor of the impulse repeater IR-4. Ringing relay 1426 is thereby operated to close a circuit through 40 contacts of the signal-repeating relay 1423 for supervisory pulse relay 1427. As a result, relays 1428 to 1431 are caused to go through a cycle of operations, and relay 1427 is then restored to permit relays 1438 and 1431 to restore. During 45 this cycle of operations a 60-cycle-modulated, 1,000-cycle ringing impulse is transmitted over the toll line TL-4. Signal-repeating relay 1423 responds to this impulse to close a circuit through contacts of the restored relay 1107, contacts of 50 the actuated selector-seizing relay 1120, and contacts of the restored relay 1110, for ring-control relay 1116. Upon operating, ring-control relay 1116 closes a circuit for ring-prepare relay 1115, whereupon relay 1115 prepares a circuit 55 for ring relay 1114. When ring-control relay 1116 restores it closes a circuit through contacts of the actuated relay 1115 for momentarily operating ringing relay 1114. Relay 1114 operates to apply negative potential momentarily to the 60 positive talking conductor of the trunk T-4, extending through the incoming toll first selector to the toll office selector TOS-4, Fig. 9. The ground-connected ringing relay 908 thereupon responds to transmit ringing current over the 65 conductors of the inter-office trunk to cause the called subscriber to be resignalled.

17. Recalling the toll operator

In the event that the called subscriber desires 70 to signal the operator to attract her attention, the hookswitch movement causes a series of supervisory pulses to be transmitted back over the toll line TL-4 to cause intermittent operation and restoration of the supervisory relays 1410 and 75 1411 to bring about a flashing of the calling su-

pervisory lamp. It is during this hookswitch signalling operation that the closure of the locking circuit for supervisory pulse relay 1127 when it operates is of particular utility to secure the transmission of pulses of reliable length. Also, 5 the provision of interpulse-timer relay 1131 to maintain relay 1127 disconnected for an appreciable interval insure the elapse of a desired interval between pulses to enable the counting of the pulses to take place in both ends of the toll 10 line, whereby the response to the supervisory pulses in the repeater of Fig. 14 does not get out of step with the transmission thereof.

18: Group-busy signalling

15

In the event that a busy condition is encountered at a trunk group during the setting up the connection being described, the intermittent application of potential to the EC lead as described hereinbefore results in an intermittent operation 20 and restoration of supervisory relay 1122, following the restoration of relays 1109 and 1110, whereby successive supervisory pulses are transmitted back over the toll line TL-4 to the repeater of Fig. 14. The first of these supervisory 25 pulses is received in the same way described in connection with the receipt of the line-supervisory pulse, and the subsequent ones flash of the supervisory lamp 2003 in the event that the operator has restored her talking key. The 30 pulses are heard by the operator in the event that she still has her talking key thrown as the pulses are of audible frequency. It is to be noted that the automatic disconnection of the register-sender from circuit takes place in this case 35 responsive to the receipt of the first in a series of busy-signalling supervisory pulses.

19. Clearing out

When the operator takes down the connection, 40 the removal of the calling plug CP of the cord circuit CC-2, Fig. 20, from the jack J2 of Fig. 19, results in the opening of the circuit of sleeve relay 1435. Sleeve relay 1435 restores and opens the locking circuit of release relay 1405. Upon 45 restoring, release-pulse-timer relay 1407 opens the circuit of the relay 1406, which relay de-energizes and permits its weighted armature to vibrate vigorously for a period of perhaps a second, during which time the slow-responding release-pulse-timer relay 1407 is held operated. Then, when the amplitude of the vibrations of the weighted armature of relay 1406 has decreased somewhat, relay 1407 restores. Upon 50 restoring, release relay 1407 removes ground potential from holding conductor 1450, permitting line supervisory relay 1409 and sequence relay 1413 to restore.

Upon the restoration of release relay 1405, and 60 throughout the time that release-pulse-timer relay 1407 remains operated, circuits are closed through contacts of the operated relay 1407 and through contacts of the restored release relay 1405 for the winding of sending relay 1429 and for the winding of preparing relay 1428. Preparing relay 1428 disconnects the receiving conductors 1462 and removes ground potential from direction transfer relay 1465, whereupon the tone unit TU-4 operates to apply a 60-cycle-modulated 1,000-cycle potential to sending leads 1461. 70 This potential is impressed on the conductors of the toll line TL-4 through contacts of operated sending relay 1429 throughout the remaining time required for release-pulse timer relay 1407 to restore and open circuit relays 1428 and 1429. 75

In the Sao Paulo exchange, the prolonged releasing pulse is received at the tone unit TU-2 with the result that incoming signal relay 1125 is operated for a substantial length of time to maintain signal-in lead 1163 grounded for a substantial interval. Signal-repeating relay 1123 is thereby operated for a sufficient length of time to permit incoming release relay 1121 to restore. It is to be noted that ring-control relay 1116 is operated, through contacts of signal-repeating relay 1123 to close a circuit for ring-prepare relay 1115 to thereby prepare for an operation of ringing 1114. However, upon the release of selector-seizing relay 1120, which takes place upon the restoration of incoming release relay 1121 before the incoming release pulse is ended, ground potential is removed from the incoming control conductor 1151 thereby deenergizing the lower armature of ring-control relay 1116 and preventing an operation at this time of ringing relay 1114. Selector-seizing relay 1120 also removes ground potential at one point from holding conductor 1150, leaving this conductor grounded only at contacts of signal-repeating relay 1123.

When the prolonged releasing impulse is ended and signal-repeating relay 1123 restores, the ground potential is completely removed from holding conductor 1150, whereupon relays 1109, 1110, 1113, and 1117 restore. Incoming release relay 1121 reoperates upon the restoration of signal-repeating relay 1123, thereby again connecting the C terminal 1100 to release relay 1105, rendering the repeater IR-2 and the toll line TL-4 selectable again by way of terminals 1100 and the multiples thereof.

With switchover relay 1117 and selector-seizing relay 1120 both restored, holding ground potential is removed from the C conductor of the trunk T4, extending to the toll first selector TFS-3. This selector thereupon clears out and permits the succeeding toll office selector TOS-1 of Fig. 9 to clear out. The clearing out of the toll office selector permits the operated switches in the called office to clear out in the usual manner.

The entire connection is now cleared out.

H. CALLING FROM RIO DE JANEIRO TO JUNDIAHY

In order to explain a supervisory feature of the impulse repeater IR-2, Fig. 11, which is involved only in calls incoming to the Sao Paulo exchange and directed through this exchange to a manual toll line, it will be assumed that the operator at the toll board in Rio de Janeiro receives a call intended for a subscriber of the Jundiah exchange, reached from Rio de Janeiro through Sao Paulo. It may be assumed that the Rio de Janeiro toll operator uses the calling plug CP of the cord circuit CC-2 to insert into the jack J-2 Fig. 19, to extend the connection to Sao Paulo. Under this condition, a register sender such as the register sender RS-1 Fig. 18 is taken for use as previously explained to store the digits of the desired number and to transmit the corresponding series of dial pulses over the toll line TL-4.

In the repeater IR-2, selector-seizing relay 1120 and associated relays are operated responsive to the seizing pulse received and repeated by signal-repeating relay 1123. The toll first selector TFS-3 of Fig. 7 is thereby taken for use and prepared for operation.

The series of impulses constituting the desired number are repeated by incoming repeating relay 1124 into the switch operating circuit at the up-

per contacts of this relay. Also, as previously explained, ring control relay 1116 becomes operated and locks itself responsive to the first operation of incoming repeating relay 1124 to operate ring-prepare relay 1115 in preparation for a momentary operation of ringing relay 1114 when the desired line has been reached.

Upon the receipt of the first digit (the digit 1; see Fig. 2) the toll first selector TFS-2 raises its wipers opposite the first level of bank contacts and selects an idle toll line selector, the toll line selector TLS-1, Figs. 2 and 10, for example.

The toll line selector TLS-2 responds to the two final digits in the designation of the desired toll line group by raising its wipers opposite the ninth level of bank contacts rotating them into engagement with the first toll line of the group.

It may be assumed that the toll line TL-1, Figs. 1, 2, and 4 is the first one found to be idle and that it is accordingly seized by the toll line selector of Fig. 10, at terminals 460. The cut-off relay 409 in the toll line circuit TLC-1 is operated upon the seizure of this toll line, as previously explained.

1. Automatic line and answer supervision

Since no line relay is bridged across the conductors of the trunk T2, Figs. 2 and 4, over which the outgoing connections are extended to the toll line TL-1, loop-test relay 1119 restores when this toll line is seized and opens the circuit of auxiliary relay 1118. As previously explained, the restoration of loop-test relay 1119 under these circumstances results in the opening of the initial circuit for line-supervisory relay 1109 at the lower contacts of relay 1119, whereupon relay 1109 operates and opens the circuit of ring-control relay 1116 to permit this relay to restore.

Upon the restoration of relay 1116 the circuit of slow-acting relay 1115 is closed and a circuit is closed momentarily through contacts of relay 1115 for the ringing relay 1114. Relay 1114 is thereby momentarily operated to apply a negative ringing pulse to the positive talking conductor. At the same time, a circuit in parallel with the winding of relay 1114 through contacts of the non-operated switchover relay 1117 for the lower winding of supervisory relay 1122. Relay 1122 is thus locally operated and closes a circuit through contacts of the non-operated relay 1110 for supervisory pulse relay 1121. The relays 1127-1131 therefore go through the described cycle of operation to transmit 60-cycle-modulated 1,000-cycle line-supervisory pulse back over the toll line TL-4. Supervisory relay 1122 restores while this pulse is being transmitted (as its circuit is closed only momentarily) and prepares a circuit for transmitting a second supervisory pulse upon the operation of counting. It will be recalled that relay 1127 locks itself operated at its lower contacts to insure that the relays 1127-1131 go through their complete cycle of operation. At the lower contacts of auxiliary relay 1130 a circuit is closed through contacts of the operated counting relay 1109 for counting relay 1110, whereby this relay operates upon the restoration of auxiliary relay 1130 to close a new circuit through contacts of the now-restored supervisory relay 1122 for relay 1127 as soon as inter-pulse-timer relay 1131 is restored. Relays 1127-1131 are thereby caused to go through a second cycle of operations and transmit an answering-supervisory impulse back to the Rio de Janeiro exchange so as to avoid having

the calling supervisory lamp continuously lighted throughout the connection, as supervision is not obtained over the called manual line when the called subscriber answers.

5 During the transmission of the answer-supervisory pulse, counting relay 1111 is operated through contacts of the operated relay 1110 to operate the unlock relay 1112, whereby relays 1110 and 1111 are unlocked and permitted to 10 restore whereby a further supervisory impulse is prevented from being sent.

In the calling Rio de Janeiro exchange, line supervisory relay 1409 responds to the line supervisory pulse transmitted responsive to the seizure 15 of the Jundiah exchange, and thereby secures the completion of the talking circuit and the disconnection of the register sender. Answer-supervisory relay 1410 is operated responsive to the automatically transmitted answer-supervisory 20 pulse to avoid maintaining the calling supervisory lamp 2003 lighted during conversation.

In the toll line circuit TLC-1, ringing relay 403 is operated over the positive talking conductor responsive to the ring-start impulse transmitted by ringing relay 1114 of the repeater IR-2, as above pointed out. Ringing current is transmitted over the toll line TL-1 by ringing relay 403 to signal the operator in the distant Jundiah exchange. Since no pad-control resistors (such as the pad-control resistor at the repeating coil 300, Fig. 3) are provided at the repeating coil 400 of the toll line TL-1, nor at the repeating coil 1175 of the toll line TL-4, pad-control relay 1135 of the toll line TL-4 is restored to permit pad-cut-out relay 1134 to operate, and pad-control relay 402 of the toll line circuit TLC-1 is restored to permit pad-cut-out relay 401 to operate and remove the associated pad 413. Both of the toll line pads in Sao Paulo 40 are thereby removed to adapt the toll line for interconnected operation.

Upon the response of the Jundiah operator, the two operators may converse, following which the Jundiah operator may complete the connection to the desired line.

2. Recalling the originating toll operator

If, while the connection is established, the Jundiah operator wishes to call the Rio de Janeiro operator, she may do so by projecting ringing current over the toll line TL-1, preferably by several successive operations of the ringing key. Each time an impulse of ringing current is received ring-up relay 407 responds and permits slow-acting signal relay 406 to restore and close a circuit for the upper winding of start relay 409. Cut-off relay 409 being operated, a locking circuit is closed for the lower winding of relay 406 over the EC lead of the connection established in the Sao Paulo office, as ground potential is applied to this lead at the inner upper contacts of the relay through its lower winding. This locking circuit includes the 800-ohm winding of supervisory relay 1122 of the repeater IR-2 at this time. The supervisory relay therefore is operated each time start relay 408 is operated, but the start relay does not remain operated in the locking circuit because of the relatively high resistance of the upper winding of supervisory relay 1122. Therefore, when the impulse of ringing current ceases, start relay 408 restores and opens the local circuit of supervisory relay 1122, permitting this relay to restore. Each time it operates, supervisory relay 1122 closes a circuit through contacts of the 75 restored counting relay 1110 for supervisory-pulse

relay 1127, whereby a supervisory pulse is transmitted over the toll line. At the same time, counting relay 1110 is operated to shift the circuit of supervisory-pulse relay 1127 to include the normally-closed contacts of supervisory relay 1122. Therefore, each time supervisory relay 1122 restores at the end of an impulse of ringing current, it closes a circuit through contacts of the operated counting relay 1110 for supervisory pulse 1127, thereby securing the transmission of an additional 60-cycle modulated 1,000-cycle supervisory pulse over the toll line. Relay 1110 is operated incidental to the transmission of each of these latter pulses to cause unlock relay 1112 to unlock and restore relays 1110 and 1111.

In the Rio de Janeiro exchange, each time a supervisory pulse is received as the result of an actuation of supervisory relay 1122 of the repeater IR-2, the resulting operating of signal repeating relay 1423 brings about the operation of disconnect supervisory relay 1411 to operate unlock relay 1412 and restore relays 1410 and 1411. Therefore, each time a supervisory pulse is received as the result of the following restoration of the supervisory relay 1122 in the Sao Paulo exchange, answer-supervisory relay 1410 becomes reoperated. Each time relay 1410 restores it closes a circuit through contacts of the actuated line-supervisory relay 1450 for bridging the 100-ohm winding of sleeve relay 1435 around the high-resistance upper winding of this relay, thereby lighting the calling supervisory lamp 2003 in the cord circuit CC-2. This lamp becomes extinguished when answering supervisory relay 1410 becomes reoperated responsive to the supervisory pulse indicating the end of the ringing pulse. In this way, the calling supervisory lamp 2003 becomes lighted momentarily each time the operator in the distant Jundiah exchange operates her ringing key, whereby this lamp may be flashed by repeated operation of the ringing key in the Jundiah exchange to attract the attention of the Rio de Janeiro operator.

3. Recalling the terminating toll operator

The Rio de Janeiro operator may resignal the Jundiah operator at any time by operating her ringing key to cause a pulse to be transmitted in the opposite direction over the toll line TL-4 which causes ringing relay 1164 in the repeater IR-2 to operate momentarily as previously described. This operator results in the application of a negative potential to bring about the operation of ringing relay 1402 in the toll line circuit TLC-1 to project ringing current over the toll line TL-1, leading to the Jundiah exchange.

4. Clearing out

After the conversation has been completed, when the toll operator at the position of Figs. 20 and 21 takes down the cord circuit TCC-2, the associated repeater IR-4 clears out as previously described and transmits a prolonged release pulse to the repeater IR-2, responsive to which this repeater clears out also, as does the associated toll first selector TFS-3, Fig. 7. Responsive to the clearing out of the toll first selector TFS-3, the toll line selector TLS-1 of Fig. 10 clears out and frees the toll line circuit TLC-1, Fig. 4.

I. CALLING FROM RIO DE JANEIRO TO CAMPINAS

In order to explain certain features of the apparatus which come into play only when a connection is made through the Sao Paulo exchange from one toll dialing line to another, it will be

- assumed that a call is received at the Rio de Janeiro toll board of Figs. 20 and 21 for a subscriber of the Campinas exchange, Fig. 1. It has been explained hereinbefore that the trunks such as TL-2, Figs. 1 and 2, extending between Sao Paulo and Campinas, are accessible to selectors in the Sao Paulo exchange, being reached responsive to the dialing of the digit combination 49.
- 10 It may be assumed that the Rio de Janeiro toll operator inserts the calling plug CP of the cord circuit CC-2 into the jack J2, Fig. 19, and thereby takes the repeater IR-4 for use with results hereinbefore explained. These results include the transmission of a seizing pulse over the toll line to prepare the distant repeater for operation and to cause it to seize the associated toll first selector, Fig. 7, in addition to the starting of a preselected finder in the calling exchange to cause a register sender to be associated with the repeater IR-4. It may be assumed that the finder F-3 Fig. 17 is the one operated, in which case it associates the register sender RS-1 of Fig. 18 with the repeater of Fig. 14 as previously described.

1. Setting up the routing digits

Since the connection is to be completed through the Sao Paulo exchange to a line in the distant Campinas exchange, the digits required to be transmitted exceed the maximum of digits (six) that can be stored in the register sender RS-1 at one time. Therefore, the operator is instructed to set up a portion of these digits and wait until they have been sent before she sets up further digits. It may be assumed that the operator is instructed to set up the three routing digits and then wait until they have been transmitted. The first two of these digits are the digits 4 and 9 required to extend the connection of a toll line extending to the Campinas exchange from the Sao Paulo exchange, while the third of these digits is the one used in the Sao Paulo exchange to extend connection from an incoming toll first selector to a toll office selector. The remaining digits therefore are the ones constituting the listed number of the desired line in the Campinas exchange.

When the operator sets up the first routing digit on the appropriate one of her digit keys 2100, the relay group RG of Fig. 17 operates as previously described to cause this digit to be registered on the relays of the digit-storage device DS-1, following which the input-distributor relay 1821 operates to disconnect the digit-storing device DS-1 and substitute the digit-storing device DS-2. The second routing digit, therefore, is stored on the digit-storing device DS-2, and the third is stored on the digit-storing device DS-3.

Upon the storing of the first routing digit, the grounding of start conductor 1810 at contacts of input distributor relay 1821 results in the operation of the relay 1828 of the supervisory pair including relays 1828 and 1829. The upper contacts of relay 1828 shunt the upper contacts of relay 1829 to maintain ground potential connected to relays C and D of the group RG after relay 1829 has operated.

70 When the first stored digit is retransmitted through the sending and counting operation of the relays illustrated at the bottom of Fig. 18, parts 1 and 2, output distributor relay 1831 is operated to render the digit-storage device DS-2 effective to control the sending operation, and

input-distributor 1821 is restored. Similarly, input-distributor relay 1822 associated with digit-storage device DS-2 is restored upon the retransmission of the second stored digit, while the input-distributor relay 1823 is restored upon the completion of the retransmission of the third and final stored digit. Upon the restoration of relay 1823, start conductor 1810 again becomes ungrounded, whereupon the sending operation is terminated as the interrupter relays 1837 to 1839 no longer have an actuating ground potential extended thereto.

Keeping in mind that pilot relay 2102 is maintained operated over the ring conductor of the position equipment and through relays C and D of the relay group RG, through the ground connection controlled by relays 1826, 1828, and 1829, it will be understood, that lamp 2104 remains lighted after the three routing digits have been set up until they have all been retransmitted. When ground potential is removed from start conductor 1810 of the register sender, relay 1828 of the sender-supervisory pair restores and opens the circuit of the slow-acting relay 1829. Therefore, ground potential is disconnected from relays C and D of the relay group RG for the interval required for the slow-acting relay 1829 to restore. At this time, relay 2103 restores and extinguishes the pilot light 2104.

A moment later, sender-supervisory relay 1829 restores and disconnects locking conductor 1812 from the grounded holding conductor 1722 permitting input distributor relays 1831-1833 to restore in preparation for the retransmission of additional digits to be stored on the digit-storage devices DS-1 to DS-3. At the same time, relay 1829 again extends ground potential at its upper contacts to relays C and D of the relay group RG whereupon pilot relay 2103 reoperates and relights the pilot lamp 2104.

2. Setting up the listed number

When this lamp again becomes lighted, the operator may proceed at once to set up the five digits in the listed number of the called Campinas subscriber, the digits being set up on the digit-storage devices DS-1 to DS-5. The register sender operates as explained to retransmit these five digits, following which it remains connected to the repeater IR-4 through the finder F-3 until the line-supervisory signal is received from the called exchange.

In the Sao Paulo exchange, the toll first selector TFS-3 of Fig. 7, upon the receipt of the first routing digit 4, raises its wipers opposite the fourth level and selects an idle toll-line selector, the toll-line selector TLS-2 of Fig. 8 for example, the selection being accomplished through multiples of terminals 800 in the bank of the selector of Fig. 7. The toll line selector TLS-2 responds to the second routing digit 0 to raise its wipers opposite the ninth level and select an idle toll line extending to the Campinas exchange from either the ninth level or tenth level, the selector TLS-2 being a level-hunting selector as previously pointed out and explained. It may be assumed that the toll line TL-2 of Figs. 1 and 2 is seized by the selector TLS-2 by way of the impulse repeater IR-1 of Fig. 2. The impulse repeater IR-1 and the associated tone unit TU-1 being duplicates respectively of the impulse-repeater IR-2 and the associated tone unit TU-2, the impulse repeater IR-1 is made ready for operation upon seizure and a 60-cycle-modulated, 1,000-cycle seizing pulse is transmitted over

the toll line TL-2 to the Campinas exchange. As previously mentioned, it is assumed that the Campinas exchange is provided with a cordless toll board as in the case of the Sao Paulo exchange and that the trunking arrangement in the Campinas exchange is similar to that in the Sao Paulo exchange. It will be understood of course that the Campinas end of the toll line TL-2 is provided with an impulse repeater similar to the 10 impulse repeater in the Sao Paulo exchange and that a toll first selector such as TFS-2 is provided in the Campinas exchange for each of the toll lines such as TL-2. Therefore, the incoming toll first selector in the Campinas exchange 15 is seized and made ready for operation.

3. Toll-to-toll adaptation

Special operations occurring upon the seizure 20 of the repeater IR-1 of Fig. 2 will now be explained. It has been mentioned previously that the toll-to-toll relay 1108 of the repeater IR-2 comes into play only when the associated toll dialing line is interconnected with another similar line. In this event, one winding of the toll-to-toll relay 1108 is energized in series with the other winding of the corresponding relay of the other repeater, upon the completion of the connection between the line.

It will be recalled that auxiliary relay 1118 is maintained operated by loop-test relay 1119 until the loop is opened. With auxiliary relay 1118 operated, the EC lead of the trunk T4 (extending to the incoming toll first selector TFS-3 of Fig. 7) extends through the 250-ohm lower winding of toll-to-toll relay 1108 to the grounded conductor 1150, thereby impressing a ground potential on the EC lead through this winding of relay 1108. When the impulse repeater IR-1 of Fig. 2 is seized, this repeater transmits a seizing impulse 30 to the distant exchange as previously pointed out, during which the auxiliary relay therein corresponding to auxiliary relay 1130 of the impulse repeater IR-2 operated. This relay impresses a battery potential on the EC lead incoming there- 40 to and corresponding to the EC lead incoming to the repeater IR-2 through the EC terminal 1100 and multiples thereof. This battery potential is impressed through the upper winding of the toll-to-toll relay in the repeater IR-1 corresponding 50 to toll-to-toll relay 1108 of the impulse repeater IR-2. As a result, these two toll-to-toll relays energized in series with each other.

When the toll-to-toll relay 1108 of the impulse repeater IR-2 is energized through its lower winding, it disconnects the grounded incoming control lead 1151 from the armature of ring-control relay 1116 to restore ring-prepare relay 1115; it disconnects the ring-down lead 1136; and it transfers the upper terminal of the upper winding of line-supervision relay 1109 to ground, whereupon this relay operates immediately. One result of the operation of relay 1109 that has a bearing on the present call is the disconnection of the losser resistor 1143 and the line-relay bridge from across the talking conductors. Relay 1109 also opens the locking circuit of ring-control relay 1116 and permits it to restore, but without effect, as ring-prepare relay 1115 has already been restored. Relay 1109 also opens the 60 local circuit previously established through resistors 1142 and 1145 for pad-control relay 1133, permitting this relay to restore and actuate the pad-cut-out relay 1134 to thereby cut-out the pad 70 1160 because the connection has been extended 75 to another toll line.

Toll-to-toll relay 1109 also closes a circuit from the grounded incoming-control conductor 1151 for the lower windings of switch-over and loop-test relays 1117 and 1119 in series. Switch-over relay 1117 is thereby operated, while the operated relay 1119 is held locally. Relay 1117 extends the connection through the repeater at its two uppermost armatures, at the same time removing the upper winding of relay 1119 from in bridge of the talking conductors. 10

In the outgoing repeater IR-1 of Fig. 2, the operation of the toll-to-toll relay in this repeater corresponding to toll-to-toll relay 1108 results also in the operation of the associated relay corresponding to relay 1109. In the repeater IR-1 15 therefore the line relay is disconnected from in bridge of the incoming talking conductors; the connection is extended to the outgoing conductors of the toll line through the repeating coil corresponding to repeating coil 1175; and pad-cut-out relay is operated in the repeater IR-1 to remove the pad at the toll line TL-2. 20

With the toll-to-toll relay 1108 operated in the impulse repeater IR-2, and with the corresponding relay operated in the impulse repeater IR-1 25 of Fig. 2, both repeaters are disabled from repeating further dial and supervisory pulses. The repeater on the distant end of the toll line TL-2, located in the Campinas exchange, is controlled directly from the impulse repeater IR-4 Figs. 2 30 and 14. All dial transmitted by the repeater IR-4 pass over the toll lines TL-4 and TL-2 in series and are received and handled at the impulse repeater in the distant Campinas exchange as previously explained for the repeater IR-2, 35 Fig. 11 when the call is to be completed in the Sao Paulo exchange.

It is to be noted that the previously mentioned removal of ground potential from the pulse-cut-in lead 1166 by relay 1108 results in the restoration of pulse-cut-in relay 1204 to remove incoming impulse-relay 1203 from circuit. Therefore, the remaining dial pulses, although received at the tone unit TU-2 through the receiving conductors 1162, have no effect upon the incoming-impulse relay 1203. The incoming signal relay 1205, however, is maintained effective to control the signal-repeating relay 1123 over the signal-in lead 1163 for the sole purpose of enabling relay 1123 to restore the incoming release relay 1121 and thereby clear out the repeater when the prolonged release pulse is transmitted. The operations of signal-repeating relay 1123 occurring when supervision pulses are transmitted are ineffective to actuate ring-control relay 1116 because auxiliary relay 1118 is maintained operated by the locally held loop-test relay 1119, no pulses are transmitted over ring-down lead 1136 because of the actuated condition of the toll-to-toll relay 1108. 50 55 60

When the connection has been completed to the called line in the Sao Paulo exchange, responsive to the transmission of the remaining trains of dial pulses, the line supervisory impulse transmitted back by the repeater in the Campinas exchange passes over the two toll lines in series and results finally in the operation of line supervisory relay 1409 in the impulse repeater IR-4. Responsive to the operation of this relay, the 65 previously-described operations take place, including the freeing of the finder F-3 and associated register sender RS-2 of Figs. 17 and 18. 70

Succeeding operations involved in the call are as explained hereinbefore. 75

4. Clearing out

When the operator takes down the connection and thereby causes the repeater IR-4 to transmit the prolonged release pulse, this release pulse is responded to at the repeaters IR-2 and IR-1 in Sao Paulo, and at the incoming repeater in the Campinas exchange response to this prolonged release pulse to clear out in the manner described 10 in connection with the repeater IR-2 on a call incoming from Rio de Janeiro to a line of the Sao Paulo exchange.

In the repeater IR-2, the response of signal-repeating relay 1123 to the prolonged release 15 pulse results in the making of an additional ground connection to the hold conductor 1150 at the upper contacts of this relay and in the release of the slow-acting incoming-release relay 1121 to unlock and restore selector-seizing relay 1120. 20 Upon the restoration of selector-seizing relay 1120, ground potential is removed from the incoming-control conductor 1151, thereby opening the circuit previously established by toll-to-toll relay 1108 through the lower windings of relays 25 1117 and 1119 in series. Relay 1117 remains operated in its locking circuit to the holding conductor 1150, maintained grounded at contacts of signal-repeating relay 1123 after the selector-seizing relay 1120 restores. Loop-test relay 1119 30 however restores and permits auxiliary relay 1118 to restore and break the circuit previously closed for the lower winding of toll-to-toll relay 1108, in series with the upper winding of the corresponding relay in the impulse repeater IR-1 of 35 Fig. 2. The toll-to-toll relays are thus restored in both repeaters during the receipt of the prolonged release pulse. The talking conductors channel however remains established between the calling Rio de Janeiro exchange and the called Campinas exchange throughout the transmission of the release pulse, as switch-over relay 40 1117 remains operated, thereby maintaining the connection extended through the talking conductors and maintaining ground potential on the C lead of the trunk T-4 after the selector-seizing relay 1120 has restored.

When the release pulse is terminated and signal-repeating relay 1123 restores, incoming-release relay 1121 is reoperated and ground potential is removed from holding conductor 1150. At 50 this point, the locked relays 1109 and 1117 restore, completely returning the repeater IR-2 to normal condition. Relay 1117 removes ground potential from the C conductor of the trunk T-4 permitting the selectors of Figs. 7 and 8 to clear 55 out and free the toll line extending to the Campinas exchange.

J. CALLING FROM CAMPINAS TO RIO DE JANEIRO

60 In order to complete the description of features of the system having to do with connections wherein two dialing toll lines are connected together for tandem working, the essential operations involved in the extension of a connection 65 from the Campinas exchange to a line in the Rio de Janeiro exchange will be explained.

The connection may be extended from the Campinas toll board to the toll line TL-2 of Figs. 1 and 2 in the same way that the connections are 70 extended from the Sao Paulo toll board to an outgoing toll line.

When the toll line TL-2 of Figs. 1 and 2 is seized in the Campinas exchange, a seizing pulse is received over this toll line at the impulse repeater IR-1, Fig. 2, to prepare this repeater for 75

operation and to cause the seizure of the associated toll first selector TFS-2. Then, when the routing digit 4 is dialed, the toll first selector TFS-2 is operated to raise its wipers opposite the fourth level and rotate them in search of an idle toll line selector such as the toll line selector TLS-2, Figs. 2 and 8.

The toll-line selector TLS-2 of Fig. 8 responds to the next routing digit 6 to select a toll line leading to the Rio de Janeiro exchange. It may be assumed that this toll line is the toll line TL-4, in which case the selection is accomplished through terminals 1100. Line relay 1103 of the repeater IR-2 is operated over the incoming talking conductors, and release and release-pulse timer relays 1105-1107 are operated responsive to current flow over the incoming C lead. Upon operation of release-pulse-timer relay 1107, a circuit is closed through contacts of sequence relay 1113 and by way of contacts of relays 1123 and 1131 for supervisory-pulse relay 1127 to cause this relay to operate as hereinbefore described to secure the operation of the associated relays 1128-1131, whereby the relays concerned go through the described cycle of operations to transmit a momentary seizing pulse over the toll line TL-4. While this seizing pulse is being transmitted, auxiliary relay 1130 connects the upper winding of toll-to-toll relay 1108 to the incoming EC lead, whereupon the upper winding of toll-to-toll relay 1108 is operated in series with the lower winding of the corresponding toll-to-toll relay in the impulse repeater IR-1, Fig. 2. The impulse repeater IR-1 is thereupon adapted for toll-to-toll working as previously explained for the repeater IR-2 during a call in the reverse direction between the Rio de Janeiro and Campinas exchanges.

At this time, when toll-to-toll relay 1108 operates, since incoming control conductor 1151 is not grounded, no circuit is closed for the lower windings of relays 1117 and 1119 in series. Relay 1108 locks its upper winding to the incoming EC lead independent of contacts of auxiliary relay 1130; it disconnects the upper contacts of answer-supervisory relay 1110 to prevent application of ground potential to the incoming EC lead upon the operation of relay 1109; and it operates line-supervisory relay 1109 at its inner upper armature. Relay 1109 disconnects the lesser resistor 1143 from in bridge of the left-hand windings of repeating coil 1175 and extends the incoming talking conductors to the toll line by way of the repeating coil, at the same time disconnecting the cut-off control relay 1102 and line relay 1103 from in bridge of the incoming talking conductors. Line relay 1103 restores, but its contacts have been rendered ineffective by the operation of relay 1109. Relay 1109 also opens the circuit of pad-control relay 1133 to permit pad-cut-out relay 1134 to operate from conductor 1150 to cut out the pad 1160.

The dial pulses received from the outgoing repeater in the Campinas exchange pass through the negative and positive terminals 1100 and over the toll line TL-4, without effect at the tone unit TU-2 and the repeater IR-2. The incoming signal relay 1205 of the tone unit TU-2 however, is effective to control the signal-repeating relay 1123 when supervisory pulses are received 70 from the called Rio de Janeiro exchange, as well as when ringing impulses may be transmitted to the Rio de Janeiro exchange. Relay 1123 controls the answer-and-disconnect supervisory relays 1110 and 1111 and unlock relays 1112 as 75

previously described, but the operation of these relays at this time produces no further result as the upper contacts of answer-supervisory relay 1110 have been rendered ineffective upon the 5 operation of toll-to-toll relay 1108, and the lower contacts of the relay 1110 are ineffective because incoming-control conductor 1151 is not grounded at this time.

The equipment in the Rio de Janeiro exchange 10 responds during this call as explained in connection with the described call from Sao Paulo to Rio de Janeiro.

When the conversation has been completed and the connection is to be broken down, a prolonged release pulse of 60-cycle-modulated, 1,000-cycle current is transmitted by the outgoing repeater in the Campinas exchange, which pulse is received simultaneously by the impulse repeater IR-1 Fig. 2; by the impulse repeater IR-2, Figs. 20 2 and 11; and by the impulse repeater IR-4, Figs. 2 and 14. This release pulse has the effect in the impulse repeater IR-1, incoming from the Campinas exchange, described in connection with a call in reverse direction through the impulse 25 repeater IR-2. In the impulse repeater IR-2, the prolonged energization of signal-repeating relay 1123 results in the restoration of incoming release relay 1121. Since relay 1120 is restored, the only effect produced at this time, by the restoration of relay 1121 is the opening of the initial 30 circuit of release relay 1105, over the incoming C lead from ground supplied by the toll line selector. When this occurs, release relay 1105 restores, permitting relays 1106 and 1107 to restore. The restoration of relay 1107 being delayed by the previously described operation of the weighted-armature relay 1106, circuits are closed (through contacts of the actuated relay 1107 and through contacts of restored release relay 1105) for preparing and sending relays 1128 and 1129 whereupon relays 1128 and 1129 operate pursuant to the transmission of a prolonged release pulse from the repeater IR-2 over the toll line TL-4.

Sequence relay 1113 is operated by sending relay 1129 to lock itself to conductor 1150 and to maintain release relay 1105 disconnected from the C terminal 1100 until the repeater is completely cleared out.

When the relay 1128 operates it opens the talking conductor to isolate the repeating coil 1175 and the receiving conductors 1162 from the toll line TL-4, thereby terminating the application of release current to the toll line TL-4 as received from the repeater in the Campinas exchange. At the same time, preparing relay 1128 permits direction-transfer relay 1202 to restore and thereby cause 60-cycle-modulated, 1,000-cycle current to be impressed on the sending leads 55 1161. With sending relay 1129 operated, this signal current is transmitted over the toll line TL-4. In this way, upon the interruption of the release current from the originating exchange, release current starts to be sent out from the repeater IR-2 with a discontinuity so small that the incoming signal and signal repeating relays in the Rio de Janeiro exchange do not have time to restore.

While the release pulse is being transmitted 60 from the repeater IR-2, the release pulse being transmitted from the Campinas exchange is terminated and the repeater IR-1 of Fig. 2 clears out and permits the associated toll first selector TFS-2 to clear out and thereby permit the release of the toll line selector TLS-2 of Figs. 2

and 8 to take place and free the repeater IR-2.

Relay 1107 remains operated, and the release pulse continues to be transmitted, until the amplitude of vibration of the weighted armature of release-pulse timer relay 1106 has decreased 5 sufficiently to permit relay 1107 to restore and open the circuits of relays 1128 and 1129. Relay 1107 also removes ground potential from holding conductor 1150, completing the clearing out of the repeater by permitting the locked relays to 10 restore.

The apparatus in the Rio de Janeiro exchange clears out in the usual manner responsive to the transmission of the release pulse which is started by current incoming from the Campinas exchange 15 and completed by current transmitted from the Sao Paulo exchange by the repeater IR-2 and the associated tone unit TU-2. The release pulse is slightly longer under the described circumstances and it normally is, but this causes 20 no unwanted operation.

Calls to and from the Santos exchange by way of Sao Paulo are handled in the same way as calls to and from the Campinas exchange by way of Sao Paulo.

25

K. AUTOMATIC TIMED CLEAROUT OF THE REPEATER IR-2

Arrangements are provided for clearing out the repeater IR-2 in the event that a spurious seizing pulse is received. It will be understood that transient electrical conditions may be set up in the toll line TL-4 from outside causes, an electrical storm for example, which may simulate the transmission of a seizing pulse from the distant 30 exchange causing a momentary operation of incoming signal relay 1205. Under this condition, signal-repeating relay 1123 may operate as in the case of the receipt of a seizing pulse to bring about the operation of selector-seizing relay 1120 35 and the resulting operation of loop test and auxiliary relays 1119 and 1118.

In order to provide for the clearing out of the repeater IR-2 under this condition, the common time-pulse lead 1176 and the time-pulse relay 45 1132 are provided. Time pulse relay 1132 is another of the differential, stored-energy counting relays. When auxiliary relay 1118 operates upon the taking for use of the repeater IR-2 in an incoming call, it connects the time pulse lead 50 1176, through contacts of toll-to-toll and ring-control relays 1108 and 1116 to the junction of the windings of time-pulse relay 1132. Time-pulse lead 1176 is preferably arranged to be grounded momentarily once every few seconds. 55 This lead remains connected to time pulse relay 1132 until ring-control relay 1116 operates responsive to the first operation of incoming repeating relay 1124, which results upon the receipt of the first dial impulse over the toll line 60 TL-4. Therefore, ring control relay 1116 operates to disconnect the time-pulse lead before two pulses can be received upon the time pulse lead following the seizure of the repeater in a normal call. Subsequently, the restoration of auxiliary 65 relay 1118 further disconnects the time pulse lead 1176 so as to maintain it disconnected after the ring control relay 1116 has been restored upon the establishment of the line-supervisory condition hereinbefore discussed. At the same time, 70 the locking circuit of time-pulse relay 1132 is opened at contacts of loop-test and line-supervisory relays 1119 and 1109 whereby this relay is restored in the event that it has been operated because of the receipt of a time pulse before the 75

operation of ring-control relay 1116 and the following the operation of auxiliary relay 1118.

Now, when the repeater IR-2 is taken for use under the abnormal conditions previously discussed 5 no dial pulses are received and incoming repeating relay 1124 is therefore not operated to cause ring control relay 1116 to operate and lock. Under this condition, the first time the time-pulse lead 1176 becomes grounded energy is stored in 10 time-pulse relay 1132, with the result that this relay operates upon the cessation of the time pulse and locks itself to the grounded holding conductor 1150 through the lower contacts of the actuated loop-pulse relay 1119, and contacts of 15 relays 1109, 1103, and 1101. Then, the next time the time-pulse lead 1176 becomes grounded (perhaps a few seconds later) signal-repeating relay 1123 is operated over the time pulse lead and through contacts of the now-actuated time-pulse 20 relay 1132. Relay 1132 is operated long enough to permit incoming release relay 1121 to restore and release selector-seizing relay 1120. Series relay 1104 is operated incidentally at the lower contacts of relay 1123 to close a local holding 25 circuit for the lower winding of relay 1119 which circuit is opened upon the restoration of relay 1120. Relay 1119 remains actuated through its upper winding in the loop control circuit.

With selector seizing relay 1120 unlocked 30 and restored, ground potential is disconnected from holding conductor 1150 upon the restoration of signal-repeating relay 1123 when the time pulse ends. Relays 1118 and 1132 thereupon restore. Relay 1118 disconnects the time-pulse lead from 35 relay 1132, and also opens the loop. Relay 1119 is thereupon permitted to restore, and the associated incoming selector is permitted to clear out. It is to be noted that time-pulse lead 1176 is opened by toll-to-toll relay 1108 to prevent unnecessary operation of relay 1132 when an incoming toll call is extended to a second dialing toll line.

L. AUTOMATIC TIMED CLEAROUT OF THE REPEATER IR-4

45 Similarly, the impulse repeater IR-2, Fig. 14, may be cleared out by a provision including the common time-pulse lead 1468 and the time-pulse relay 1432. The pulses delivered by time-pulse 50 1468 are sufficiently spaced that two can not be received during the time auxiliary relay 1418 is held energized in a normal call. It is to be noted that the locking circuit of time-pulse relay 1432 is directly controlled by contacts of auxiliary relay 1418.

55 In the clearing out of the repeater IR-4 following the receipt of a spurious seizing pulse, relay 1432 is operated responsive to the first pulse over lead 1458, and the pulse lead is transferred 60 at the end of this pulse to the signal-in conductor 1453. Therefore, upon receipt of the next time pulse (some seconds later) signal-repeating relay 1423 operates to restore incoming-release relay 1421 and thereby permit selector seizing relay 1420 to restore, following which relays 1419 and 1418 restore. Relay 1432 restores responsive 65 to the restoration of relay 1418. The repeater is cleared out and returned to normal condition when signal-repeating relay 1423 restores responsive to the restoration of relay 1432.

M. GUARDING A DEFECTIVE AUTOMATIC TOLL LINE

70 Provisions are made (as described in connection with manual toll-line circuit TLC-4, Fig. 4,) whereby an operator may cause a toll line to be

guarded against further seizure in her exchange and may also cause the application of a guard tone to the toll line to warn an operator who may take it for use at the distant end that the toll line is defective. This operation may occur 5 when an operator takes a toll line for use and finds that she is unable to secure a satisfactory grade of service thereover.

Guard relay 1125 of the repeater IR-2, Fig. 11, is provided to guard the automatic toll line 10 TL-4 from seizure in Sao Paulo when the toll line is out of order. When this guard relay is operated responsive to the application of a negative potential to the negative talking conductor, by a key such as K-7, Fig. 5, it locks itself over 15 conductor 1147 extending to the test panel; it transfers the C terminal 1100 from the winding of release relay 1105 to ground so as to render the repeater IR-2 non-selectable and to operate chain relay 1135; it disconnects ground potential 20 from the inner lower armature of signal-repeating relay 1123 to prevent operation of selector-seizing relay 1120 in the event that toll line is seized in the distant exchange; and it connects the illustrated common guard-tone leads to the 25 switchboard side of the toll line TL-4 to impress a warning guard-tone on the toll line to inform an operator in Rio de Janeiro of the defective condition of the toll line in the event that the toll line is seized from the other end 30 thereof.

It is to be noted that conductor 1146 is provided and extended from the upper winding of relay 1125 to the test panel, whereby guard relay 1125 may be actuated from the test panel when 35 so desired, and it may be held operated from the test panel over this lead after the locking circuit of the relay has been opened over conductor 1147 to permit a signal lamp lighted by means of this conductor to become extinguished. 40

The guard relay 1425, included in the impulse repeater IR-4, is operable over the ring-conductor of the multiple jack J2 Fig. 19 through the operation of a guard key such as key K-14 Fig. 21. In addition to applying guard tone to 45 the talking conductors; locking itself over conductor 1447 extending to the test panel; and removing ground potential from the inner lower armature of signal repeating relay 1423, guard relay 1425 connects a negative potential through 50 the illustrated 200-ohm resistor to the sleeve conductor S extending to the sleeve of the jack J2 and the multiples thereof, thereby marking the repeater IR-4 and the associated toll line busy at the jack J2 and the multiples thereof. 55

N. TESTING THE AUTOMATIC TOLL LINES

Since the cooperation of a number of circuits is required in completing connection from Sao Paulo to lines of the Rio de Janeiro exchange, 60 it is advantageous that arrangements be provided whereby a test operator in Sao Paulo can extend the connection to a toll line leading to Rio de Janeiro and ascertain quickly whether or not the toll line and associated equipment in 65 Rio de Janeiro are in condition to function properly. Preferably, a group test connector is provided for the use of the test operator through which connection can be extended to any desired one of the toll lines extending from Sao Paulo 70 to Rio de Janeiro. These test connectors are not shown, as they form no part of this invention. The testing arrangements, however, will be described with reference to the automatic selection of a random one of the toll lines from 75

the Sao Paulo toll board equipment illustrated in Fig. 5. The principal difference between a test made from the toll board and a test made from a special test position through a test connector is that the toll board operator is unable to predetermine with which toll line connection will be made, because the automatic-toll-line selectors operate as previously described to make connection with the first idle toll line.

10 For test purposes, the testing operator dials the digit 9 following the seizure of the toll line, with results which will be described.

It may be assumed that the toll operator at the position of Fig. 5 extends connection by way 15 of the cord circuit CC-1, Fig. 5, toll first selector TFS-1, Fig. 6, and the automatic-toll-line selector TLS-2, Fig. 8, to the toll line TL-4 by way of the impulse repeater IR-2, Fig. 11. When this connection is effected, the repeater 20 IR-2 transmits the described seizing pulse over the toll line TL-4 to the repeater IR-4, Fig. 14. This repeater responds as previously described to cause a preselected coder to be seized through the preselector PS, Fig. 15, which coder may be 25 assumed to be the coder CR of Fig. 16. This coder is thereupon prepared for operation as previously described.

In addition, the line circuit LC-2, Fig. 20, is caused to function as described hereinbefore 30 pursuant to the taking for use of a toll first selector and of a register sender to enable the connection to be further extended.

In order to cause the test condition to be imposed, the operator at position in Fig. 5 dials the 35 digit 9, causing a series of nine impulses to be transmitted over the toll line TL-4 and to be repeated and by the incoming repeating relay 1424 to the seized coder CR.

The operator may now restore her keys K-6 40 and K-3, and await the receipt of a supervisory signal indicative of the fact that the equipment in Rio de Janeiro is in condition to function properly.

When the key K-6 is restored, the loop is 45 unbalanced in the described manner to permit cut-off-contact relay 1102 to actuate cut-off relay 1101 to dry the loop and extend the talking conductors. Ringing relay 1126 is then momentarily actuated by an automatic operation of relay equipment at the toll board to cause a ring-start pulse to be sent over the toll line and stored in ring-prepare relay 1415.

In the coder CR, Fig. 16, as will be observed 50 by referring to the code tables shown at Figs. 16A and 16B, the receipt of the digit 9 results in the operation of storage relays A and C of the digit-storing device DS-1. These relays prepare a circuit over conductor 1653 for the upper winding of the differential test-control relay 1601. This circuit is further prepared by the upper contacts of distributor relay 1621 when relay 1621 55 is operated following the transfer of the digit 9 from the counting relays of Fig. 16, part 1, to the digit storage device DS-1, Fig. 16, part 2.

The circuit for the upper winding of differential relay 1601 is completed over the conductor 60 65 1660, depending upon start relay 1636 having operated. The start relay 1636 operates dependent upon connection of a register sender in the Rio de Janeiro exchange to a selected toll first selector.

Upon the completion of the circuit of its upper winding, relay 1601 is operated to close a circuit for relay 1602. Relay 1602 operates and closes a 70 75 circuit for relay 1603. Relay 1603 thereupon locks

its lower winding to the holding conductor 1600, whereby it remains operated until the coder is again cleared out. A branch circuit exists for the lower winding of differential relay 1601 in parallel with the lower winding of relay 1603. 5 As a result, relay 1601 becomes demagnetized by the opposing effect of its lower winding. The weighted armature of relay 1601 is thereby released and permitted to vibrate for a substantial interval of time in order to maintain the associated relay 1602 operated for a sufficient length 10 of time to permit the next succeeding digit to be received and stored on the digit-storing device DS-2 in a normal call. Assuming for the moment that a normal call is being handled, the 15 operation of transfer relay 1622 which takes place at the end of the transfer of the second digit to the digit-storing device DS-2 opens the circuit of the upper winding of relay 1601, which circuit does not become reclosed until the coder is again 20 cleared out. When this occurs, relay 1601 is immediately reoperated from its lower winding to 25 retract its armature and thereby prevent relay 1602 from restoring.

In the test call being described, no further digit 25 pulses are received, and transfer relay 1622 is therefore not operated to open the upper winding of relay 1601. Under this condition, relay 1602 is permitted to restore when the amplitude of the vibratory armature of relay 1601 has fallen 30 off somewhat. With relay 1603 operated and locked, the restoration of relay 1602 results in the 35 opening of the associated pulse lead P, thereby permitting relays 1604 and 1605 to restore. The restoration of relay 1604 is followed by the restoration of release relay 1606 to remove ground potential from holding conductor 1600 and thereby clear out the coder CR. Relay 1603 remains operated for an interval after ground potential is removed from conductor 1600 so as to prevent the 40 immediate reclosure of the pulse lead P. Before relay 1603 restores, the pulse lead P is opened in the associated impulse repeater IR-4, Fig. 14, by an operation which will be now described.

When the pulse lead is opened in the coder, the 45 upper winding of group-test relay 1419 becomes deenergized, permitting the relay to restore. Upon restoring, relay 1419 closes a circuit through contacts of the actuated coder-seizing relay 1437 for the lower winding of supervisory relay 1422, 50 at the same time opening the circuit of auxiliary relay 1418 and the initial circuit of locked coder-seizing relay 1437. Relay 1419 also opens a further point in the initial circuit of its upper winding, whereby the already opened pulse lead is 55 opened at a second point. Auxiliary relay 1418 prepares a circuit for switch-over relay 1417 in addition to disconnecting the priming circuit of line-supervisory relay 1409 from contacts of relays 1422 and 1410. Line supervisory relay 1409 60 is permitted to operate as a result both of the restoration of auxiliary relay 1418 and of the operation of supervisory relay 1422.

When supervisory relay 1422 responds to the closure of the circuit of its lower winding upon 65 the restoration of test relay 1419, it closes a circuit through contacts of the non-operated relay 1410, for supervisory-pulse relay 1427. Relays 1427-1431 are therefore caused to go through the previously described cycle of operations, during 70 which a line-supervisory pulse is transmitted back over the toll line TL-4 to the Sao Paulo exchange. It is the receipt of this supervisory pulse at the test switchboard which indicates to the test operator that the toll line TL-4 and associ- 75

ated equipment in the Rio de Janeiro exchange are in operating condition.

Switchover relay 1417 is operated by preparing relay 1428 during the transmission of the supervisory pulse. Relay 1417 opens the locking circuit of coder-seizing relay 1437, in addition to closing a locking circuit for itself. Upon the restoration of coder-seizing relay 1437, the local circuit for the lower winding of supervisory relay 1422 is opened and is maintained open until the repeater is cleared out. Relay 1422 is thereupon permitted to restore.

Since counting relay 1410 is operated as previously described, incidental to the transmission of the line-supervisory pulse over the toll line TL-4, a further circuit is now closed through contacts of the restored supervisory relay 1423 and contacts of the actuated supervisory counting relay 1410 for the supervisory-pulse relay 1427, whereby an answer-supervisory pulse is sent back to the test switchboard. Relays 1411 and 1410 are restored incidental to the transmission of this answer-supervisory pulse, whereby the circuit of supervisory-pulse relay 1427 is maintained open thereafter. When the line supervisory pulse is received at repeater IR-2, line-supervisory relay 1109 operates to place a ground potential on the incoming EC lead to light the calling supervisory lamp at the switchboard of Fig. 5. This lamp is then extinguished when answer-supervisory relay 1110 responds to the answer-supervisory pulse to remove ground potential from the EC lead.

When the test operator breaks down the connection, the equipment involved is cleared out in the manner previously described. It may be pointed out that the disconnection of the sleeve lead S extending to the line circuit LC-2 of Fig. 20, upon the restoration of the selector-seizing relay 1420 results in the clearing out of the switching equipment seized through the line circuit LC-2.

O. TESTING THE REGISTER SENDER RS-1

Provisions for testing the register sender RS-1, principally to ascertain the frequency and ratio of the transmitted pulses, will now be described. These provisions include the test-transfer relay 1712 and the associated jacks 1726 and 1727, together with test plug 1728 and lamp 1729. When it is desired to test the register sender, the plug 1728 may be inserted into the jack 1727. When this plug is inserted, a circuit exists for the upper winding of relay 1712 in series with the test lamp 1729, through both contacts of the jack 1727 and of the plug 1728. Relay 1712 is energized sufficiently in this circuit to close a locking circuit for both windings in series at its inner lower contacts, to ground through the lower contact of jack 1729 and of plug 1728. On the closure of the locking circuit, relay 1712 is energized sufficiently to secure an actuation of all its contacts. The hold conductor 1722' is transferred from hold conductor 1722 to ground; test lead 1730 is disconnected so as to restore the preselecting relay 1705 and thereby guard the register sender; the output-control conductor 1723' is disconnected from control conductor 1723 to avoid unnecessary relay operations; the upper contacts of digit-stop conductor 1840 are rendered ineffective in order to secure the continuous transmission of pulses through contacts of jack 1726; and ground potential is placed on start conductor 1810 to start the interrupter relays 1837-

1839 into operation. Pulses are thereupon transmitted at the upper contacts of interrupter relay 1838 through the jack 1726 to any suitable ratio-indicating device, whereby the ratio of open interval to closed interval of these impulses may be determined.

The impulse-counting relays 1851-1860 are controlled from relay 1838 through the previously described action of priming relay 1850 to count the first ten operations of relay 1838, whereupon digit-stop relay 1840 is energized from the grounded hold conductor 1722' to lock itself through contacts of restart relay 1843. The relays 1851 to 1860 are cleared out upon the operation of digit-stop relay 1840, following which distributor control relay 1841 is operated to transmit impulses to secure the operation of relays 1851 to 1854 for the described purpose of controlling the inter-digit spacing.

Space-stop relay 1842 is next operated in a branch of the locking circuit of relay 1854 to again restore any operated ones of the counting relays 1851-1860 and prepares a circuit for restart relay 1843.

Restart relay 1843 is operated by the next pulse delivered by interrupter relay 1838, following which relays 1840-1843 are cleared out. Relays 1851 to 1860 being cleared out by this time, the relays 1851 to 1860 and 1840 to 1843 go through this same cycle of operations again, the cycle being repeated over and over again as long as the plug 1728 remains in the jack 1727.

In order to provide a reliable means of obtaining the frequency of operations of interrupter relay 1838, conductor 1724 is extended through contacts through the operated relay 1712 to the lamp 1729. Therefore upon the operation of digit-stop relay 1840, and continuing until the restart relay 1843 is operated to restore relays 1840 to 1842, the lamp is lighted. This lamp is lighted once for each complete cycle of operations of the relays 1851-1860 and 1840-1843. By observing the time required for a predetermined number of flashes of the lamp 1729 to occur, the frequency of the impulses delivered by relay 1838 may be very simply and accurately determined.

When the plug 1728 is removed from jack 1727, relay 1712 restores and permits the register sender to clear out.

It will be observed that no harm results in the event that the plug 1728 is inserted into the jack 1727 while the register sender is in use, as at that time ground potential on start conductor 1810 shunts the test winding of relay 1712, at the same time lighting the lamp 1729 steadily as a busy signal.

What is claimed is:

1. In a telephone system wherein toll calls originating in a first exchange are completed over toll lines through automatic switches in a second exchange controlled from the first exchange, means associated with a toll line over which said calls may be completed for transmitting current of an audible frequency, means for controlling the transmission of said current in accordance with digit values to transmit the desired number over the toll line, other means associated with said toll line for transmitting current of said frequency modulated by alternating current of a specific lower frequency, means in said distant exchange for demodulating said last-named current, and means controlled by the modulating component of said

- transmitted modulated current for performing one or more of the following functions: preparing the switching apparatus for operation in the distant exchange when the toll line is taken 5 for use; giving distinctive supervision in the originating exchange when the called line is reached; causing signalling of the called line to take place; giving distinctive supervision in the originating exchange when the called subscriber 10 replies and again when he replaces his receiver; and causing the established connection in the second exchange to be cleared out when the connection is cleared out in the first exchange.
15. 2. In a telephone system wherein toll calls originating in a first exchange are completed over toll lines through automatic switches in a second exchange controlled from the first exchange, means effective when an established 20 connection is to be cleared out for transmitting a current impulse of given characteristics over the toll line to the called exchange, responding means for clearing out the established connection responsive to the receipt of this impulse, 25 means effective while the connection is established for transmitting an impulse of the same characteristics except as to length, and means in the called exchange capable of distinguishing between the two impulses as to length and effective 30 for signalling the called subscriber responsive to the last said impulse instead of clearing out the connection.
3. In a telephone system wherein toll calls are set up from a first exchange over toll lines and 35 through automatic switching apparatus in a second exchange to called lines therein, said automatic switching apparatus being prepared for use and selectively actuated responsive to pulses of alternating current transmitted over a toll line from the first exchange, there being a visual 40 supervisory device at the toll board in the first exchange, means responsive to a busy condition at a trunk group in the second exchange and also responsive to a busy condition of the called line 45 in the second exchange for transmitting a succession of alternating-current pulses back over the toll line to the first exchange, and means responsive to these pulses for flashing the said supervisory device to indicate the busy condition.
4. In a telephone system as claimed in claim 3, 50 means for transmitting the pulses indicative of a busy condition at a trunk group at one rate, while the pulses transmitted indicative of a busy called line are at a distinctively different rate, 55 the said means in the first exchange for flashing the supervisory device being effective to flash the said device at a rate proportional to the rate of reception of pulses, whereby the operator is informed as to which of the two busy conditions obtains.
5. In a telephone toll system, means for setting up connections from a toll board in a first exchange over toll lines and through automatic switching apparatus located in a second exchange 60 to called lines therein, said automatic switching apparatus being responsive to the transmission of alternating-current pulses over the toll lines to select the desired line indicated thereby, means effective responsive to the 65 countering of a busy condition at a trunk group or at the called line in the second exchange for transmitting successive pulses of alternating current back over the calling toll line to the first exchange, said pulses being audible in the telephone of the calling toll operator in the event 70 that she has her telephone connected, and means in the first exchange responsive to the said pulses of alternating current for giving the toll operator a flashing visual indication of the busy condition. 75
6. In a telephone toll system for setting up toll calls through automatic exchanges in tandem, a first exchange, a second exchange, and a third exchange, the said second exchange and the said third exchange being automatic exchanges, the second exchange being inter-connected with the first exchange and with the third exchange through alternating-current-dialing toll lines, each of said toll lines being provided with pulse-repeating apparatus in each of the exchanges in which it terminates, said repeating apparatus at the originating exchange being effective to repeat local pulses over the associated toll line as alternating-current pulses, the repeating apparatus in the called exchange being effective to repeat alternating-current pulses received over the toll line as appropriate switch-controlling pulses, means effective when a connection is set up from a first exchange to the second exchange by way of one of said toll lines for maintaining the repeating apparatus in operating condition throughout the time that the connection is established, whereby supervisory and ring-control pulses are appropriately repeated over the toll line, the arrangement for calling between the second exchange to the third exchange being similar to that for calling between the first exchange and the second exchange, and means effective when the third exchange is called by way of the second exchange and upon the interconnection of the two toll lines for disabling the repeating apparatus in the second exchange to permit the repeating apparatus in the first and third exchanges to cooperate directly over the two toll lines in tandem relationship in the further setting up and supervising of the connection. 30
7. In an alternating-current-dialling toll system, first, second, and third, exchanges; said second and third exchanges being automatic exchanges; means in the first exchange for causing automatic switching apparatus to be taken for use in the second exchange and for transmitting controlling alternating-current pulses over the toll line to the second exchange; repeating means in the second exchange responsive to said pulses for controlling the automatic switching apparatus to set up a connection to a desired line to the second exchange, there being similar arrangements provided for enabling switching apparatus in the third exchange to be controlled from the second exchange, the automatic switching apparatus in the second exchange being effective responsive to specific control pulses received from the first exchange to 40 extend connection to a toll line leading from the second exchange to the third exchange; and means effective from the establishment of the connection through the two toll lines in series, from the first exchange through the second exchange to the third exchange, for disabling the repeating apparatus in the second exchange to permit the repeating apparatus in the third exchange to be directly controlled from the first exchange over the two toll lines in tandem connection. 50
8. In an automatic-telephone toll-dialing system wherein automatic switching apparatus in a called exchange is controlled over a toll line by alternating-current control pulses transmitted 65

from a distant calling exchange to effect the desired connection, repeating apparatus in the called exchange for repeating the incoming alternating-current pulses to effect the desired control 5 over the automatic switching apparatus, means whereby the incoming talking conductors are normally open between the toll line and the automatic switching apparatus to avoid interference, and means automatically effective upon the 10 establishment of a connection with the desired called line for closing the talking conductors through from the toll line to the talking conductors of the actuated switch train.

9. In a telephone exchange system a network 15 of manual and automatic exchanges interconnected by toll lines, and the toll lines interconnecting automatic exchanges being arranged for alternating-current-dialling of the automatic switches in the distant exchange and for 20 the transmission and translation of alternating-current supervisory pulses over the toll line, the arrangement being such that a line-supervisory pulse is transmitted back to the calling exchange when the automatic switching apparatus has extended the connection to a called automatic line, while answer-supervisory pulse is transmitted back when the called subscriber replies, and a disconnect supervisory pulse is transmitted back when he again replaces his receiver, the line 30 supervisory pulse being utilized at the repeating apparatus associated with the toll line for terminating the dialling condition and placing the toll line in condition for conversation, as well as to light the supervisory lamp at the calling toll board, 35 and means effective when the automatic switching apparatus in a second exchange is controlled from a calling exchange to extend connection to a manual toll line leading to a manual exchange for automatically transmitting a line supervisory 40 pulse back over the toll line to the calling exchange, followed invariably by an answering supervisory pulse, whereby the operator in the originating exchange received dark-lamp answered supervision.

45 10. In a telephone toll system wherein exchanges are interconnected by dialling toll lines, means in a first exchange for taking a toll line for use and for transmitting series of alternating-current dial pulses thereover to a second exchange, automatic switching apparatus in the second exchange responsive to the transmitted dial pulses to set up a connection to a desired called line in the second exchange, means in the first exchange effective following the transmission 50 of the final dial pulses for transmitting a characteristic alternating-current pulse to initiate ringing on the called line, means in the second exchange for receiving and storing the characteristic ring-start pulse, supervisory means in the 55 second exchange for transmitting a signal when the connection has been extended to the desired line, and means responsive to the said signal indicative of the fact that the automatic switching apparatus has completed connection to the desired line for releasing the stored ring-start pulse in the switch train to initiate ringing on the called line.

11. In a telephone system wherein toll calls originating in a first exchange are completed over 70 toll lines through automatic switches located in a second exchange and controllable from the first exchange, the control of the automatic switches in the second exchange being exercised through the transmission of voice-frequency pulses over 75 the toll lines, means in the second exchange for

receiving and translating the voice frequency pulses into suitable switch-control pulses, the toll lines being provided with telephone repeaters for amplifying attenuated voice currents, there being a losser resistor associated with the distant end 5 of a toll line to introduce sufficient loss to prevent singing of the telephone repeaters, and means effective when the desired connection has been extended and controlled automatically through automatic switches of the second exchange for disconnecting the losser resistor.

12. In a telephone toll system wherein automatic switches are controlled over a toll line to complete desired connections, there being telephone repeaters interposed in the toll line for the 15 two-way amplification of attenuated voice currents, a loss device associated with the toll line to avoid singing of the toll line repeaters while the toll line is not in use and while a connection is being built up, and means controlled automatically from the train of interconnected switches for disabling the loss device when the connection has been completed.

13. In a telephone toll system wherein the toll lines are provided with telephone repeaters for the two-way amplification of attenuated voice currents, an attenuation pad for introduction in a toll line when the toll line is interconnected with a local line, means controlled over the connection built up to or from the toll line for causing said pad to be introduced or not depending upon whether the toll line is interconnected with a local line or with another toll line, automatic switching apparatus effective to extend connection to said toll line and effective responsive to control exercised over the toll line in an incoming call for extending connection from the toll line, repeating and translating apparatus associated with the toll line for enabling the control of the automatic switching apparatus thereover to be 40 effected, means included in said repeating and translating apparatus for maintaining said attenuation pad introduced while the automatic switching apparatus is being operated to extend a connection, and means controlled over the connection extended through the automatic switching apparatus for terminating the local control over the toll line pad to permit said pad to remain introduced in the toll line or not depending upon whether connection has been extended to 50 a local or to another toll line.

14. In a telephone toll system, a toll line extending from a first exchange to a second exchange, automatic switching apparatus in the second exchange operable responsive to alternating-current pulses transmitted from the first exchange to set up a connection to a desired line, means effective when the connection is to be broken down for transmitting a prolonged pulse of characteristic current over said toll line, a slow acting means in the second exchange for causing the connection to be broken down responsive to the receipt of a prolonged pulse but not responsive to receipt of a short pulse, means effective while the connection is established over the toll line and responsive to the operation of the ringing key at the calling toll board for transmitting current having the same characteristics as the release pulse current, and means associated with the outgoing end of the toll line in the first exchange for interrupting the ringing pulse in the event that the operator maintains the ringing key actuated for a substantial interval, whereby the characteristic current is not transmitted over 75

the toll line for a long enough interval to cause the connection to be released.

15. In a telephone toll system wherein connections built up over toll lines are supervised by the transmission of voice-frequency pulses, there being a pulse of voice frequency current transmitted as an answer-supervisory pulse when the called subscriber removes his receiver and another similar pulse transmitted as a disconnect-supervisory pulse when the called subscriber replaces his receiver, the transmission of the supervisory pulses from the called exchange to the calling exchange being under the joint control of a supervisory relay in the called exchange and pulse-counting apparatus, there being pulse-counting apparatus in the calling exchange for counting the received pulses and for alternately lighting and extinguishing the supervisory call lamp at the toll board responsive to the receipt 20 of alternate supervisory pulses, means in the second exchange effective in the event that the automatic switching apparatus therein has been operated over the toll line to extend connection to an operator's switchboard and responsive to a 25 ringing operation on the part of the operator at said switchboard to transmit a supervisory pulse back to the calling switchboard as a recall signal to the calling operator, and means automatically effective upon the termination of the ringing operation for transmitting a further signal back to the calling exchange to again extinguish the calling supervisory lamp.

16. In a telephone toll system, a toll board located in an automatic exchange, toll lines radiating from said automatic exchange and accessible from the toll board through automatic switching apparatus, the operation of the automatic switching apparatus being controlled over a balanced loop circuit, there being toll lines extending 30 from the said exchange to a second automatic exchange, such toll lines being equipped so as to enable the automatic switches in the second exchange to be pulse-controlled from the toll board in the first exchange, switching arrangements 35 automatically effective when connection is set up from the said toll board to a local line for opening the control loop when the connection has been completed, means associated with each of the 40 said toll lines extending to the said automatic exchange and including a differential relay in the control loop for opening the control loop, and means at the toll board effective when all of the 45 pulses necessary to control the automatic switching apparatus in the second exchange to set up a connection have been transmitted for unbalancing the control loop to enable the said differential relay to cause the control loop to be opened.

17. In a telephone toll system wherein two automatic exchanges are interconnected by toll lines, means at a toll board in the first exchange for transmitting dial pulses indicative of the second exchange and for transmitting further dial pulses indicative of the desired called line in the second exchange, automatic switching apparatus in the first exchange responsive to the transmitted dial pulses indicative of the second exchange for extending connection to an idle one of the interexchange toll lines, means responsive to the seizure of the toll line for transmitting a seizing pulse thereover to the second exchange, a group of coders in the second exchange common to the toll lines, a preselector interposed between said toll lines and said coders, means for causing said preselector to maintain 70 one of the said coders normally preselected,

means effective responsive to the receipt of a seizing pulse over one of said toll lines for connecting such toll line to a preselected coder and for causing the preselector to immediately pre-select another idle coder, repeating and translating apparatus associated with said toll line for causing the digit valves indicated by the subsequently transmitted dial pulses to be registered in said coder, automatic switching apparatus in the second exchange controlled in accordance 10 with the digit valves registered in said coder for extending the connection to the desired called line in the second exchange.

18. In a telephone system as claimed in claim 17, means associated with said preselector and effective when no coder is available for preselection for preselecting a busy-signalling device, and means effective in the event that a seizing pulse arrives over one of the toll lines while the busy signalling device is preselected for seizing 20 the busy signalling device, and means controlled from the seized busy signalling device for transmitting a characteristic busy signal back over the toll line to the calling exchange.

19. In a telephone toll system, a first exchange, 25 a second exchange, said second exchange being an automatic exchange, toll lines interconnecting said exchanges, register senders in the first exchange common to said toll lines for registering digits of a called number in the second exchange and for retransmitting the digits of the called number over a toll line to effect operation of automatic switches in the second exchange, means in the first exchange for taking a register sender and a toll line for use, means 30 effective when the digits of the called number have been registered and retransmitted over said toll line and the automatic switches have completed the connection to the called line for transmitting a momentary line supervisory pulse back over the toll line to the first exchange, and means 35 responsive to said pulse for returning said register sender to common use.

20. In a telephone system, a register sender controllable from an operator's switchboard and having registering capacity of a given number of digits, some of the telephone numbers containing digits in excess of the said registering capacity, means in said register sender for enabling registers therein to be used a second time after the digits initially registered thereon have been 40 retransmitted, and means for notifying the operator at said switchboard when the registers are in condition to record a second group of digits.

21. In a register sender including means for transmitting and counting successive trains of digit pulses, a group of pulse-counting relays, means for transmitting outgoing digit pulses and for sending pulses to the counting relays, means effective when the counting relays have counted the desired number of digit pulses for terminating the transmission of outgoing pulses, while permitting the transmission of local pulses to continue, and means effective responsive to the counting of a predetermined number of spacing 50 pulses by the relays used to count digit pulses for restarting the transmission of digit pulses.

22. In a register sender as claimed in claim 21, means for enabling the number of counting relays required to be operated in the inter-digit 55 interval to be readily adjusted.

23. In a telephone system wherein automatic switching apparatus in a second exchange is controlled over alternating-current-dialling toll lines from a first exchange to extend connections 70

to called lines in the second exchange, means in the second exchange responsive to the receipt of a prolonged pulse of alternating current from the first exchange for clearing out an established connection, the receipt of said pulse being subject to interference in the event that the called subscriber actuates his hook switch one or more

times during the receipt thereof and therefore superimposes strong induced currents on the talking conductors, and means responsive at the beginning of the receipt of the prolonged pulse for disconnecting the called line from the receiving apparatus to avoid interference. 5

JOHN WICKS.
